Application May 16, 1940, Serial No. 335,560

68 Claims. (Cl. 179—26)

The present invention relates to telephone systems and more particularly to improvements in remotely controllable line switching apparatus for selectively interconnecting the lines terminating at a switching point.

Line switching equipment of this type is frequently used when only a small number of subscribers' lines are served by the equipment and the equipment is necessarily located at a point remote from central exchange facilities. In certain installations of this character it is desirable from the standpoint of initial cost and cost of maintainance to provide an arrangement wherein no current source is required at the switching point for supplying current to the component elements of the switching equipment. This is particularly true of the equipment provided at a switching center in a rural area for effecting connections between the small number of lines required to serve the subscribers of the area.

It is an object of the present invention, therefore, to provide in a telephone system of the character indicated, an improved and exceedingly simple arrangement whereby the line switching equipment provided at a switching center may selectively be controlled either directly or through an automatic switch train from an operator's position in a distant central exchange, and wherein current for energizing the switching equipment at the switching center is supplied entirely over the control trunk extending to the switching center.

It is another object of the invention to provide a telephone system of the character described, wherein the apparatus provided in the exchange terminating the control trunk for controlling the switching equipment located at the switching center is arranged selectively to impress control voltages designating different lines terminating at the switching center on the different sides of the control trunk.

It is a further object of the invention to provide a telephone system of the character described, wherein the apparatus provided in the exchange terminating the control trunk for controlling the switching equipment provided at the switching center is arranged selectively to impress control voltages having different polarities upon the different sides of the control trunk in order to effect the desired line switching operations.

It is still another object of the invention to provide a system of the character described, wherein the apparatus provided for selectively impressing the different control voltages on the control trunk is selectively controllable through an automatic

switch or an automatic switch train from a distant telephone station, such, for example, as a control operator's position in a distant central office.

5 It is a further object of the invention to provide in a system of the character described, an improved arrangement for identifying calling ones of the lines terminating at the switching center when the calls are routed to the control operator's position.

10 It is a still further object of the invention to provide in a system of the character described, an improved line lockout arrangement for guarding the control trunk, when occupied with a call, against seizure over another of the lines terminating at the switching center.

15 In the illustrated embodiments of the invention, the switching equipment provided at the switching centers may selectively be controlled

20 over control trunks directly from an operator's position in the exchange terminating the control trunk, or may be controlled through the automatic switching equipment of a tandem exchange terminating the control trunk from a control

25 operator's position in a distant central office. In each embodiment of the invention, a group of switching relays is provided at the switching center for performing the required line switching operations. These relays are all energized and controlled over the control trunk extending to the distant exchange.

30 In one embodiment of the invention, only two subscribers' lines are terminated at the switching center, provisions being made whereby ringing currents transmitted over these lines are in turn projected over the different sides of the control trunk to the distant exchange.

35 In the other embodiment of the invention, three subscribers' lines are terminated at the switching center, and provisions are made for rectifying ringing voltages impressed upon two of these lines when calls are initiated thereon, and for impressing the rectified ringing voltages upon the same side of the control trunk with different polarities.

40 In the disclosed arrangements where-
45 in the control trunks are terminated directly at an operator's position in a distant exchange, the ringing voltages transmitted over different sides of the control trunks, and of different polarities, are utilized to control apparatus for selectively

50 energizing signal devices individually corresponding to the subscribers' lines, thereby to identify the lines upon which the calls are initiated. In the arrangement wherein the control trunks terminate at a tandem exchange, ringing current, regardless of the character thereof, is utilized for

the purpose of causing a finder switch to seize the calling control trunk and to route a connection therefrom to the control operator's position located in the distant central office. This apparatus is also arranged selectively to impress control voltages upon the two sides of the calling control trunk for the purpose of controlling the line switching relays at the switching center terminating the calling line to effect a lockout of all lines terminating at the switching center, other than the calling line.

In the disclosed arrangements, wherein the control trunks are directly terminated at a control operator's position, the operator, upon answering a call routed over a calling control trunk, automatically effects the application of a predetermined control voltage to one side of the control trunk, whereby the relays located at the distant calling switching center are caused to lock out all lines except the calling line, and to connect the calling line to the control trunk. The equipment provided at the control operator's position in association with the calling control trunk may also selectively be controlled by the operator to impress another predetermined control voltage upon the control trunk for the purpose of causing the relay equipment in the distant switching center to connect the desired called line to the control trunk, thereby to set up a talking circuit between the calling and called lines. In the other disclosed arrangement, wherein the equipment provided at the switching center is controllable through a tandem exchange from an operator's position located in a central office, the operator, upon answering a call routed over one of the control trunks, may directly control impulse-responsive apparatus provided in the tandem exchange through the automatic switching equipment of the tandem exchange, selectively to impress the control voltage designating the called line upon the control trunk extending to the calling or called switching center to operate and establish a connection between the called line and the control trunk.

Further features of the invention relate to the particular arrangement of the circuit elements, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawings in which Figures 1 and 2, when placed end to end in the order named, illustrate a telephone system having certain features of the present invention embodied therein, Figs. 7 and 8, when placed end to end in the order named, illustrate a second embodiment of the invention, and Figs. 3, 4, 5, 6, 7, 9, 10, 11 and 12, when combined in the manner illustrated in Fig. 13, illustrate a more elaborate telephone system wherein the switching centers shown in Figs. 1 and 7 are controllable through the automatic switching apparatus of a tandem exchange from a control operator's position in a remote central office.

Referring now more particularly to Figs. 1 and 2 of the drawings, the system there illustrated comprises a central office in which is provided an operator's position 30, a distantly located switching center or rural community exchange 10, and a trunk 31 interconnecting the operator's posi-

tion with the switching center. The switching center terminates three subscribers' lines 11, 12 and 13, which may be of the single party or multiparty type, as desired, or as the subscriber requirements and the number of subscribers in the area served by this center dictate. One or more of the enumerated lines may be of the paystation type if desired. The lines 11, 12 and 13 are illustrated as serving the substations A, B and C, respectively, each of which is of the local battery type. Thus, the substation A is illustrated as comprising a transmitter 20a, a receiver 21a, an induction coil 23a, and a local battery 27a, which are arranged to be interconnected through operation of a hook switch 22a to form a substation of the well-known anti-side-tone type. For the purpose of selectively signaling the substations associated with the line 11, assuming this line to be of the multiparty type, and of signaling the operator attending the operator's position 30, a hand generator 25a of the well-known magneto type is provided at the substation A. This substation also includes a ringer 24a, which is bridged across the conductors of the line 11 to be energized by ringing current transmitted over this line. The apparatus provided at the substations B and C is in all respects identical with that provided at the substation A and, accordingly, corresponding reference numerals have been used to identify corresponding parts of the three circuits.

The equipment provided at the switching center 10 includes automatic switching apparatus for selectively connecting the three subscribers' lines 11, 12 and 13 to the trunk 31 extending to the operator's position 30 in the distant central office. This apparatus comprises five relays R100, R110, R120, R130 and R140, the last three of which are line switching relays of the slow-to-operate type and individually corresponding to the lines 13, 11 and 12, respectively. The relays R120, R130 and R140 are effectively polarized by unidirectional conductive devices in the form of rectifiers 105, 114 and 146, respectively. Preferably these rectifiers are of the well-known dry disc or copper oxide type. The line switching relays R120, R130 and R140 are arranged to be energized over circuits including the trunk conductors 31a and 31b and the windings of a line balancing coil 150. The windings of this coil are of high impedance and, accordingly, serve to block the flow of alternating current through the windings of the line switching relays.

The trunk 31 terminates at the central office in a trunk circuit 35, which includes a repeating coil 200 and three signal lamp control relays R200, R210 and R220, which are individually energized in response to the initiation of calls on the lines 13, 11 and 12, respectively. More specifically, the relay R200 is polarized by a shunting unidirectional conductive device 203 to respond to rectified ringing voltage of one polarity transmitted over the trunk conductor 31a, and the relay R210 is polarized by a shunting unidirectional conductive device 213 to respond to rectified ringing current of the opposite polarity transmitted over the trunk conductor 31a. The two unidirectional conductive devices 203 and 213 are also preferably in the form of dry disc or copper oxide rectifiers. The apparatus embodied in the trunk circuit 35 includes three additional relays R230, R240 and R250, which are provided for selectively impressing voltages of different polarities upon the two sides of the trunk 31 in order selectively to energize the line switching

relays R120, R130 and R140 provided at the distant switching center. In this regard it is pointed out that the exchange battery conventionally provided at the central office and having its positive terminal connected to a grounded bus is utilized as one source of current for energizing the line switching relays at the switching center 10. An auxiliary direct current source is also provided, this auxiliary source having its negative terminal connected to the grounded bus and having its ungrounded positive terminal connected to the right terminal of the resistor 257. The switchboard side of the repeating coil 260 is multiplied to three line jacks 265, 266 and 267, which individually correspond to the lines 11, 12 and 13. These jacks have associated therewith signal devices in the form of lamps 268, 269 and 270, which also individually correspond to the lines 11, 12 and 13.

For the purpose of handling calls routed to the operator's position 30, this position is equipped with an operator's cord circuit, which includes an operator's telephone set 271, call and answer plugs 277 and 280, a drop 272 and ringing control keys 275 and 279. These keys include contacts connected to the respective terminals of an alternating ringing current generator 276, and may selectively be operated for the purpose of impressing voltage of this generator upon the tip and ring contacts of the plugs 277 and 280. Current for energizing the transmitter provided in the operator's telephone set 271 is supplied from the exchange battery through the windings of a battery feed coil 273.

Briefly to consider the operation of the system illustrated in Figs. 1 and 2 of the drawings, it is pointed out that calls initiated on the lines 11, 12 and 13 are forwarded to the operator's position 30 to cause the energization of the signal lamps 268, 269 and 270, respectively. A calling subscriber, in initiating a call, is expected to monitor his line in order to determine the idle or busy condition thereof before operating his hand generator to transmit ringing current over the line. Thus, if a call is initiated at the substation A, for example, the receiver 21a is removed from its supporting hook, whereby the hook switch 22a is caused to operate to connect the transmitter 20a and the receiver 21a to the line 11. After ascertaining that the line is idle, the calling subscriber may initiate the call by operating the hand generator 25a. In response to this operation the switch spring 26a is moved out of engagement with its associated lower contact and into engagement with its associated upper contact to complete a circuit for transmitting ringing current over the line 11. The path traversed by this current extends from the lower terminal of the generator 25a by way of the line conductor 11b, the contacts 134, the winding of R110, the condenser 106, the conductor 11a, and the switch spring 26a to the upper terminal of the generator 25a. When energized over this circuit the relay R110 operates to complete, at its contacts 111, an obvious path for short-circuiting the condenser 106. At its contacts 113, the relay R110 opens a point in the circuit for energizing the relay R130. At its contacts 112, the relay R110 completes a circuit for transmitting positive half-cycles of the ringing current over the conductor 31a of the trunk 31 to energize the upper winding of the relay R210. More specifically, the relay R210 is, following operation of the relay R110, energized by pulsating direct current over a circuit which extends from ground

5 by way of the rectifier 114, the contacts 112 and 134, the conductor 11b, the windings of the generator 25a, the switch spring 26a, the conductor 11a, the contacts 144, 124 and 111, the conductor 31a, the upper winding of R210, the rectifier 203, and the contacts 236, 245 and 255 back to ground. It will be noted that the rectifier 213 connected in shunt with the upper winding of the relay R210 is so poled that it will not pass current of the polarity transmitted through the rectifier 114 over the conductor 31a of the trunk 31. On the other hand, the rectifier 203 presents a very low impedance to current of this polarity and, accordingly, the upper winding of the relay R200, which is shunted by this rectifier, is effectively short-circuited. Thus, only the relay R210 is substantially energized by the rectified ringing current transmitted over the conductor 31a of the trunk 31. When thus energized the relay R210 first closes its X contacts 211 to complete a locking circuit for itself, this circuit extending from ground by way of the contacts 255, 245, 236 and 211, and the lower winding of R210 to battery. After this circuit is completed, the relay R210 completes, at its contacts 212, an obvious circuit for energizing the signal lamp 268 individually corresponding to the line 11. The illuminated condition of this lamp serves to inform the operator attending the operator's position 30 that a call is present on the trunk 31 and, more particularly, on the line 11, which should be answered.

In order more fully to describe the manner in which the signal lamps 268, 269 and 270 are selectively energized, it is pointed out that if the hand generator 25c is operated to project ringing current over the line 13 during the initiation of a call at the substation C, the relay R109 is energized over a circuit extending from the terminals of the generator 25c and including the conductors 13a and 13b, the contacts 122 and the condenser 104. This relay, in operating, opens, at its contacts 103, a point in the operating circuit for the relay R120 and completes, at its contacts 101, an obvious alternative path for short-circuiting the condenser 101. At its contacts 102, the relay R109 completes a circuit including the rectifier 105 for transmitting the negative half-cycles of the ringing current over the trunk line conductor 31a to energize the upper winding of the signal lamp control relay R200. More specifically, the circuit for energizing the relay R200 extends from ground by way of the contacts 255, 245 and 236, the upper winding of R200, the rectifier 213, the conductor 31a, the contacts 101, 132 and 145, the conductor 13b, the windings of the generator 25c, the switch spring 26c, the conductor 13a, the contacts 122 and 102, and the rectifier 105 back to ground. The rectifier 105 is so poled that the current traversing this circuit will not pass through the rectifier 203 but is readily passed by the rectifier 213. Accordingly, the relay R200 is energized by the pulsating direct current traversing its upper winding. The action 55 of the rectifier 213 to pass the rectified ringing current transmitted over the line 13 effectively short-circuits the upper winding of the relay R210 so that this relay is not substantially energized. The relay R200, in operating, locks to ground through the contacts 254, 201, 236, 245 and 255. At its contacts 262, the relay R200 completes an obvious circuit for energizing the signal lamp 270, which corresponds to the line 13.

From the above explanation it will be apparent that the two relays R200 and R210 are operative

in response to oppositely poled half-wave ringing currents transmitted over the upper line conductor 31a of the trunk 31, selectively to control the energization of the signal lamps 268 and 270, which individually correspond to the lines 11 and 13. The signal lamp control relay R220, which corresponds to the line 12 and serves to control the signal lamp 269, on the other hand, is energized by alternating ringing current transmitted over the lower line conductor 31b of the trunk 31. Thus, if the hand generator 25b provided at the substation B is operated during the initiation of a call at this substation, ringing current is transmitted through the upper winding of the relay R220 over a circuit which extends from ground by way of the contacts 253, 244, 235 and 222, the upper winding of R220, the conductor 31b, the condenser 152, the contacts 131 and 121, the conductor 12b, the windings of the generator 25b, the switch spring 26b, the conductor 12a and the contacts 141 back to ground. When energized over this circuit, the relay R220 operates and locks to ground over a path including the contacts 221, 235, 244 and 253. At its contacts 223, the relay R220 completes a circuit including the contacts 235, 244 and 253 for energizing the signal lamp 269 which corresponds to the line 12.

In order to answer a call routed to the operator's position over the trunk 31 from one of the lines terminating at the switching center 10, the operator attending this position may insert one of the plugs 277 and 280 of her cord circuit in the jack which corresponds to the calling subscriber's line. Thus, if the signal lamp 268 is energized, indicating that a call is present on the line 11, the operator may insert the plug 277 in the jack 265. In response to this operation, negative battery potential is impressed upon the sleeve contact of the jack 265 through the resistor 278 to energize the relay R230. This relay, in operating, opens, at its contacts 235, a point in the above-traced locking circuit for the relay R220, and a point in the circuit for energizing the signal lamp 269. At its contacts 236, the relay R230 opens the locking circuit for the relay R210, and a point in the locking circuit for the relay R200. The relay R210 is thus deenergized and restores to open, at its contacts 212, the circuit for energizing the signal lamp 268. With the relay R230 operated, the locking circuits for all three of the signal control relays R200, R210 and R220, are held open. At its contacts 231, the relay R230 bridges the windings 261 and 262 of the repeating coil 260 across the conductors of the trunk 31 in series with the condenser 237. At its contacts 232, the relay R230 completes a path including the resistor 256, the contacts 232 and the winding 261, for impressing negative battery potential upon the trunk conductor 31a. When this path is completed, the slow-to-operate line switching relay R130, individual to the line 11, is energized and operates. More specifically, the circuit for energizing the relay R130 extends from ground through the rectifier 114 and by way of the contacts 113, the winding of R130, the upper winding of the balancing coil 150, the conductor 31a, the winding 261, the contacts 231 and 232, and the resistor 256 to the negative terminal of the exchange battery. The rectifier 114 included in this circuit is so poled that its resistance to current flow is substantially negligible. It will be noted that the relay R120 and the rectifier 105 are connected in parallel with the relay R130 and the rectifier 114. The rectifier 105 is, however, so poled that it blocks the flow of current through

the relay R120 when negative battery potential is impressed upon the trunk conductor 31a. Thus, only the relay R130 is energized. In operating, the relay R130 opens, at its contacts 131, 5 a point in the above-traced path for transmitting ringing current from the line 12 over the lower trunk conductor 31b to the relay R220 embodied in the trunk circuit 35. At its contacts 132, the relay R130 opens a point in the above-traced path for transmitting rectified ringing current from the line 13 over the trunk conductor 31a to the relays R200 and R210 embodied in the trunk circuit apparatus 35. At its contacts 134, the relay R130 similarly opens a point 10 in the above-traced path for transmitting rectified ringing current from the line 11 over the upper trunk conductor 31a to the relays R200 and R210. Thus, the circuits, individual to the lines 11, 12 and 13, for transmitting signaling currents over the trunk 31 to energize the relays R200, R210 and R220, are interrupted.

At its contacts 136, the relay R130 opens a point in one of the circuits for energizing the relay R120. At its contacts 137, the relay R130 25 prepares another circuit for energizing the line switching relay R120. At its contacts 133 and 135, the relay R130 connects the conductors of the calling line 11 through the condensers 151 and 152 to the conductors of the trunk 31 and, in so doing, establishes a communication connection between the calling substation A, for example, and the operator's telephone set 271. After this connection is established, the operator attending the operator's position 30 may 30 converse with the calling subscriber to ascertain the substation desired. If the call initiated at the substation A is of the revertive type, the operator will ascertain this fact by monitoring the connection for a short time interval.

If the calling subscriber desires the assistance of the operator in setting up a reverting call connection, the operator may either instruct the calling subscriber as to the code assigned to the desired substation and then retire from the connection by withdrawing the plug 277 from the jack 265, or she may signal the called substation directly by operating the ringing key 275 in accordance with the code assigned to this substation. In the latter case, ringing current is projected over the trunk 31 and the calling line 11 each time the ringing key 275 is operated to its off-normal position. The local circuit traversed by this current may be traced as extending from the left terminal of the ringing current generator 276 by way of the switch springs 275a, the tip contact of the plug 277, the tip contact of the jack 265, the repeating coil windings 264 and 263, the ring contact of the jack 265, the ring contact of the plug 277, and the contacts 275b to the opposite terminal of the ringing current generator 276. The alternating character of the current traversing this circuit causes, by induction, current to traverse a circuit extending from one terminal of the ringer provided at the called substation by way of the line conductor 11a, the contacts 133, the condenser 151, the trunk conductor 31a, the winding 261, the contacts 231, the condenser 237, the winding 262, the trunk conductor 31b, the condenser 152, the contacts 135, and the line conductor 11b to the opposite terminal of the ringer provided at the called substation. Thus, the ringer provided at the called substation is energized each time the ringing key 275 is operated by the operator handling the call. The coded character of the signals produced

through operation of the ringers provided at the substations associated with the line 11 serves to inform the called subscriber that his substation is being signaled and to inform the subscribers at the other substations that they are not to answer the call. In the event the signaling operation is performed at the calling substation A by the calling subscriber, the operator, upon ascertaining this fact, may release the operated switching equipment after the ringing operation is ended and the call is answered, by withdrawing the plug 277 from the jack 265. In response to this operation the relay R230 is deenergized and restores to open the above-traced circuit for energizing the relay R130 provided at the switching center 10. The relay R130, in releasing, disconnects the line 11 from the trunk 31. Thus, the apparatus provided at the switching center 10 and also that embodied in the trunk circuit 35 is fully released. If the called party is served by a substation line terminating at the central office, the operator attending the position 30 may extend the connection to the desired line in the manner conventionally followed in manual office practice.

If the call originating at the substation A is intended for a substation such, for example, as the substation B associated with the line 12, the operator handling the call at the operator's position 30 may obtain a connection with the desired line by inserting the other plug 230 of her cord circuit in the jack 266 corresponding to the line 12. In response to this operation, negative battery potential is impressed upon the sleeve contact of the jack 266 through the resistor 281 to energize the relay R240. The relay R240, in operating, opens, at its contacts 244 and 245, additional points in the above-traced holding circuits for the relays R220, R210 and R200. At its contacts 241, the relay R240 completes an obvious shunt across the operated contacts 231 of the relay R230. At its contacts 243, the relay R240 completes a path including the resistor 258 and the repeating coil winding 262 for impressing negative battery potential upon the lower trunk conductor 31b. When this path is completed, the relay R140 is energized and operates. More specifically, the circuit for energizing the relay R140 extends from the grounded terminal of the exchange battery provided in the central office by way of the rectifier 146, the winding of R140, the lower winding of the balancing coil 150, the conductor 31b, the winding 262, the contacts 243 and the resistor 258 to the negative terminal of the exchange battery. It will be noted that with the relay R130 operated, a parallel branch of the circuit just traced extends through the contacts 137, the winding of R120, the contacts 103 and the rectifier 105. The rectifier 105 is, however, so poled that it will not pass current through the winding of the relay R120 when negative battery potential is impressed upon the upper winding terminal of the relay R120. Accordingly, only the relay R140 is energized in response to operation of the relay R240 embodied in the trunk circuit 35. The relay R140, in operating, opens, at its contacts 141, 144 and 145, additional points in the above-traced signaling circuits. At its contacts 142 and 143, the relay R140 connects the conductors of the desired or called line 12 through the condensers 151 and 152 to the conductors of the trunk 31. Thus, a three-way connection involving the lines 11 and 12 and the trunk 31 is established.

After this connection is set up, the operator may monitor the called line for a short time in-

terval in order to determine the idle or busy condition thereof. Assuming the called line 12 is idle, the operator may signal the called substation B by operating the ringing key 279 in accordance with the ringing code assigned to the substation B. Two methods of signaling the called substation may be followed. Thus, the operator may instruct the calling subscriber to hang up, and then operate the ringing key 279 to transmit ringing current over both the calling and called lines. In this case the path traversed by the ringing current, each time the ringing key 279 is moved off normal, extends from the left terminal of the ringing current generator 276 by way of the contact springs 279a, the tip contact of the plug 230, the tip contact of the jack 266, the repeating coil windings 264 and 262, the ringing contact of the jack 266, the ringing contact of the plug 230, and the contact springs 279b to the opposite terminal of the ringing current generator. The alternating character of this current causes induced voltages to be developed in the repeating coil windings 261 and 262. Thus, ringing current is caused to traverse two branch circuits which include, in parallel, the ringers bridged across the conductors of the called line 12 and the ringers bridged across the calling line 11. Thus, the ringer 24b provided at the called substation B is energized over a circuit which extends by way of the trunk conductor 31a, the condenser 151, the contacts 142, the conductor 12a, the windings of the ringer 24b, the conductor 12b, the contacts 143, the condenser 152, and the trunk conductor 31b. After operating the ringing key 279 in accordance with the code assigned to the called substation B, the operator attending the position 30 may monitor the connection to ascertain whether or not the call is answered at the called substation. In this regard it will be apparent that a three-way communication connection is established between the calling substation A, the called substation B, and the operator's telephone set 271, when the call is answered at the called substation B and the calling subscriber again removes the receiver 21a from the supporting hook of the hook switch 22a.

An alternative method of signaling the called subscriber, which may be followed by the operator handling the call, is that of removing the answer plug 277 from the jack 265 before operating the ringing key 279 in accordance with the code designating the desired substation. In such case the relay R230 is deenergized to open the operating circuit for the relay R130 when the plug 277 is withdrawn from the jack 265. Thus, the two relays R230 and R130 are deenergized and restored. The relay R130, in releasing, disconnects the conductors of the line 11 from the trunk 31. Accordingly, when the key 279 is operated to transmit ringing current over the trunk 31, this current is only projected over the called subscriber's line 12 to energize the ringers provided at the substation served by this line. After the ringing operation is completed and the call is answered, the operator handling the call may again insert the plug 277 in the jack 265 to cause the sequential reoperation of the relays R230 and R130, whereby a three-way connection between the subscribers' lines 11 and 12, and the trunk 31, is again completed. Thus, a three-way communication circuit is established between the calling and called substations and the operator's telephone set 271.

If the call routed to the operator's position 30

from the calling substation A is intended for a substation, such, for example, as the substation C associated with the line 13, the operator may obtain a connection with the desired line 13 by inserting the plug 280 in the jack 267. In response to this operation, negative battery potential is impressed through the resistor 281 upon the sleeve contact of the jack 267 to energize the relay R250. This relay, in operating, opens, at its contacts 253, 254 and 255, points in the above-traced locking circuits for the signal lamp control relays R200, R210 and R220. At its contacts 251, the relay R250 completes an obvious shunt across the operated contacts 231 of the relay R230. At its contacts 252, the relay R250 completes a path including the resistor 251, the contacts 234 and 242, and the winding 262 for impressing the positive potential of the auxiliary current source provided in the central office, upon the lower trunk conductor 31b. In response to this operation, the relay R120, individual to the line 13, is energized and operates. More specifically, the circuit for energizing the relay R120 extends from the grounded negative terminal of the auxiliary current source by way of the rectifier 105, the contacts 103, the winding of R120, the contacts 137, the lower winding of the balancing coil 150, the conductor 31b, the winding 262, the contacts 242, 234 and 252, and the resistor 257 to the positive terminal of the auxiliary current source. It will be noted that a branch of this circuit extends through the relay R140 and the rectifier 146. The rectifier 146 is, however, so poled that it will not pass current through the relay R140 when the positive terminal of the auxiliary current source is connected to the trunk conductor 31b in the manner just described. Accordingly, only the relay R120 is energized. This relay, in operating, opens, at its contacts 121, 122 and 124, additional points in the previously traced signaling circuits. At its contacts 123 and 125, the relay R120 connects the conductors of the called line 13, through the condensers 151 and 152, to the conductors of the trunk 31. Thus, a three-way connection between the subscribers' lines 11 and 13, and the trunk 31, is established. After this connection is set up and when the operator actuates the ringing key 279 in accordance with the code assigned to the called substation C to project ringing current over the trunk 31, the ringer 24c provided at the called substation is energized. The circuit for energizing this ringer includes the conductor 31a, the condenser 151, the contacts 125, the conductor 13b, the windings of the ringer 24c, the conductor 13a, the contacts 123, the condenser 152, and the trunk conductor 31b. In this regard it will be recalled from the above explanation that, if the second described method of signaling the called substation is followed, the answer plug 277 is withdrawn from the jack 265 before the ringing operation is started. In such case, the relays R230 and R130 are deenergized and restore. These two relays, in releasing, open two points in the initially completed circuit for energizing the relay R120 and complete an alternative circuit for energizing this relay. This alternative circuit extends from the grounded negative terminal of the auxiliary current source by way of the rectifier 105, the contacts 103, the winding of R120, the contacts 136, the upper winding of the balancing coil 150, the trunk conductor 31a, the repeating coil winding 261, the contacts 251, 233 and 252, and the resistor 257 to the positive terminal of the auxiliary current

source. Thus, the control circuit for the relay R120 is shifted from the lower trunk conductor 31b to the upper trunk conductor 31a in response to the release of the relays R230 and R130, but the relay R120 is held energized to maintain the connection between the called line 13 and the trunk 31. It will be noted that a branch of the auxiliary circuit for energizing the relay R120 extends through the winding of the relay R130, the contacts 113 and the rectifier 114. The rectifier 114 is, however, so poled that it will not pass current through the winding of the relay R130 when the positive terminal of the auxiliary current source provided in the central office is connected to the upper trunk conductor 31a. Accordingly, only the relay R120 is energized over this auxiliary circuit. After the ringing operation is ended and the call is answered at the called substation, the operator may reinsert the plug 277 in the jack 265 to cause the reoperation of the two relays R230 and R130. In this regard it will be noted that the relay R230, in operating, first opens, at its contacts 233, the path over which the positive potential of the auxiliary current source is impressed upon the upper line conductor 31a before it completes, at its contacts 232, the previously traced path for impressing the negative potential of the exchange battery upon the upper trunk conductor 31a. The relays R130 and R230, in reoperating, open the auxiliary circuit for energizing the relay R120 and recomplete the initially traced operating circuit for this relay. The relay R130, in operating, again connects the calling line 11 to the trunk 31 to establish a three-way connection between this line, the called line 13 and the trunk 31.

The release of either of the two connections set up in the manner explained above is entirely under the control of the operator attending the operator's position 30. In order to signal the operator that the connection is no longer desired, the calling subscriber may operate the hand generator 25a, provided at the calling substation A, to transmit ringing current by way of the line 11, the trunk 31, and the repeater 260, thereby to energize the drop 272 embodied in the operator's cord circuit. Alternatively, the "ring-off" operation may be performed at the called substation. When the drop 272 is thus energized, it operates in a conventional manner to inform the operator that the connection is no longer desired. To release the connection the operator withdraws the plug 277 from the jack 265 and the plug 280 from the one of the two jacks 236 and 267 in which it is inserted. When the plug 277 is withdrawn from the jack 265, the relays R230 and R130 are sequentially deenergized and restore. Similarly, if the plug 280 is withdrawn from the jack 267, the relays R240 and R140 are sequentially released in a manner clearly apparent from the above explanation. Alternatively, if the plug 280 is withdrawn from the jack 267, the relays R250 and R120 are sequentially deenergized and released. Thus, when the plugs 277 and 280 are respectively withdrawn from the jacks corresponding to the calling and called subscribers' lines, all of the relays embodied in the trunk circuit 35 and all of the relays provided at the switching center 10 are caused to release. Thus, the equipment is conditioned to handle another call.

From the above explanation it will be apparent that, if the call routed over the trunk 31 to the operator's position 30 originates at the substation

B, for example, associated with the line 12, the operator will insert the plug 277 in the jack 266, in order to answer the call. In response to this operation, the relay R240 is energized over a circuit including the sleeve contact of the jack 266 and operates to open the locking circuits for the signal lamp control relays R200, R210 and R220. At its contacts 243, the relay R240 completes the previously traced path for impressing negative battery potential upon the trunk conductor 31b, thereby to energize the relay R140. The relay R140, in operating, opens the circuits for transmitting ringing current over the trunk 31, and, at its contacts 142 and 143, connects the calling line to the trunk 31. After this connection is established the operator may route the call to a desired substation associated with either of the two lines 11 and 13, by inserting the plug 280 in the jack 265, or the jack 267. In this regard it will be understood from the above description that, if the plug 280 is inserted in the jack 265, the relays R230 and R130 are sequentially energized. Further, the relay R130 functions to connect the line 11 to the trunk 31. On the other hand, if the plug 280 is inserted in the jack 267, the relays R250 and R120 are sequentially energized and the latter relay, in operating, connects the line 13 to the trunk 31 to establish the desired three-way connection. By way of completing the explanation, it is pointed out that, if the substation A, for example, associated with the line 11 is desired by the calling party, ringing current may be transmitted by way of the line 11 to energize the ringer 24a over a circuit which includes the trunk conductor 31a, the condenser 151, the contacts 133, the line conductor 11a, the windings of the ringer 24a, the line conductor 11b, the contacts 135, the condenser 152, and the trunk conductor 31b. The manner in which the desired substation is signaled, the talking circuit between the calling and called substations is established, and the operated switching equipment is released, will be clearly apparent from the preceding explanation.

If the call routed to the operator's position 30 originates at a substation such, for example as the substation C associated with the line 13, the signal device 270 associated with the jack 267 is energized and, accordingly, the operator will insert the plug 277 in the jack 267 to answer the call. In response to this operation, the relays R250 and R120 are sequentially energized in the manner previously explained. The relay R120, in operating, connects the calling line 13 to the trunk 31 to establish a communication connection between the calling substation and the operator's telephone set 271. After this connection is established the call may be extended to a substation associated with either of the two lines 11 and 12, in a manner clearly apparent from the above explanation.

Calls initiated on the central office subscribers' lines and routed to the operator's position 30 may be extended to the substations served by the lines 11, 12 and 13 under the control of the operator attending this position, in a manner which will readily be understood from the above description. Thus, to extend a call to the line 11, the operator may insert either of the two plugs 277 and 280 in the jack 265, to cause the sequential operation of the relays R230 and R130. The relay R130, in operating, establishes a connection between the line 11 and the operator's cord circuit, so that the operator may signal the desired substation by operating one of the two ringing

keys 275 and 279. Similarly, either of the two plugs 277 and 280 may be inserted in the jack 266 to cause the operation of the relays R240 and R140, whereby a connection is established between the subscriber's line 12 and the operator's cord circuit. Finally, if one of the plugs 277 and 280 is inserted in the jack 267, the relays R250 and R120 are caused to operate to establish a connection between the line 13 and the operator's cord circuit. From the foregoing description it will also be apparent that the line switching relays R120, R130 and R140, provided at the switching center 10, are selectively controlled in accordance with the polarities of the potentials impressed upon the two sides of the trunk 31. Thus, to energize the relay R120 individual to the line 13, positive potential of the auxiliary current source may be impressed upon either side of this trunk. To energize the relay R130 individual to the line 11, the negative potential of the exchange battery is impressed upon the upper trunk conductor 31a. Finally, the relay R140 individual to the line 12 is energized in response to the application of the negative potential of the exchange battery to the lower trunk conductor 31b. It will also be observed that, with any one of the relays R120, R130 and R140 operated, the corresponding line is connected to the trunk 31 and the other two lines are prevented from obtaining access to this trunk.

The system formed by combining Figs. 7 and 8 of the drawings is, in general, similar to that illustrated in Figs. 1 and 2 of the drawings and described above, and the same general method is used in handling the calls originating on the lines 14 and 15 serving the subscribers of the outlying community. In the system shown in Figs. 7 and 8, however, only two subscribers' lines are provided to serve the subscribers of the small community area. These lines may be of the single party, multiparty or paystation type and are illustrated as serving the local battery substations D and E, respectively. Since the two substations D and E are identical with the substations A, B and C, illustrated in Fig. 1 of the drawings, corresponding reference numerals have been used to identify corresponding parts of the various substation circuits. The two subscribers' lines 14 and 15 terminate at a remotely controlled exchange or switching center 70, which is connected by means of a trunk 55 with a distantly located central office. The switching center 70 comprises automatic switching apparatus in the form of a pair of slow-to-operate relays R700 and R710 for selectively connecting the two lines 14 and 15 to the trunk 55. More specifically, these relays individually correspond to the lines 15 and 14, respectively, and are arranged to be energized over circuits including the trunk conductors 55a and 55b, respectively, and the windings of a line balancing coil 720 from the current source provided in the central office. The windings of the coil 720 are of high impedance and accordingly function to block the flow of alternating current through the windings of the line switching relays R700 and R710. The trunk 55 terminates in the central office in a trunk circuit 80, which is associated with the operator's position 85. This trunk circuit includes a repeating coil 800, a pair of signal lamp control relays R810 and R820, and a pair of line switching control relays R830 and R840, the latter relays being arranged respectively to control the energization of the relays R710 and R700 provided at the switching center 70. The switch-

board side of the repeating coil 800 is multiplied to the line contacts of the two jacks 851 and 852 which individually correspond to the lines 15 and 14 and are located at the operator's position 85. These jacks have associated therewith signal devices in the form of signal lamps 853 and 854 which also individually correspond to the subscribers' lines 15 and 14. The operator's position 85 is further equipped with an operator's cord circuit which may be identical in arrangement with that illustrated in Fig. 2 of the drawings as being provided at the operator's position 30.

Briefly to consider the operation of the system illustrated in Figs. 7 and 8 of the drawings, if a call is initiated at the substation D, for example, the receiver 21d is removed from its supporting hook 22d, thereby operatively to associate the substation D with the line 14. After a connection is thus established to the line 14, the calling party may monitor this line to determine the idle or busy condition thereof. Assuming that the line is idle, the calling party may actuate the hand generator 25d for the purpose of signaling the operator attending the operator's position 85 in the distant central office. In response to operation of the generator 25d, the switch spring 26d is disengaged from its associated lower contact and operated into engagement with its associated upper contact to connect the output windings of the generator across the line 14. After this switching operation occurs, the ringing current developed through operation of the generator 25d serves to energize the upper winding of the relay R810 over a circuit extending from ground by way of the contacts 713, the conductor 14a, the switch spring 26d, the windings of the generator 25d, the line conductor 14b, the contacts 704, the condenser 705, the trunk conductor 55b, the upper winding of R810 and the contacts 811, 834 and 844 back to ground. When thus energized, the relay R810 operates and locks to ground over a path including the contacts 812, 834 and 844. At its contacts 812, the relay R810 completes an obvious circuit for energizing the signal lamp 854. The illuminated condition of this lamp serves to inform the operator attending the operator's position 85 that a call is present on the line 14 which should be answered.

In order to answer the call, the operator may insert the answer plug of her cord circuit in the jack 852. In response to this operation, battery potential is impressed upon the sleeve contact of the jack 852 to energize the relay R830. In operating, the relay R830, at its contacts 831, opens a point in the operating and locking circuits for the relay R820. At its contacts 834, the relay R830 opens the above-traced circuits for energizing the relay R810 and the signal lamp 854. When thus deenergized the relay R810 restores. At its contacts 832, the relay R830 completes a path for bridging the windings 800a and 800b of the repeating coil 800 across the conductors of the trunk 55 in series with the condenser 861. At its contacts 833, the relay R830 completes a circuit for energizing the slow-to-operate relay R710 provided at the switching center 70. This circuit extends from ground by way of the winding of R710, the winding 722 of the balancing coil 720, the conductor 55b, the repeating coil winding 800b, the contacts 833 and the resistor 835 to battery. The relay R710, in operating, opens its contacts 713 to disconnect the line conductor 14a from ground, and thus open a point in

the above-traced circuit traversed by the ringing current. At its contacts 711, the relay R710 opens a point in the circuit for transmitting ringing current over the trunk 55 when a call is initiated at one of the substations associated with the line 15. Thus, the line 15 is effectively prevented from obtaining access to the trunk 55. At its contacts 712 and 714, the relay R710 connects the conductors of the line 14 to the conductors of the trunk 55 through the condensers 705 and 706. Thus, a talking circuit is established between the calling substation D and the telephone set embodied in the operator's cord circuit in use at the operator's position 85. After this communication circuit is established, the operator may challenge the connection to determine whether or not the call is intended for another substation associated with the line 14. In such case, the operator may release the trunk 55 by withdrawing the answer plug of her cord circuit from the jack 852, thereby to cause the sequential deenergization of the relays R830 and R710, in an obvious manner. After these relays restore, calls may be routed to the operator's position from the substations associated with the line 15, in the manner described hereinafter, even though the line 14 is occupied with a reverting call. If the assistance of the operator is required by the calling subscriber in order to set up the desired reverting call connection, the operator may instruct the calling party as to the code assigned to the called substation, whereby the calling subscriber may signal the called substation directly. Alternatively, the operator may instruct the calling subscriber to hang up and signal the called substation from her position by operating the ringing key embodied in her cord circuit, in accordance with the code designating the desired substation. In the latter case, ringing current is transmitted over the tip and ring contacts of the jack 852, through the repeating coil 800 and over the trunk 55 and the subscriber's line 14, to energize, in parallel, the ringers respectively provided at the substations associated with the subscriber's line. After the ringing operation is completed, the operator may monitor the connection to ascertain that the desired talking circuit is established, and then release the trunk circuit 80 and the switching equipment at the switching center 70, by withdrawing the answer plug of her cord circuit from the jack 852. In response to this operation, the relays R830 and R710 are sequentially released in the manner explained above. Thus, the trunk 55 is rendered accessible to the other subscriber's line 15 terminating at the switching center 70.

Assuming that the above-described call originating at the substation D is intended for a subscriber's line terminating at the central office, the operator may extend the connection to the desired line in the manner conventionally followed in manual office practice. If the call originating at the substation D is intended for a substation, such, for example, as the substation E, associated with the line 15, the operator may establish a connection with this line by inserting the calling plug of her cord circuit in the jack 851. In response to this operation, negative battery potential is impressed upon the sleeve contact of the jack 851 to energize the relay R840. The relay R840, in operating, opens, at its contacts 841, a further point in the circuits for energizing the relay R820 and the signal lamp 853. At its contacts 842, the relay R840

completes an obvious path in shunt with the operated contacts 832 of the relay R830. At its contacts 844, the relay R840 opens a further point in the circuit for energizing the lower winding of the relay R710 in parallel with the signal lamp 854. At its contacts 843, the relay R840 completes a path including the resistor 845, the contacts 832 and 842 in parallel, and the winding 800a for impressing negative battery potential upon the trunk conductor 55a. In response to this operation, the slow-to-operate line switching relay R700 is energized over a circuit including the trunk conductor 55a and the winding 721 of the balancing coil 720. When thus energized, the relay R700 operates to disconnect the conductor 15b of the line 15 from ground. At its contacts 701 and 703, the relay R700 connects the conductors of the line 15 through the condensers 706 and 705 to the conductors of the trunk 55. After the relay R700 operates, both of the lines 14 and 15 are connected to the trunk 55. To signal the called substation, the operator may instruct the calling party at the substation D to hang up and then operate the ringing key embodied in her cord circuit in accordance with the code assigned to the desired substation E. In response to operation of the ringing key, ringing voltage is impressed between the tip and ring contacts of the jack 851 in the usual manner. This voltage causes ringing current to traverse the windings 800c and 800d of the repeating coil 800. This current is, by induction, transmitted over the trunk 55 to energize the ringers provided at the substations respectively served by the lines 14 and 15. Thus, the ringer 24e, provided at the called substation E, is energized over a circuit including the line conductor 15a, the contacts 701, the condenser 706, the trunk conductor 55a, the winding 800a, the contacts 832 and 842 in parallel, the condenser 801, the winding 800b, the trunk conductor 55b, the condenser 705, the contacts 703, and the line conductor 15b. A branch of this circuit extends by way of the line conductors 14a and 14b of the line 14 and the contacts 712 and 714 so that a portion of the ringing current is caused to traverse the windings of the ringer 24d provided at the substation D. Thus, the ringers provided at the substations respectively served by the lines 14 and 15 all respond to the ringing current transmitted over the trunk in response to operation of the ringing key embodied in the operator's cord circuit. The coded character of the signals produced incident to energization of these ringers serves to inform the subscriber at the substation E that his substation is being called, and to inform the subscribers at the other substations served by these lines that the call is intended for the substation E.

An alternative method of signaling the called substation E may be followed, wherein the operator, after answering the call and inserting the calling plug of her cord circuit in the jack 851 to cause the operation of the relay R700 in the manner just explained, withdraws the answer plug from the jack 852 to cause the deenergization and release of the relays R830 and R710 in the order named. In this case, the relay R710, in restoring, disconnects the conductors of the line 14 from the conductors of the trunk 55. Accordingly, when the operator actuates the ringing key of her cord circuit, ringing current is not projected over the line 14 and the ringers provided at the substations served by this line are not energized. A conversational circuit is estab-

lished between the operator's telephone set and the substation E when the called subscriber removes the receiver 21e from its supporting hook 22e. In the event the first method of ringing is followed by the operator handling the call, the answering of the call at the substation E also results in the completion of a talking circuit between this substation and the calling substation D. On the other hand, if the second described method of signaling the called substation is followed, the operator must reinser the answer plug of her cord circuit in the jack 852 in order to cause the line 14 to again be connected to the trunk 55. More specifically, when the answer plug of the operator's cord circuit is reinserted in the jack 852, the relay R830 is energized by the negative voltage impressed upon the sleeve terminal of the jack. In operating, the relay R830 completes the previously traced operating circuit for the relay R710. The relay R710, in reoperating, again connects the conductors of the line 14 to the trunk 55. Thus, a connection is established between the calling and called substations D and E.

When the conversation is ended and the connection is no longer desired, either the calling or the called subscriber may signal the operator to this effect by operating the hand generator provided at his substation. Assuming that the hand generator 25d, provided at the calling substation D is operated for this purpose, ringing current is transmitted by way of the line 14, the trunk 55, and the repeating coil 800 to energize the drop bridged across the tip and ring contacts of the answer plug embodied in the operator's cord circuit. The operation of this drop serves to inform the operator that the connection is no longer desired, whereupon she may release the connection by withdrawing the call and answer plugs of her cord circuit from the jacks 852 and 851. When the connection is thus cleared out at the operator's position, the two relays R830 and R840 are deenergized and restore. These relays, in releasing, disconnect the trunk conductors 55b and 55a from the negative terminal of the exchange battery. Thus, the two relays R700 and R710 are deenergized and restore. When these two relays release, all of the equipment involved in setting up the connection is fully restored to normal.

The manner in which a call may be routed from the substation E, for example, associated with the line 15, to the control operator's position in the central office, is substantially similar to the above described method of routing a call to this operator's position from a calling substation associated with the line 14. In the latter case, however, when the hand generator 25e, provided at the substation E, is operated, ringing current is projected over the trunk conductor 55a to energize the signal control relay R820. More specifically, this relay is energized over a circuit which extends from ground by way of the contacts 702, the line conductor 15b, the windings of the generator 25e, the switch spring 26e and its associated upper contact, the line conductor 15a, the contacts 711, the condenser 706, the conductor 55a, the lower winding of R820, and the contacts 822, 831 and 841 back to ground. When its lower winding is thus energized, the relay R820 operates and locks to ground through the contacts 821, 831 and 841. At its contacts 821, the relay R820 completes a circuit including the contacts 831 and 841 for energizing the signal lamp 853 individual to the line 15. Thus, the operator attending the position 85 is informed that a call

is present on the line 15. To answer the call, the operator may insert the answer plug of her cord circuit in the jack 851. In response to this operation, negative battery potential is impressed upon the sleeve contact of the jack 851 to energize the relay R840. The relay R840, in operating, opens its contacts 841 to deenergize the relay R820 and the signal lamp 853. At its contacts 842, the relay R840 bridges the windings 800a and 800b of the repeating coil 800 across the trunk conductors 55a and 55b in series with the condenser 801. At its contacts 844, the relay R840 opens a point in the previously traced operating circuit for the relay R810, thereby to prevent this latter relay from responding to a call initiated on the line 14. At its contacts 842 and 843, the relay R840 connects the negative terminal of the exchange battery through the resistor 845 and the winding 800a to the trunk conductor 55a, thereby to energize the line switching relay R760.

The relay R760, in operating, connects the line 15 through the condensers 765 and 766 to the trunk 55, and opens the signaling circuit between the line 14 and this trunk. Thus, a communication connection is established between the calling substation E and the telephone set embodied in the operator's cord circuit. If the call initiated at the substation E is intended for another substation also associated with the line 15, the operator may ascertain this fact by monitoring the connection for a short time interval. After ascertaining that the call is of the reverting type and waiting for the call to be answered, the operator may release the trunk circuit apparatus and the equipment at the switching center by withdrawing the answer plug of her cord circuit from the jack 851. In response to this operation, the relays R840 and R760 are sequentially restored in the order named and in a manner clearly apparent from the preceding explanation.

If the call originating at the substation E is intended for a central office subscriber, the operator handling the call may extend the connection to the desired line in the manner conventionally followed in manual office practice. If, on the other hand, the call is intended for a substation, such, for example, as the substation D, associated with the line 14, the operator may establish a connection to the called line by inserting the calling plug of her cord circuit in the jack 852 to cause the sequential operation of the relays R830 and R710 in a manner clearly apparent from the preceding explanation. From this point on, the manner in which the called substation is signaled and the apparatus involved in setting up the desired connection is released at the end of the call, is exactly the same as described above.

Calls initiated on the central office subscribers' lines and intended for the substations associated with the subscribers' lines 14 and 15, may be routed to the called substations under the control of the operator attending the operator's position 85. Thus, if a call intended for the substation D, for example, is routed to this operator's position, the operator may establish a connection with the called line 14 by inserting the calling plug of her cord circuit in the jack 852, thereby to cause the sequential operation of the two relays R830 and R710. The relay R710, in operating, connects the line 14 to the trunk 15 in the manner previously explained. After this connection is established, the operator may signal the called substation D by actuating the ring-

ing key of her cord circuit in accordance with the code assigned to this substation. In this case, the communication connection between the calling and called lines is set up by way of the talking conductors of the operator's cord circuit when the call is answered at the called substation D. Further, the release of the connection is entirely under the control of the operator attending the operator's position 85, the relays R830 and R710 being sequentially released in response to withdrawal of the calling plug from the jack 852. In a similar manner, a call may be routed to the substation E, for example, associated with the line 15 from a calling central office subscriber's line under the control of the operator attending the operator's position 85. To this end the operator at this position, upon answering a central office call intended for this substation, inserts the calling plug of her cord circuit in the jack 851 to cause the sequential operation of the two relays R840 and R710. The relay R710, in operating, connects the line 15 to the trunk 55 in the manner pointed out above. After this connection is established, the operator may actuate her ringing key to project coded ringing current over the line 15 for the purpose of energizing the ringer 24e provided at the called substation. Here, again, the desired conversational circuit is established by way of the talking bridge of the operator's cord circuit when the call is answered at the called substation E. Further, the two relays R840 and R710 are sequentially deenergized when the calling plug is withdrawn from the jack 851 to remove negative battery potential from the sleeve contact of this jack.

From the above explanation it will be apparent that the signal lamp control relays R820 and R830 are selectively energized by ringing currents projected over the lines 15 and 14, respectively, and the trunk conductors 55a and 55b, respectively. Further, the line switching relays R760 and R710 are selectively energized in accordance with the side of the trunk 55 to which the negative terminal of the exchange battery is connected under the control of the two relays R830 and R840. Thus, if the negative battery potential is impressed upon the trunk conductor 55a, the relay R760 is energized. Alternatively, if negative battery potential is impressed upon the trunk conductor 55b, the other line switching relay R710 is energized. It will further be apparent from the above description with reference to the two arrangements respectively disclosed by Figs. 1, 2 and Figs. 7, 8, that the desired line switching operations are all obtained by switching equipment which is supplied with energizing current from the central office. Accordingly, it is not necessary to provide a source of operating current at either of the two switching centers.

Due to the simplicity of the switching equipment, the apparatus included therein may be housed in a small container, and if desired, mounted upon a line pole conventionally located in the center of the small community served by the subscribers' lines.

As indicated in the introductory portion of the specification, the apparatus provided at either or both of the switching centers 10 and 70 may be controlled through the automatic switching equipment of a tandem automatic exchange in handling calls involving the substations served by the lines 11 to 15, inclusive. Thus, the apparatus illustrated in Figs. 1 and 7 of the drawings may be combined with the apparatus illustrated in Figs. 3, 4, 5, 6, 9, 10, 11 and 12 of the

drawings to form a system wherein the switching equipment provided at the switching centers 10 and 70 is arranged to route calls through the switching equipment, illustrated in Figs. 3, 4, 5, 6, 9, 10 and 11 and provided in a tandem exchange, to an operator's position 60 located in a distant central office. Moreover, this apparatus is so arranged that it may be controlled through the switching equipment of the tandem exchange from the operator's position 60, selectively to interconnect the subscribers' lines 11, 12, 13, 14 and 15 with their respective associated trunks 31 and 55. In the system as thus formulated, the trunk 31 is terminated at the tandem office in the trunk circuit illustrated in Figs. 3 and 4 of the drawings. Similarly, the trunk 55 extending to the switching center 70 is terminated in the tandem exchange in the trunk circuit illustrated in Figs. 5 and 6 of the drawings. These trunk circuits are accessible to the finder and connector switches of the links which are provided for setting up connections between the subscribers' lines, such, for example, as the line 61, extending to the tandem office, and for setting up connections involving the subscribers' lines 11 to 15, inclusive, terminating at the distant switching centers 10 and 70. Each of the subscribers' lines served by the tandem exchange terminates in a line circuit which conventionally comprises the usual line and cut-off relays. Thus, the line 61 is illustrated as extending to a line circuit 62 through which the associated line is rendered accessible to the finder and connector switches of the exchange. Only one of the links, namely the link 48, is illustrated in the drawings, this link being shown in Figs. 9, 10 and 11 as comprising a finder switch 970 and a connector switch 1170. These switches are of the well-known rotary type, each comprising five sets of contacts of eleven points each and five wipers. As shown in the drawings, the control trunk 45 terminates in the tandem exchange in a repeating coil 1080. This repeating coil has associated therewith a battery feed coil 1065 which is utilized for certain relay control operations described with particularity hereinafter.

Briefly considered, the control equipment of the link comprises a finder-stop relay R910, a pair of line switching relays R920 and R1030, a line or pulsating relay R940 and a slow-acting relay R930. The line switching relay R920 is arranged to control a pair of signal control relays R1050 and R1060 which function to transmit a splash of signal current over the trunk 45 to the control operator's position; each time the finder switch 970 is operated to seize a calling line. For the purpose of controlling the application of paystation tone signal voltage to the control trunk 45, and of performing other unique control operations incident to the routing of connections through the trunk circuits illustrated in Figs. 3, 4, 5 and 6 of the drawings, six additional control relays R950, R1000, R1010, R1020, R1040 and R1010 are provided. The first of these relays is of the differentially wound type, such that it only operates when one of its two windings is alone energized. The relays R1000 and R1060, on the other hand, are of the slow-to-operate type. The relay equipment of the link further includes a control relay R1160, which is a slave to the slow-acting hold relay R930, a pair of impulse-responsive line test and pulse circuit control relays R1140 and R1150, a busy test relay R1130, an idle test or line switching relay R1110, and a reverting call relay R1120. The last-mentioned

relay, as well as the relays R1070 and R1100, is only utilized in setting up reverting call connections between the lines terminating at one of the two switching centers 10 and 70. In order to impress negative battery potential upon the line wipers 1177 and 1178 of the connector switch 1170 in performing certain control operations involving the trunk circuits illustrated in Figs. 3, 4, 5 and 6 of the drawings, an additional battery feed coil 1105 is provided. The manner in which the circuit elements, briefly described above, are wired to perform the desired control functions, is pointed out with particularity in the following description pertaining to the operation of the system.

It will be understood from the above description of the finder-connector link 48 that each of the links provided in the tandem exchange terminates a combined control and talking trunk which extends to the operator's switch-board in the distant central office. For the purpose of assigning the links to the use of calling ones of the lines terminating at the tandem exchange in a predetermined order, there is provided a link distributor 48 which may be of any conventional arrangement, although preferably is of the all-relay, preselective type.

The control trunk 45 terminates at the operator's position 60 in the central office in a trunk circuit which includes a repeating coil 1275, a non-locking connect key 1292, a non-locking ringing key 1281, a dial key 1285 of the locking type, a calling device 1284, and a plurality of control relays R1200, R1210, R1220, R1230, R1240, R1250, R1260 and R1270. The switchboard side of the repeating coil 1275 is connected through the contacts of the ringing control relay R1200 to the tip and ring contacts of a line jack 1281. An operator's cord circuit is also provided at this position for use by the operator in handling calls extended to the position 60. For the purpose of indicating the presence of calls routed by way of the line 45 to the operator's position 60, a signal lamp 1283 is provided. Ringing current for signaling over lines selected through the connector ends of the links provided in the tandem exchange is supplied by an alternating current ringing generator 1293.

Briefly described, the trunk circuit illustrated in Figs. 3 and 4 of the drawings as terminating the trunk 31 extending to the switching center 10, comprises a repeating coil 303 and a group of start relays R300, R320 and R340, which individually correspond to the lines 11, 12 and 13 and cooperate with the relays R310, R330 and R350, respectively, to initiate operation of the finder switches of links assigned by the link distributor 48 when calls are initiated on the respective corresponding lines. The series connected relays R300 and R340 are polarized by shunting rectifiers 302 and 342, respectively, so that they are respectively energized by currents of opposite polarity transmitted over the same conductor 31a of the trunk 31. The relays R310, R330 and R350 also function to impress suitable potentials upon the two sides of the trunk 31 to control the operation of the line switching relays R120, R130 and R140 provided at the switching center 10. For the purpose of selectively controlling the relays R310, R330 and R350 in establishing connections between the trunk 31 and called ones of the lines 11, 12 and 13, an additional group of impulse responsive relays comprising the relays R360, R362, R370, R372, R380 and R382 is provided. The relays of the last mentioned group

are arranged selectively to be energized under the control of the operator attending the operator's position 60, through the provision of impulse-responsive apparatus which includes a pulsing relay R450, a slow-to-release hold relay R440 and a slow-to-release impulse controlled relay R420. The apparatus embodied in the trunk circuit further comprises a release relay R430, a reverting call relay R390, a start relay R400, a cut-off relay R410 and three relays R460, R470 and R480 which cooperate with the reverting call relay R390 to effect the connection of a calling one of the lines 11, 12 and 13 to the trunk 31 after ringing current has been transmitted over a called one of these lines to signal the called subscriber. In certain installations, one or more of the lines 11, 12 and 13 terminating at the switching center 10 may be of the paystation type. Accordingly, the start relay R400 is arranged selectively to control a circuit for transmitting a paystation tone signal to the operator's position 60 in response to the initiation of calls on those of the lines 11, 12 and 13 which are of the paystation type.

The trunk circuit illustrated in Figs. 5 and 6 of the drawings, which terminates the trunk 55 extending to the switching center 70, is substantially similar to the above described trunk circuit terminating the trunk 31. Briefly described, the trunk circuit terminating the trunk 55 in the tandem exchange comprises a repeating coil 690 to which the conductors of the trunk 55 extend, and a pair of start relays R600 and R620 which individually correspond to the lines 14 and 15, respectively. These relays are respectively energized when ringing currents are projected over the corresponding lines and have associated therewith line switching control relays R610 and R630, respectively, which are utilized for the purpose of impressing control potentials upon the trunk conductors 55a and 55b selectively to control the energization and operation of the line switching relays R700 and R710 provided at the switching center 70. Additional impulse responsive relays R640, R650, R660 and R670 are provided for controlling the operating circuits of the two relays R610 and R630 in order to effect a connection of the trunk 55 with a called one of the lines 14 and 15. These additional relays are arranged selectively to be controlled by apparatus which comprises a line or pulsing relay R550, a slow-to-release hold relay R540, and a slow-to-release impulse-responsive relay R520. The control equipment of the trunk circuit further includes a reverting call relay R580, a start relay R590, a cut-off relay R510, and a release relay R530. The start relay R500 is also arranged to control a circuit for transmitting a paystation tone signal to the operator's position in the event either of the two lines 14 and 15 is of the paystation type, and a call is initiated thereon. Three additional relays R560, R570 and R580 are provided for further controlling the operating circuits of the relays R610 and R630, in order to connect a calling one of the two lines 14 and 15 to the trunk 55 after ringing current has been transmitted over a called one of the lines to signal the desired substation.

In describing the operation of the system formed by combining the apparatus shown by Figs. 1 and 7 of the drawings, with the apparatus illustrated in Figs. 3, 4, 5, 6, 9, 10, 11 and 12 of the drawings, the manner in which calls initiated on the lines 11, 12 and 13 are routed to the operator's position 60 in the central office will first be considered. In this regard it will be recalled

from the preceding explanation that when a call is initiated on the line 11 and ringing current is transmitted over this line, the positive half-cycles of the ringing current are transmitted over the trunk conductor 31a. It will further be recalled that when a call is initiated at a substation associated with the line 13, and ringing current is projected over this line, the negative half-cycles of the ringing current are transmitted over the trunk conductor 31a. Also, when a call is initiated at a substation served by the line 12, and ringing current is projected over this line, the ringing current is transmitted over the trunk conductor 31b. These ringing currents of different polarities impressed upon the two sides of the trunk 31, are utilized selectively to control the energization of the three relays R300, R320 and R340. Thus, when ringing current is transmitted from the line 11 over the trunk conductor 31a, the relay R300 is energized over a circuit including this trunk conductor, the contacts 315, 334 and 353, and the rectifier 342. In this regard it is pointed out that the rectifier 302 is so poled that it will not pass ringing current of positive polarity transmitted over the trunk conductor 31a. The rectifier 342, on the other hand, is so poled that it readily passes current of this polarity and, accordingly, constitutes an effective short-circuit across the winding of the relay R340. Thus, only the relay R300 is substantially energized when rectified ringing current of positive polarity is transmitted over the trunk conductor 31a. When thus energized, the relay R300 operates to complete, at its contacts 301, an obvious circuit for energizing the relay R310. The relay R310, in operating, locks to ground over a path including its X contacts 317, C423, and the contacts 431. At its contacts 318, the relay R310 completes a circuit for energizing the start relay R400, this circuit extending from ground by way of the contacts 414, C426, the contacts 318, C424 and the winding of R400 to battery. At its contacts 315 and 316, the relay R310 opens points in the respective operating circuits for the relays R300, R320 and R340. At its contacts 311, the relay R310 bridges the repeating coil windings 304 and 305 across the conductors of the trunk 31 in series with the condenser 308. At its contacts 312, the relay R310 completes a path including the resistor 397, the contacts 392 and the winding 304 for impressing negative battery potential upon the upper trunk conductor 31a. When this path is completed, the relay R130 is energized and operates in the manner previously explained. In operating, the relay R130 connects the conductors of the calling line 11 to the conductors of the trunk 31 and opens points in the previously traced signalling circuits individual to the three lines 11, 12 and 13. With the relay R130 in its operated position, the lines 12 and 13 are prevented from obtaining access to the trunk 31.

The start relay R400, in operating, prepares or completes, at its contacts 408, a locking circuit for itself, depending upon the character of the calling line 11. Thus, if the line 11 is of the paystation type, a strap connection 426a is provided, whereby a locking circuit for the relay R400 is established when this relay operates. This locking circuit extends from ground by way of the contacts 422 and 406, the strap 426a, C426, the contacts 318, C424, and the winding of R400 to battery. If the line 11 is not of the paystation type, the strap connection 426a is omitted from the circuit wiring and accordingly operation of

the relay R400 to close its contacts 406 is without effect. At its contacts 401, the relay R400 prepares the above-mentioned circuit for transmitting the usual paystation tone signal to the control operator's position in the central office. At its contacts 402, the relay R400 completes an obvious path for impressing ground potential upon the private conductor 43d of the line 43, thereby to mark the trunk circuit illustrated in Figs. 3 and 4 as busy in the bank contacts of the connector switches provided in the tandem exchange. At its contacts 404, the relay R400 completes a path including the winding of the cut-off relay R410 for impressing negative battery potential upon the control conductor 43c of the line 43, thereby to mark this line in the bank contacts of the finder switches provided in the tandem exchange. At its contacts 405, the relay R400 completes a path including the contacts 412 for impressing ground potential upon the start conductor C49 extending to the distributor 48. When this conductor is grounded, the apparatus of the distributor 48, cooperating with the control equipment of the finder switch embodied in an assigned one of the finder-connector links, causes the finder switch of the assigned link to seize the line 43 in the manner subsequently explained.

If a call is initiated on the line 13, such that ringing current of negative polarity is transmitted by way of this line and the trunk conductor 31a, the relay R340 is energized instead of the relay R300. In this regard it will be noted that the rectifier 302 is so poled that it readily passes current of this polarity and, accordingly, constitutes an effective short circuit across the winding of the relay R380. The rectifier 342, on the other hand, will not pass current of negative polarity transmitted over the trunk conductor 31a. Accordingly, only the relay R340 is substantially energized when a call is initiated on the line 13. When thus energized, the relay R340 operates to complete, at its contacts 341, an obvious circuit for energizing the relay R350. The relay R350, in operating, locks to ground over a path including its X or preliminary make contacts 355, C423 and the contacts 431. At its contacts 356, the relay R350 completes an alternative circuit for energizing the start relay R400, this circuit extending from ground by way of the contacts 413, C425, the contacts 356, C424 and the winding of R400 to battery. At its contacts 353 and 354, the relay R350 opens the respective operating circuits for the relays R300, R320 and R340. At its contacts 351, the relay R350 bridges the repeating coil windings 304 and 305 across the conductors of the trunk 31 in series with the condenser 308. At its contacts 352, the relay R350 completes a path including the resistor 393 and the contacts 393, the contacts 313 and the winding 304 for connecting the positive terminal of the auxiliary current source provided in the tandem exchange to the trunk conductor 31a. When positive potential is thus impressed upon the trunk conductor 31a, the relay R120 provided at the switching center 10 is energized and operates to connect the calling line 13 to the trunk 31 in the manner previously explained. With the relay R120 in its operated position, the lines 11 and 12 are prevented from obtaining access to the trunk 31. The relay R400, upon operating in response to operation of the relay R350, performs the functions explained above with reference to the call initiated on the line 11.

In the event a call is initiated at a substation served by the subscriber's line 12, so that ringing current is projected over this line and the lower trunk conductor 31b, the relay R320 is energized over a circuit including this trunk conductor and the contacts 316, 335 and 354. When thus energized, the relay R320 completes, at its contacts 321, an obvious circuit for energizing the relay R330. The relay R330, in operating, locks to ground over a path including its X contacts 336, C423 and the contacts 431. At its contacts 337, the relay R330 completes the previously traced alternative operating circuit for the start relay R400. At its contacts 334 and 335, the relay R330 opens points in the respective operating circuits for the relays R300, R320 and R340. At its contacts 331, the relay R330 bridges the repeating coil windings 304 and 305 across the conductors of the trunk 31 in series with the condenser 308. At its contacts 333, the relay R330 completes a path including the resistor 396, the contacts 391 and the winding 305 for impressing negative battery potential upon the lower trunk conductor 31b. When this conductor is connected to the negative terminal of the exchange battery, the line switching relay R140 is energized and operates. In operating, the relay R140 connects the calling line 12 to the trunk 31 and locks out the other lines 11 and 13 terminating at the switching center 10 to prevent these lines from obtaining access to the trunk 31.

As explained above, when the start relay R400 operates in response to the initiation of a call on one of the three subscribers' lines 11, 12 and 13, it functions to mark the link line 43 as a calling line in the bank contacts of the finder switches provided in the tandem exchange, and to impress ground potential upon the distributor start conductor C49. Assuming that the finder-connector link 40 is assigned to the use of the calling line 43, the start relay R400 is energized and operates in response to the application of ground potential to the distributor start conductor C49. This relay, in operating, prepares, at its contacts 901, a circuit for energizing the respective lower windings of the relays R910 and R920 in series with the cut-off relay R410. At its contacts 902, the relay R900 completes a circuit for energizing the operating magnet 981 of the finder switch 970, this circuit extending from ground by way of the contacts 1151, the wiper 1180 and its associated normal contact, C923, the contacts 931, 926, 911 and 902, and the winding of the magnet 981 to battery. When thus energized, the magnet 981 conditions its associated ratchet and pawl mechanism to step the wipers of the switch 970, in the usual manner. At its contacts 982, the magnet 981 completes an obvious circuit for energizing the upper winding of the relay R910. The relay R910 now operates to open, at its contacts 911, the above-traced circuit for energizing the magnet 981. The magnet 981 is thus deenergized, permitting its associated ratchet and pawl mechanism to advance the wipers of the finder switch 970 one step. At its contacts 982, the magnet 981 opens the operating circuit for the relay R910. The relay R910 is thus deenergized and restores to recomplete the circuit for energizing the magnet 981. The interrelated operation of the magnet 981 and the relay R910 continues until the wipers of the finder switch 970 are operated into engagement with the set of contacts 911, 926, 931 and 932.

tacts terminating the calling link line 43. More specifically, when the wiper 973 is operated to engage the contact terminating the conductor 43c, the above-mentioned circuit, including the respective lower windings of the relays R910 and R920 and the winding of the cut-off relay R410, is completed. This circuit extends from ground by way of the contacts 901, the lower winding of R910, the lower winding of R920, the wiper 973, the conductor 43c, the contacts 404, and the winding of R410 to battery. When thus energized, the relay R910 immediately operates to open, at its contacts 911, the previously traced operating circuit for the magnet 981. Thus, the stepping operation of the finder switch 970 is arrested with the wipers of this switch standing in engagement with the contacts terminating the conductors of the link line 43. The relay R920 also operates when its lower winding is energized over the above-traced circuit. In operating, this relay first completes, at its X or preliminary make contacts 923, a locking circuit for itself, this circuit extending from ground by way of the contacts 1151, the wiper 1180 and its associated normal contact, C983, the contacts 923 and the upper winding of R920 to battery. At its contacts 926, the relay R920 disconnects the guard conductor 912, individual to the link 40, from ground, and opens a further point in the previously traced operating circuit for the magnet 981. When ground potential is removed from the conductor 912, the link 40 is marked as busy at the contacts of the distributor relays embodied in the distributor 48. At its contacts 924, the relay R920 completes a path for short-circuiting its lower winding in series with the lower winding of the relay R910 and, incident thereto, completes a path for impressing ground potential directly upon the control conductor 43c of the link line 43. When its lower winding is thus deenergized, the relay R910 restores to reprepare the operating circuit for the magnet 981. At its contacts 921 and 922, the relay R920 connects the conductors 43a and 43b of the link line 43 to the link line conductors C984 and C985, respectively, thereby further to prepare a communication circuit between the calling circuit and the operator's position 60. At its contacts 925, the relay R920 completes a circuit including the conductor C987 and the contacts 1052 for energizing the slow-to-operate relay R1030. At its contacts 927, the relay R920 further prepares the circuit for transmitting a paystation tone signal over the control trunk 45 to the operator's position 60. At these same contacts, the relay R920 prepares a circuit for energizing the reverting call relay R1120. At its contacts 928, the relay R920 prepares a circuit for energizing the slow-to-release control relay R1080. At its contacts 929, the relay R920 completes a circuit for energizing the line switching relay R1030, this circuit extending from ground by way of the wiper 1181 and its associated normal contact, C993, the contacts 929, C994, and the lower winding of R1030 to battery.

The cut-off relay R410 operates when energized in series with the lower windings of the two relays R910 and R920. In operating, the relay R410 locks to the grounded control conductor 43c over a path including the contacts 411. At its contacts 413 and 414, the relay R410 opens points in the above-traced operating circuits for the relay R400, causing the last-men-

tioned relay to restore in the event the calling line terminating at the switching center 10 is not of the paystation type. If the calling line extends to a paystation, the relay R400 is held energized over the previously traced locking circuit, which includes the contacts 406 and the strap 426a, or a corresponding strap extending to the conductor C425. As its contacts 412, the relay R410 disconnects the distributor start conductor C49 from ground. Assuming that the start relay R400 is deenergized in response to operation of the cut-off relay R410, this relay, in releasing, opens the prepared paystation tone circuit at its contacts 401 and, at its contacts 402, opens the initially completed path for impressing guarding ground potential upon the private conductor 43d of the link line 43. At its contacts 403, the relay R400 completes an alternative path including the grounded control conductor 43c and the contacts 411 for impressing ground potential upon the private conductor 43d to maintain the link line 43 marked as busy in the bank contacts of the connector switches having access to this line. At its contacts 404, the relay R400 opens a point in the initially completed circuit for energizing the cut-off relay R410. At its contacts 405, the relay R400 opens a further point in the path for applying ground potential to the distributor start conductor C49. When this conductor is thus disconnected from ground, the link distributor 48 operates to select another idle link and to prepare a circuit for energizing the start relay embodied therein which corresponds to the relay R900 of the link illustrated.

As explained above, the relays R1030 and R1080 are energized in response to the operation of the line switching relay R920 which occurs when the finder switch 970 operates to seize the calling link line 43. In operating, the relay R1030 opens, at its contacts 1033, a point in the operating circuit for the relay R1040. At its contacts 1034, the relay R1030 opens a point in the prepared locking circuit for the relay R1100. At its contacts 1036, the relay R1030 opens a point in the path, traced hereinafter, for impressing busy tone voltage upon the control trunk 45. At its contacts 1031 and 1032, the relay R1030 extends the communication connection to the windings of the repeating coil 1080. At these same contacts, the relay R1030 completes a simplex circuit for energizing the line relay R450 in series with the two windings of the relay R460. One branch of this circuit extends from ground by way of the winding of R450, the lower winding of R460, C467, the winding 306, the conductor 43a, the wiper 976, the contacts 921, C984, the contacts 1034 and 1032, the winding 1082, and the right winding of the balancing coil 1065 to battery. The other branch of this circuit extends from ground by way of the winding of R450, the upper winding of R450, C468, the winding 307, the conductor 43b, the wiper 977, the contacts 922, C985, the contacts 1032 and 1074, the winding 1081, and the right winding of the balancing coil 1065 to battery. The relay R460 is of the differentially wound type, such that it does not operate when both of its windings are concurrently energized. The relay R450, however, operates to complete, at its contacts 453, an obvious circuit for energizing the slow-to-release hold relay R440. At its contacts 452, the relay R450 opens a point in the circuit for transmitting current pulses to the line selecting relays R360, R370 and R380. At its contacts 451, the relay R450 opens a point in the

circuit for energizing the slow-to-release pulse-responsive relay R420. The relay R440, in operating, completes, at its contacts 442, an obvious multiple holding circuit for the operated one of the three relays R310, R330 and R350. At its contacts 441, the relay R440 prepares circuits for energizing the relays R330, R470 and R480, and completes an obvious circuit for energizing the slow-to-release relay R430. In operating, the relay R430 opens, at its contacts 431, a point in the common portion of the initially traced holding circuits for the relays R310, R330 and R350.

The relay R1060, in operating, completes, at its contacts 1061, an obvious path for grounding the locking lead C1092 and thus completes an obvious circuit for energizing the relay R1050. At its contacts 1063 and 1064, the relay R1060 disconnects the conductors of the control trunk 45 from the line terminals of the repeating coil windings 1084 and 1085. At its contacts 1062, the relay R1060 completes a circuit for energizing the signal control relay R1240 provided in the trunk circuit terminating the control trunk 45 at the operator's position 60. This circuit extends from ground by way of the winding of R1240, the contacts 1231, the conductor 45a, the contacts 1062, and the left winding of the balancing coil 1065 to battery. The relay R1050, upon operating in response to operation of the relay R1060, locks to ground over a path including the contacts 1051, C987 and the contacts 925 and thus completes an obvious alternative path for impressing ground potential upon the locking lead C1092. At its contacts 1052, the relay R1050 opens the operating circuit for the relay R1060. Thus, the relay R1060 is deenergized and restores to open the above-traced circuit for energizing the signal control relay R1240. At its contacts 1061, the relay R1060 opens the initially completed path for grounding the lead C1092. At its contacts 1053, the relay R1050 prepares an operating circuit for the slow-to-operate control relay R1080. With the relay R1050 operated and the relay R1060 restored, the conductors of the control trunk 45 are connected to the line terminals of the repeating coil windings 1084 and 1085. Thus, a connection is completed between the calling line and the operator's position 60.

As indicated above, the signal control relay R1240 momentarily operates in response to the momentary operation of the relay R1060. In operating, the relay R1240 completes, at its contacts 1241, a circuit including the contacts 1263 for energizing the respective lower windings of the relays R1260 and R1270 in parallel. At its contacts 1241, the relay R1240 also completes a circuit including the contacts 1272 for energizing the upper winding of the relay R1270. The relay R1260, in operating, completes a holding circuit for itself and the relay R1270, this holding circuit extending from ground by way of the contacts 1234 and 1262, and the respective lower windings of R1260 and R1270 in parallel, to battery. After this circuit is completed, the relay R1260 opens, at its contacts 1263, the initially completed circuit for energizing its lower winding in parallel with the lower winding of the relay R1270. At its contacts 1261, the relay R1260 prepares a circuit for energizing the signal lamp 1283. At its contacts 1264, the relay R1260 completes an obvious circuit for energizing the lower winding of the relay R1250. In operating, the relay R1270 opens, at its contacts 1272, the above-traced circuit for energizing its own upper winding, and completes, at its contacts 1273, an obvious multi-

ple locking circuit for the relay R1260. At its contacts 1271, the relay R1270 completes the circuit for energizing the signal lamp 1283. At its contacts 1274, the relay R1270 completes a path including the condenser 1294 for transmitting ringing current from the ringing current generator 1293 over the established connection to the calling substation, thereby to signal the calling subscriber that the call has been forwarded to the operator's position in the distant central office. The relay R1250, upon operating, prepares a locking circuit for itself at its contacts 1253. At its contacts 1252, the relay R1250 prepares a circuit for energizing the slow-to-release relay R1220. At its contacts 1251, the relay R1250 opens the normally completed direct current path which includes the repeating coil windings 1277 and 1279 and extends between the conductors of the control trunk 45. Following the operations just described, no further operation of the apparatus occurs until the call is answered by the operator attending the operator's position 60. In this regard it will be appreciated that the energized condition of the lamp 1283 serves to inform the operator attending this position that a call is present on the control trunk 45.

In order to answer the call, the operator inserts the answer plug of her cord circuit in the jack 1231. In response to this operation, the jack contacts 1232 are operated into engagement to complete the previously mentioned locking circuit for the relay R1250 and a parallel operating circuit for the relay R1230. When thus energized, the relay R1230 attracts its armature 1239 rapidly into engagement with the weighted armature 1236, whereby vibratory movement of the latter armature is initiated. At its contacts 1234, the relay R1230 opens the previously traced locking circuit for the two relays R1260 and R1270, causing both of these relays to restore. In releasing, the relay R1260 opens, at its contacts 1264, the operating circuit for the relay R1250. At its contacts 1261, the relay R1260 opens the circuit for energizing the signal lamp 1283. The relay R1270, upon restoring, opens a further point in the circuit for energizing the signal lamp 1283 and, at its contacts 1274, interrupts the above-traced path for transmitting the waiting tone signal to the calling subscriber. At its contacts 1231, the relay R1230 opens a point in the above-traced operating circuit for the signal control relay R1240. At its contacts 1232 and 1233, the relay R1230 completes a communication connection between the telephone set of the operator's cord circuit and the calling substation. This communication circuit includes the repeating coil 1275, the control trunk 45, the repeating coil 1080, the link line C984, C985, the link line 43, the repeating coil 303, the trunk 31, and the calling line. After this communication circuit is established, the operator may converse with the calling subscriber and ascertain the substation or party desired.

At its contacts 1233 and 1237, the relay R1230 completes a circuit for energizing the lower winding of the relay R950 in series with the pulsing relay R940. This circuit extends from the negative terminal of the exchange battery provided in the central office, by way of the resistor 1239, the contacts 1237 and 1231, the winding 1279, the contacts 1233, the trunk conductor 45b, the contacts 1053 and 1064, the winding 1085, C999, the lower winding of R950, and the winding of R940 to ground. When thus energized, the relays R940 and R950 both operate. In operating, the relay

R940 opens, at its contacts 942, a point in the circuit, traced hereinafter, for transmitting current pulses to the operating magnet 1183 of the connector switch 1170. At its contacts 943, the relay R940 completes an obvious circuit for energizing the slow-acting hold relay R930. The relay R930, in operating, opens, at its contacts 931, a further point in the path for grounding the guard lead 912. At its contacts 932, the relay R930 completes obvious multiple locking circuits for itself and the relay R920. At its contacts 933, the relay R930 completes a circuit including the conductor C997 for energizing the relay R1160.

The relay R1160, upon operating, prepares, at its contacts 1161, a circuit for energizing the line switching relay R1110. At its contacts 1162, the relay R1160 completes an obvious multiple path for impressing ground potential upon the hold lead 1092. At its contacts 1163, the relay R1160 completes the operating circuit for the relay R1000, and prepares locking circuits for the relays R1110 and R1120. At its contacts 1164 and 1165, the relay R1160 prepares the above-mentioned circuit for transmitting current pulses to the relays R1140 and R1150 and the connector switch operating magnet 1183 in parallel. At its contacts 1166, the relay R1160 opens a point in the circuit for energizing the magnet 1183 during the release of the connector switch 1170. At its contacts 1167, the relay R1160 completes a locking circuit for the relay R1030, this locking circuit extending from ground by way of the wiper 1181 and its associated normal contact, the contacts 1167, C934, and the lower winding of R1030 to battery.

As indicated above, the relays R940 and R950 operate concurrently. With the relay R950 operated, a circuit is completed for energizing the slow-to-operate relay R1000 when the relay R1160 operates in the manner pointed out above. This circuit extends from ground by way of the contacts 1163, C994, the contacts 1053, the winding of R1000, C986, and the contacts 951 to battery. The relay R1000 operates after an interval and, at its contacts 1091, opens a point in the path normally short-circuiting the condenser 1075. This operation is without effect in the present instance. At its contacts 1092, the relay R1000 prepares a circuit for energizing the relay R1040. At its contacts 1093, the relay R1000 prepares a circuit for energizing the relay R1020. At its contacts 1004, the relay R1000 completes the previously mentioned circuit for transmitting paystation tone current to the operator's telephone set in the event the calling line is of the paystation type. More specifically, paystation tone voltage is caused to traverse the repeating coil winding 1279 over a circuit which extends from the ungrounded terminal of the paystation current source by way of the condenser 456, the contacts 481, the conductor 43e, the wiper 979, the contacts 927, C991, the condenser 1018, the contacts 1022, 1004, 1064 and 1053, the trunk conductor 45b, the contacts 1233, the winding 1278, the contacts 1287 and 1237, the resistor 1238, and the exchange battery in the central office to the grounded terminal of the paystation tone current source. The current traversing this circuit causes a corresponding induced voltage to be developed in the repeating coil windings 1276 and 1278. This voltage is reproduced by the receiver embodied in the operator's cord circuit in the usual manner, so that the operator is informed that the calling substation is of the paystation type.

During the interval required for the above-

described operations to occur, the weighted armature 1236 continues to vibrate. After a predetermined time interval, the amplitude of vibration of this armature is sufficiently reduced so that the contacts 1235 remain in engagement. A circuit is thus completed for energizing the slow-to-operate relay R1220, this circuit extending from ground by way of the contacts 1252 and 1235, and the winding of R1220 to battery. The relay R1220, in operating, completes a circuit for energizing the upper winding of the relay R950 in series with the pulsing relay R940. This circuit extends from the negative terminal of the exchange battery provided in the central office, by way of the resistor 1238, the contacts 1237, 1287, 1211 and 1221, the winding 1277, the contacts 1232, the trunk conductor 45a, the contacts 1063, the winding 1084, C998, the upper winding of R950, and the winding of R940 to ground. Thus, both windings of the relay R950 are energized over parallel circuits. This relay is of the differentially wound type, such, that when both of its windings are concurrently energized it restores. In releasing, the relay R950 opens, at its contacts 951, the above-traced operating circuit for the relay R1000. The relay R1000 accordingly releases to open, at its contacts 1004, the above-traced circuit for transmitting paystation tone current over the control trunk 45 to the operator's telephone set in use at the operator's position 60. Thus, the paystation tone signal is terminated. At its contacts 1001, the relay R1000 again short-circuits the condenser 1075. At its contacts 1002, the relay R1000 opens the prepared operating circuit for the relay R1050. At its contacts 1003, the relay R1000 opens the prepared operating circuit for the relay R1020.

If the substation desired by the calling party is associated with a subscriber's line terminating at the central office, the operator attending the position 60 may extend the connection to the desired subscriber's line in the manner conventionally followed in manual office practice. On the other hand, if the answered call is of the revertive type and the assistance of the operator in setting up the connection is not desired, the operator may wait until the call is answered and then release the operated link 49, the trunk circuit illustrated in Figs. 3 and 4 of the drawings and the apparatus at the switching center 10 by withdrawing the answer plug of her cord circuit from the jack 1281. The manner in which this equipment is released in response to this operation is explained hereinafter. If the assistance of the operator is desired in setting up the revertive connection, the operator may either instruct the calling party as to the code assigned to the called substation, or may signal the called substation directly by actuating the ringing key 1291 in accordance with the assigned code, thereby to transmit coded ringing current from the generator 1293 back over the trunks 45 and 31 to energize the ringers provided at the substations associated with the calling line. In either case the operator may release the operated switching equipment in the manner explained hereinafter after the ringing operation is completed and the call is answered.

If the substation desired by the calling party is associated with a subscriber's line terminating at the tandem exchange, the connection is routed to the desired line through the connector switch 1170 of the operated finder-connector link 40. To this end, the operator, after ascertaining the

directory number of the desired substation, dials the digit or digits of this number. In this regard it will be recalled from the preceding explanation that the finder switches and the connector switches of the links provided at the tandem exchange are of the eleven point type, having ten line positions and a normal position. Thus, any line terminating in the bank contacts of the connector switches of the tandem exchange may be selected by a single operation of the calling device 1284 provided at the operator's position 60. In order operatively to associate this calling device with the control trunk 45, the operator may actuate the dial key 1285 to its off-normal position. In response to this operation, the contacts 1289 are moved into engagement to complete an obvious circuit for energizing the slow-to-release relay R1210. At the contacts 1290, a multiple direct current path is completed across the condenser 1213. At the contacts 1286 and 1288, an alternative circuit is completed for energizing the relay R940 in series with the two windings of the relay R950. One branch of this circuit extends from the negative terminal of the exchange battery provided in the central office by way of the resistor 1238, the contacts 1237, the contacts 1288, the pulsing springs of the calling device 1284, the contacts 1286, the winding 1279, the contacts 1233, the trunk conductor 45b, the contacts 1053 and 1064, the winding 1085, C989, the lower winding of R950, and the winding of R940 to ground. The other branch of this circuit extends from the negative terminal of the exchange battery provided in the central office by way of the resistor 1238, the contacts 1237, the contacts 1288, the pulsing springs of the calling device 1284, the contacts 1286 and 1290, the winding 1277, the contacts 1232, the trunk conductor 45a, the contacts 1063, the winding 1084, C998, the upper winding of R950, and the winding of R940 to ground. Thus, the pulsing springs of the calling device 1284 are included in the circuit for energizing the pulsing relay R940. After these alternative circuits are completed, the initially traced circuit for energizing the pulsing relay R940 in series with the two windings of the relay R950 is interrupted at the contacts 1287 of the dial key 1285. Upon operating in response to operation of this key the relay R1210 opens, at its contacts 1212, a point in the circuit for energizing the ringing relay R1200. At its contacts 1211, the relay R1210 opens a point in the initially traced direct current shunt across the condenser 1213.

After the calling device 1284 is thus operatively associated with the control trunk 45, the operator may dial the single digit designating the line extending to the substation desired by the calling party. Assuming that the substation F, served by the line 61, is desired and further, that the directory number identifying this line is the single digit 7, the operator actuates the calling device 1284 so that the pulsing springs embodied in this device are opened and closed seven times. Thus, seven current pulses are transmitted over the previously traced circuit to the pulsing relay R940. When this circuit is opened at the beginning of the open circuit period of the first impulse, it restores to interrupt, at the contacts 943, the previously traced locking circuit for the relay R930. At its contacts 942, the relay R940 completes the above-mentioned circuit for energizing the magnet 1183 in parallel with the relays R1140 and R1150. This circuit extends from ground by way of the contacts 932

and 942, C990, the contacts 1164 and 1115, to the contacts 1133 where it divides, one branch extending through the winding of the magnet 1183 to battery, and the second branch extending 5 through the contacts 1165 and the parallel connected upper windings of the relays R1140 and R1150 to battery. When thus energized, the relays R1140 and R1150 both operate. In operating the relay R1150 opens, at its contacts 1151, 10 a point in the common portion of the previously traced circuits for energizing the magnet 981 and the relays R930 and R920. At its contacts 1152, the relay R1150 completes an obvious shunt across the restored contacts 1133, so that further current pulses will be transmitted through its 15 upper winding and the upper winding of R1140 during further operation of the pulsing relay R940, regardless of the operated or restored position of the busy test relay R1130. At its contacts 1153, the relay R1150 completes an obvious path for short-circuiting its lower winding, thereby to render itself slow-to-release. At its contacts 1154, the relay R1150 completes an obvious locking circuit for the relay R1140. Due to the slow-to-release characteristic thus imparted to the relay R1150 and the inherent slow-to-release characteristic of the hold relay R930, these relays remain operated during impulsion. At its contacts 1155, the relay R1150 completes a circuit for energizing the slow-to-release relay R1100, this circuit extending by way of the finder switch wiper 980 and the grounded contact engaged thereby, the contacts 928, C992, the contacts 1155, and the winding of R1100 to battery. 20 In this regard it is pointed out that only those contacts of the contact set 975 in the finder switch 970 which terminate link lines extending to trunk circuits of the character illustrated in Figs. 3, 4, 25 5 and 6 of the drawings, are connected to ground, the remaining contacts of this contact set being left unwired. The corresponding contacts of the other finder switches are wired in the same manner. Accordingly, the relay R1100 is only energized when the link 40 is occupied with a call 30 routed through one of the two trunk circuits illustrated in Figs. 3, 4, 5 and 6 of the drawings. In operating this relay prepares, at its contacts 1103, a holding circuit for itself. At its contacts 1101 and 1102, the relay R1100 completes a 35 multiple simplex circuit for energizing the relay R450 in series with the two windings of the relay R460. One branch of this multiple circuit extends from ground by way of the winding of R450, the upper winding of R460, C408, the winding 307, the conductor 43b, the wiper 977, the contacts 922, C985, the contacts 1102, and the left winding of the balancing coil 1105 to battery. The other branch of this circuit extends from ground by way of the winding of R450, the 40 lower winding of R460, C407, the winding 306, the conductor 43a, the wiper 476, the contacts 921, C984, the contacts 1101, and the right winding of the balancing coil 1105 to battery. The purpose of providing this locking circuit is to 45 maintain the energization of the operated relays in the trunk circuit after the relay R1030 has been deenergized in the manner subsequently explained, through operation of the wipers of the connector switch 1170 to an off-normal position. 50 As explained above, the relays R1140 and R1150 are concurrently energized at the beginning of the open circuit period of the first impulse transmitted to the pulsing relay R940. In operating, the relay R1140 opens, at its contacts 1141, a point in the operating circuit for the line

switching relay R1110. At its contacts 1142, the relay R1140 prepares a test circuit over which the busy test relay R1130 is energized each time the connector switch wiper 1179 encounters a contact terminating the private conductor of a busy line. Such operation of the busy test relay R1130, during movement of the connector switch wipers to engage the contacts terminating the conductors of the called line 61, is without effect. At its contacts 1144, the relay R1140 opens a point in the circuit for impressing busy tone voltage upon the control trunk 45 extending to the operator's position 60.

When the magnet 1183 is energized at the beginning of the open circuit period of the first 15 impulses transmitted to the pulsing relay R940, it conditions its associated ratchet and pawl mechanism to step the wipers of the connector switch 1170 one step. When the pulsing relay switch R940 subsequently reoperates, the magnet 1183 20 is deenergized. The ratchet and pawl mechanism controlled by the magnet 1183 is thus released and operates to advance the wipers of the switch 1170 one step from the normal position 25 into engagement with the contacts terminating the conductors of the first line to which the connector switch 1170 has access. When the wiper 1180 is moved off normal, a further point is opened in the previously traced circuits for energizing the magnet 981 and the relays R930 and 30 R920. At the wiper 1181 and its associated normal contact, the previously traced operating and locking circuits for the relay R1030 are interrupted. The relay R1030 is thus deenergized and 35 restores to disconnect the link line conductors C984 and C985 from the line terminals of the repeating coil windings 1081 and 1082. In response to this operation, the initially traced circuit for energizing the relay R450 in series with the two windings of the relay R460 is interrupted. At its contacts 1033, the relay R1030 prepares the 40 operating circuit for the relay R1040. At its contacts 1034, the relay R1030 completes the previously mentioned holding circuit for the relay R1100, this circuit extending by way of the 45 grounded finder switch wiper 980, the contacts 928, C992, the contacts 1034, C1095, the contacts 1123 and 1103, and the winding of R1100 to battery.

During the remaining six impulses of the digit 50 designating the called line 61, the pulsing relay R940 operates to deliver six additional current pulses to the operating magnet 1183 and the respective upper windings of the relays R1140 and R1150. The magnet 1183, operating in conjunction with its associated ratchet and pawl mechanism, responds to these current pulses by advancing the wipers of the connector switch 1170 six additional steps. Thus, the connector switch wipers are left standing in engagement with the contacts terminating the conductors of the line 61. At the end of the digit, the line relay R940 is held energized over the previously traced circuit controlled by the pulsing springs of the calling device 1284. Accordingly, the circuit for energizing the magnet 1183 in parallel with the respective upper windings of the relays R1140 and R1150 is held open. Shortly following the end of the digit, the relay R1150 restores to open, at its contacts 1152, the path shunting the contacts 1133. At its contacts 1151, the relay R1150 70 reprepares the previously traced circuits for energizing the magnet 981 and the relays R920 and R930. At its contacts 1153, the relay R1150 opens the path short-circuiting its lower winding.

At its contacts 1154, the relay R1150 opens the holding circuit for the relay R1140. At its contacts 1155, the relay R1150 opens the previously traced operating circuit for the relay R1100. The relay R1140, in releasing, prepares, at its contacts 1144, the above-mentioned circuit for impressing busy tone voltage upon the control trunk 45. At its contacts 1142, the relay R1140 opens a point in the circuit for energizing the busy test relay R1130.

During the interval required for the relays R1150 and R1140 to release following the end of the digit dialed by the operator, the selected line 61 is tested to determine its idle or busy condition. If the line is busy, ground potential is impressed upon the private conductor 61d thereof, in the usual manner. On the other hand, if the line is idle, battery potential is impressed upon this conductor through the winding of the cut-off relay conventionally embodied in the line circuit 62. Assuming that the line 61 is busy, the busy test relay R1130 is energized immediately the wipers of the connector switch 1170 are operated into engagement with the contacts terminating the conductors of this line. The circuit for energizing the busy test relay extends by way of the grounded private conductor 61d, the wiper 1179, the contacts 1142 and the winding of R1130 to battery. In operating, the relay R1130 opens a point in the operating circuit for the line switching relay R1110 at its contacts 1131. At its contacts 1132, the relay R1130 prepares a locking circuit for itself. At its contacts 1133, the relay R1130 opens a point in the previously traced circuit for energizing the magnet 1183 in parallel with the respective upper windings of the relays R1140 and R1150. At its contacts 1134, the relay R1130 prepares a circuit for energizing the reverting call relay R1120. The holding circuit for the busy test relay R1130 is completed when the relay R1140 restores in the manner pointed out above, this circuit extending from ground by way of the contacts 1161, 1112, 1132 and 1143, and the winding of R1130 to battery. With the busy test relay R1130 operated, and the relay R1140 restored, the previously mentioned circuit is completed for transmitting busy tone to the operator's telephone set in use at the operator's position 60. One of the links of this circuit may be traced as extending from the ungrounded terminal of the busy tone current source, not shown, by way of the condenser 1158, the contacts 1144, 1135 and 1124, C1097, the contacts 1036, 1064 and 1053, the trunk conductor 45b, the contacts 1233, 55 the winding 1279, the path short-circuiting the condenser 1213, the winding 1277, the contacts 1232, the trunk conductor 45a, the contacts 1063, the winding 1084, C998, the upper winding of R950, and the winding of R940 to the grounded terminal of the busy tone current source. The busy tone current traversing this circuit is, by induction, repeated to the channel including the repeating coil windings 1276 and 1278 and the receiver of the operator's telephone set, whereby the usual busy tone signal is reproduced by this receiver.

In order to inform the calling subscriber that the called substation is busy, the operator handling the call at the operator's position may restore the dial key 1285 to normal, thereby to re-establish a transmission circuit between the control trunk 45 and the calling substation. More specifically, when the key 1285 is returned to its normal position, the contacts 1290 are disengaged to open the direct current path shunting

the condenser 1213, and the contacts 1289 are disengaged to open the operating circuit for the slow-to-release relay R1210. At the contacts 1287, the previously traced branch circuit is completed for energizing the line relay R940 in series with the lower winding of the differentially wound relay R950. With the relay R1210 operated, the other branch circuit, namely that for energizing the relay R940 in series with the upper winding of the relay R950, is held open at the contacts 1211, 1221 and 1251. Accordingly, the differentially wound relay R950 is unbalanced and operates in response to the release of the dial key 1285. It will be noted that when the slow-to-release relay R1210 restores, the branch circuit for energizing the winding of R940 in series with the upper winding of the relay R950 is recompleted at the contacts 1211, thereby to cause the release of the relay R950. During the interval when the relay R950 is operated, the previously traced operating circuit for the relay R1000 is completed. The relay R1000, in operating, completes an alternative circuit for energizing the relay R1020, this circuit extending from ground by way of the wiper 1181, the engaged seventh contact of the contact set 1175, C1096, the contacts 1003 and 1014, and the winding of R1020 to battery. When thus energized, the relay R1020 operates and locks to the grounded lead C1092 over a path including the winding of R1010 and the contacts 1021. The relay R1010 is thus short-circuited. Thereafter, and when the relay R1000 restores in response to the sequential release of the relays R1210 and R950, the path short-circuiting the winding of the relay R1010 is interrupted at the contacts 1003, permitting this relay to be energized in series with the relay R1020. In operating, the relay R1020 also opens, at its contacts 1022, a point in the above-traced circuit for transmitting paystation tone signal current over the control trunk 45 to the operator's position 60. The relay R1010, in operating, opens, at its contacts 1015, a point in the operating circuit for the relay R1070. At its contacts 1013, the relay R1010 prepares the operating circuit for the relay R1040. At its contacts 1014, the relay R1010 opens a point in the operating circuit for the relay R1020 and a point in the path for short-circuiting its own winding. At its contacts 1011 and 1012, the relay R1010 connects the link line conductors C984 and C985 to the line terminals of the repeating coil windings 1081 and 1082 over paths respectively including the condensers 1016 and 1017. A transmission circuit is thus established between the control trunk 45 and the calling substation, whereby a portion of the busy tone current is transmitted over the calling end of the connection to signal the calling party that the desired line is busy.

If the operator desires to converse with the calling subscriber after receiving the busy signal and before releasing the connection, she may momentarily actuate the connect key 1292, thereby to terminate the busy signal and to reestablish a communication circuit with the calling substation. Thus, when the key 1292 is operated the relays R1210, R950 and R1000 sequentially operate in the order named and in the manner previously described. These relays release in the same order when the key 1292 is released. The relay R1000, in operating, completes a circuit for energizing the relay R1040, this circuit extending by way of the grounded holding lead C1092, the contacts 1002, 1013 and 1033 and the wind-

ing of R1040 to battery. In operating the relay R1040 locks to the grounded lead C1092 through its contacts 1041 and the upper winding of the relay R1030 and thus short-circuits this winding. When the relay R1000 subsequently releases, the path short-circuiting the upper winding of the relay R1030 is opened at the contacts 1002 and this winding is energized in series with the relay R1040. The relay R1030 now operates to open the busy tone current transmission circuit at its contacts 1036. Thus, the busy signal is terminated. At its contacts 1031 and 1032, the relay R1030 again connects the link line conductors C984 and C985 to the line terminals of the repeating coil windings 1081 and 1082, thereby to reestablish a talking circuit between the calling substation and the operator's telephone set and to recomplete the initially traced circuit for energizing the pulsing relay R450 in series with the two windings of the relay R460. At its contacts 1034, the relay R1030 opens the previously traced locking circuit for the relay R1100. The relay R1100 now restores to open, at its contacts 1101 and 1102 the above-traced auxiliary circuit for energizing the relay R450 in series with the two windings of the relay R460. Following the operations just described, no further operation of the apparatus occurs until the connection is released under the control of the operator handling the call at the operator's position 60.

In the event the desired line 61 is idle at the time it is selected, in the manner explained above, battery potential is present upon the private conductor 61d thereof, so that the busy test relay R1110 is effectively short-circuited during the interval when the test circuit including the winding of this relay is completed. Accordingly, the busy test relay does not operate. Shortly following the selection of the called line 61 and when the relay R1140 restores, in the manner previously explained, the operating circuit for the line switching relay R1110 is completed. This circuit extends from ground by way of the contacts 1161, 1112 and 1131, the upper winding of R1110, the contacts 1141, the wiper 1179, the private conductor 61d, and the winding of the cut-off relay embodied in the line circuit 62 to battery. When thus energized, the cut-off relay of the line circuit 62 operates to disconnect the winding of its associated line relay from the talking conductors of the line 61, in the usual manner. The relay R1110 also operates when energized over the above-traced circuit. In operating, this relay first completes a locking circuit for itself at its X contacts 1114. This circuit extends from ground by way of the contacts 1163 and 1114, and the lower winding of R1110 to battery. After this locking circuit is completed, the relay R1110 opens its contacts 1112 and closes its contacts 1112'. At the contacts 1112', a path including the contacts 1181 and the wiper 1179 is completed for impressing ground potential directly upon the private conductor 61d of the line 61, thereby to mark this line as busy in the bank contacts of the other connector switches and to maintain the energization of the cut-off relay embodied in the line circuit 62. At its contacts 1115, the relay R1110 opens a point in the previously traced circuit for energizing the magnet 1183 in parallel with the respective upper windings of the two relays R1140 and R1150. At its contacts 1116, the relay R1110 prepares a point in the operating circuit for the relay R1070. In this regard it is pointed out that only those

contacts of the contact set 1176 which correspond to the positions assigned for terminating the trunks 43 and 44 extending to the trunk circuits illustrated in Figs. 3, 4, 5 and 6 of the drawings are connected to ground. Further, this ground connection to the indicated contacts extends to corresponding contacts of each of the other connector switches. The remaining contacts of the contact set 1176 in the connector switch 1170, and the corresponding contacts of the other connector switches, are left unwired. Accordingly, the relay R1070 is, in the case under consideration, not energized in response to operation of the line switching relay R1110.

At its contacts 1111 and 1113, the relay R1110 connects the talking conductors of the called line 61 to the line terminals of the repeating coil windings 1081 and 1082 over paths respectively including the line wipers 1177 and 1178 of the connector switch 1170, the link line conductors C1090 and C1091, and the contacts 1074 and 1072. Thus, a circuit is completed, whereby the operator may transmit ringing current over the control trunk 45 through the repeater 1080 and over the conductors of the called line 61 to energize the signal device provided at the called substation F. To this end, the operator first restores the dial key 1285 to normal, thereby to cause the relay operations described above in connection with the routing of the call to a busy line. In the course of these operations, the two relays R1020 and R1010 are caused to operate so that the calling line is effectively connected to the control trunk 45 through the condensers 1016 and 1017. After restoring the dial key 1285 to normal, the operator actuates the ringing key 1291 in accordance with the code assigned to the substation F, assuming the line 61 to be of the multiparty type. Each time this key is operated to close its contacts, a circuit including the contacts 1212 is completed for energizing the slow-to-operate ringing control relay R1200. This relay, in operating, opens its contacts 1201 and 1203 to insert the condensers 1205 and 1206 in the local link including the receiver of the operator's telephone set. At its contacts 1202 and 1204, the relay R1200 completes a circuit for transmitting ringing current through the windings 1276 and 1278 of the repeating coil 1275. This circuit extends from the ungrounded terminal of the ringing current generator 1293, by way of the contacts 1204, the windings 1278 and 1276 in series, and the contacts 1202 to the grounded terminal of the ringing current generator. A portion of the ringing current is bypassed through the condensers 1206 and 1205 and the receiver of the operator's telephone set, so that the usual ring-back tone signal is reproduced by this receiver. The current traversing the windings 1276 and 1278 is, by induction, repeated to the link including the repeating coil windings 1277, 1279, 1084 and 1085, and the control trunk 45. The ringing current traversing the last-mentioned link circuit is, in turn, repeated to the circuit extending to the called substation F and including the repeating coil windings 1081 and 1082. The ringing current traversing the latter circuit results in the energization of the signal device provided at the called substation F, in the usual manner, so that the called party is signaled. A portion of the ringing current traversing the windings 1081 and 1082 of the repeating coil 1080, is by-passed through the condensers 1016 and 1017 to the calling end of the connection, whereby the receiver provided

at the calling substation is energized to produce the usual ring-back tone signal. Thus, an indication is given to the calling subscriber that the called substation is being rung. After the ringing operation is completed, the non-locking ringing key 1291 is released to deenergize the ringing control relay R1200. With this relay in its restored position, a talking circuit including the repeating coils 1275 and 1080, and the control trunk 45, is established between the operator's telephone set and the called line 61. Accordingly, when the call is answered, the operator may instruct the answering party to hold the connection for a short time interval. After the call is answered, the operator, in order to establish a talking circuit between the calling and called substations, momentarily operates the connect key 1292 to its off-normal position to complete an obvious circuit for energizing the slow-to-release relay R1210. The relay R1210, in operating, unbalances the circuit for energizing the differentially wound relay R950 by opening, at its contacts 1211, the branch circuit for energizing the upper winding of this relay. The relays R950 and R1000 are thus caused sequentially to operate. In operating, the relay R1000 opens, at its contacts 1001, the path short-circuiting the condenser 1075, but this operation is without effect in the present instance. At its contacts 1002, the relay R1000 completes the above-traced operating circuit for the relay R1040. The relay R1040, in operating, locks to ground over a path including the upper winding of R1030, the contacts 1041, C1092, and the contacts 1162. When this locking circuit is completed, the upper winding of R1030 is short-circuited in an obvious manner. Thereafter, and when the connect key 1292 is released by the operator to cause the sequential deenergization and release of the relays R1210, R950 and R1000, the path short-circuiting the upper winding of R1030 is interrupted at the contacts 1002, permitting this winding to be energized in series with the relay R1040. When thus energized, the relay R1030 operates to open, at its contacts 1033, a further point in the operating circuit for the relay R1040. At its contacts 1034, the relay R1030 opens the previously traced locking circuit for the relay R1100. At its contacts 1031 and 1032, the relay R1030 connects the link line conductors C984 and C985 directly to the conductors of the called line 61, and directly to the line terminals of the repeating coil windings 1081 and 1082. Thus, a three-way communication connection is established between the calling substation served by the calling one of the lines 11, 12 and 13, the called substation F, and the operator's telephone set. It will be noted that when the link line conductors C984 and C985 are reconnected to the line terminals of the repeating coil windings 1081 and 1082, the initially traced circuit for energizing the line relay R450 in series with the two windings of the differentially wound relay R460, is recompleted. Shortly thereafter, the relay R1100 restores to open, at its contacts 1101 and 1102, the previously traced alternative circuit for energizing the relay R450 in series with the two windings of the relay R460. Following the release of the relay R1100, no further operation of the apparatus occurs until the connection is cleared out under the control of the operator handling the call at the operator's position 60. In this regard it will be understood that the operator attending this position may monitor the connection from time to time to ascertain when

the connection is no longer desired, or may rely upon the operation of the disconnect signal device embodied in her cord circuit to produce an indication that the connection is no longer desired. It will also be understood that the calling subscriber, served by one of the lines 11, 12 and 13 terminating at the distant switching center 10, is expected to actuate the hand generator provided at the calling substation for the purpose of energizing the disconnect signal device of the operator's cord circuit when the connection is no longer desired. In response to this operation, ringing current is transmitted over the trunk 31 through the repeating coil 303, over the trunk 43, through the line wipers of the finder switch 970, over the link line C984, C985, through the repeating coil 1080, over the control trunk 45, and through the repeating coil 1275, to energize the drop or other disconnect signal device bridged across the talking conductors of the operator's cord circuit in use at the operator's position 60. The operation of this device serves to inform the operator that the connection is ready to be released.

In order to release the connection, the operator withdraws the answer plug of her cord circuit from the jack 1281. In response to this operation, the contacts 1282 are disengaged to open the operating and locking circuits for the relays R1230 and R1250, respectively. These two relays, in restoring, open the operating circuit for the relay R1220. The relay R1230, in restoring, also opens, at its contacts 1232, 1233 and 1237, the previously traced circuit for energizing the pulsing relay R940 in series with the two windings of the relay R950. The relay R940 is thus de-energized and restores. In releasing, this relay opens, at its contacts 943, the locking circuit for the slow-acting hold relay R930. The relay R930 restores after an interval to open, at its contacts 932, the holding circuit for the relay R920 and a further point in its own holding circuit. At its contacts 933, the relay R930 opens the operating circuit for the slave relay R1160. Thus, the two relays R920 and R1160 are de-energized and restore. The relay R1160, in releasing, opens, at its contacts 1161, a point in the previously traced locking circuit for the busy test relay R1130, causing the last-mentioned relay to restore, if operated. At its contacts 1162, the relay R1160 opens one of the multiple paths for impressing ground potential upon the lead C1092. The other of these paths is opened at the contacts 925 in response to the release of the relay R920. When this lead is disconnected from ground, the operated ones of the relays R1010, R1020, R1030, R1040 and R1050 are all deenergized and restore. At its contacts 1163, the relay R1160 opens the previously traced locking circuit for the relay R1110, causing the latter relay to restore. Thus, all of the relays embodied in the finder-connector link 40 are restored to normal.

The relay R1160, in releasing, also opens, at its contacts 1161, the previously traced path for impressing ground potential upon the private conductor 61d of the called line 61. In response to this operation, the cut-off relay embodies in the line circuit 62 is deenergized and restores, and the line 61 is marked as idle in the bank contacts of the connector switches having access thereto. The relay R1160, in restoring, also completes the previously mentioned alternative circuit for energizing the connector switch operating magnet 1133. This circuit extends from ground by way

5 of the wiper 1181, the multiplied second to tenth contacts of the contact set 1175, the contacts 1166 and 1184, and the winding of the magnet 1183 to battery. Due to the circuit interrupting action of the contacts 1184 included in this circuit, the magnet 1183 operates buzzer fashion to drive the wipers of the connector switch 1170 back to their respective normal or first positions, wherein the multiplied contacts of the contact set 1175 are disconnected from ground to open the alternative operating circuit for the magnet 1183. Thus, operation of the magnet 1183 is arrested when the wipers of the connector switch 1170 are restored to normal. With these wipers at normal, the previously traced operating circuit for the finder switch operating magnet 981, is reprepared at the wiper 1180 and its associated normal contact. Further, the path for impressing ground potential upon the guard lead 912, individual to the link 40, is recompleted, thereby to mark this link as idle in the contacts of the distributor relays embodied in the distributor 48. This path extends from ground by way of the contacts 1151, the wiper 1180 and its associated normal contact, C988, and the contacts 931 and 926 to the guard conductor 912. When the connector switch wiper 1181 is restored to its normal position, the previously traced operating circuit for the relay R1030 is reprepared. After the operations just described are completed, the finder-connector link 40 is fully restored to normal.

When the line switching relay R920 restores, in the manner pointed out above, the contacts 921 and 922 are disengaged to open the above-traced circuits for energizing the pulsing relay R450 in series with the two windings of the relay R460. At its contacts 924, the relay R920 disconnects the control conductor 43c from ground, thereby to cause the deenergization and release of the cut-off relay R410 and to remove guarding ground potential from the private conductor 43d of the trunk 43. The trunk circuit 43 is thus marked as idle in the bank contacts of the connector switches provided in the tandem exchange. The relay R450, in releasing, opens, at its contacts 453, the operating circuit for the slow-to-release hold relay R440, and completes, at its contacts 451, the operating circuit for the slow-to-release relay R420. This circuit extends from ground by way of the contacts 441 and 451, C409, the contacts 384, 374 and 364, C415, and the winding of R420 to battery. At its contacts 452, the relay R450 prepares a circuit for energizing the upper winding of R390 in parallel with the relay R360. This circuit is completed in response to operation of the relay R420 and extends from ground by way of the contacts 452 and 423 to C419, where it divides, one branch extending through the contacts 395 and the upper winding of R390 to battery, and the other branch extending through the contacts 376 and 366, and the winding of R360 to battery. The resulting operation of the relays R360 and R390 is without effect at the present time. Shortly following the operation of the relays R420, R390 and R360, the hold relay R440 restores to open, at its contacts 441, the operating circuit for the relay R430, and points in the operating and locking circuits for the relays R390, R470 and R480. At its contacts 442, the relay R440 disconnects the locking lead C423 from ground, thereby to deenergize the operated one of the three relays R310, R330 and R350, and to open a point in the locking circuits for the relays R360, R362, R370, R372, R380 and R382. Shortly following the release of the relay

R449, the relay R420 restores to open the previously mentioned circuit for energizing the relays R360 and R390 in parallel. Following the release of the relay R420 and the relays R360 and R390, the relay R430 restores to reconnect the locking lead C423 to ground. Thus, all of the relays embodied in the trunk circuit illustrated in Figs. 3 and 4 of the drawings are released. When the one of the three relays R310, R330 and R350, which corresponds to the calling subscribers line releases in response to the release of the relay R440, it opens the completed path for impressing either negative or positive battery potential upon one of the two sides of the trunk 31. Accordingly, the operated one of the three relays R120, 15 R130 and R140, provided at the switching center 10, is deenergized and restores. Thus, all of the apparatus involved in setting up the connection between a substation served by one of the lines 11, 12 and 13 terminating at the switching center 10 and a line terminating at the tandem exchange is fully released.

In the event the above-described call, routed to the central office operator's position 60 from a line terminating at the switching center 10, is extended to a line terminating at the central office, the connector portion of the link 40 is, of course, not utilized in setting up the connection. Accordingly, at the time the connection is ready to be released, only the relays R920, R930, R940, R1030, R1050 and R1160 of the link 40 are operated. These relays are released when the connection is cleared out at the operator's position 60 to cause the deenergization and release of the trunk circuit relays R1220, R1230 and R1250, in the manner explained above. Thus, the relays R940, R930 and R920 are sequentially released in the order named when the relay R1230 restores. The relay R920, upon restoring, causes the trunk circuit illustrated in Figs. 3 and 14 of the drawings and the operated switching equipment at the switching center 10 to release in the exact manner explained above. The relay R930, in releasing, opens, at its contacts 933, the operating circuit for the relay R1160. The relay R1160, in restoring, opens, at its contacts 1167, the operating circuit for the relay R1030. The relays R1160 and R920, in restoring, open the two paths for impressing ground potential upon the locking lead C1092, and, accordingly, the relay R1050 is deenergized and restores. Thus, all of the apparatus embodied in the finder-connector link 40 is restored to normal.

If the above described call, initiated on one of the subscribers lines terminating at the switching center 10, is to be routed to a substation associated with another of these lines, the operator handling the call at the operator's position 60, after answering the call and ascertaining the directory number of the desired substation, may cause the desired connection to be set up by operating the dial key 1285 to its off-normal position and actuating the calling device 1284 to dial the two digits of this number. The first of these digits is utilized to direct the wipers of the connector switch 1170 into engagement with the contacts terminating the conductors of the trunk 43. The second digit is utilized to set the line select relays R360, R362, R370, R372, R380 and R382, in accordance with the particular line desired by the calling subscriber.

The manner in which the connector portion of the link 40 responds to the impulses of the first digit dialed by the operator, is exactly the same as described above with reference to the call

routed to the line 61. At the end of this digit, the wipers of the connector switch 1170 are left standing in engagement with the contacts terminating the conductors of the trunk 43. This trunk is, of course, marked busy, due to the presence of ground potential upon the private conductor 43d thereof. Accordingly, the busy test relay R1130 is energized immediately the trunk 43 is selected. This relay is locked to ground over a path including the contacts 1143, 1132, 1112 and 1161 when the relay R1140 restores shortly after the end of the first digit. In the case under consideration, the relay R1150, upon restoring shortly following the end of the first digit, completes a circuit for energizing the upper winding of the reverting call relay R1120, this circuit extending from ground by way of the contacts 1151, the wiper 1180, C989, the wiper 979, the contacts 927, C991, the contacts 1134, and the upper winding of R1120 to battery. In this regard it is pointed out that only those contacts of the contact set 1174 which correspond to the trunks 43 and 44 individual to the two trunk circuits illustrated in Figs. 3, 4, 5 and 6 of the drawings, are connected to the corresponding contacts of the contact set 974 in the finder switch 970. Thus, the conductor C989' is used to connect the respective sixth contacts of the contact sets 974 and 1174, which contacts respectively correspond to the trunk 44 extending to the trunk circuit illustrated in Figs. 5 and 6 of the drawings. This cross wiring between the finder and connector switch contact banks is only provided for the contacts of these banks which correspond to the two trunk circuits illustrated, the remaining contacts of the two contact sets 974 and 1174 being left unwired. The same wiring arrangement is used in the other finder-connector links provided in the tandem exchange.

The reverting call relay R1120, upon operating, locks to ground over a path including the contacts 1121 and 1163. At its contacts 1122, the relay R1120 completes a circuit including the contacts 1163 for energizing the line switching relay R1110. At its contacts 1123, the relay R1120 opens the previously traced locking circuit for the relay R1100. At its contacts 1124, the relay R1120 opens a point in the previously traced circuit for transmitting busy tone current over the control trunk 45 to the operator's position 60. The line switching relay R1110, upon operating, locks to ground over a path including the contacts 1114 and 1163. At its contacts 1115, the relay R1110 opens the previously traced circuit for transmitting current pulses to the magnet 1183 and the respective upper windings of the two relays R1140 and R1150. At its contacts 1112, the relay R1110 opens the locking circuit for the busy test relay R1130. At its contacts 1111 and 1113, the relay R1110 connects the line terminals of the repeating coil windings 1081 and 1082 to the conductors 43a and 43b of the trunk 43. In response to this operation, a multiple circuit is completed for energizing the pulsing relay R450 in series with the two windings of the relay R460. One branch of this circuit extends from ground by way of the winding of R450, the upper winding of R460, C408, the winding 307, the conductor 43b, the wiper 1178, the contacts 1113, C1091, the contacts 1001 and 1074, the winding 1081, and the right winding of the balancing coil 1065 to battery. The other branch of this circuit extends from ground by way of the winding of R450, the lower winding of R460, C407, the winding 308, the conductor

43a, the wiper 1177, the contacts 1111, C1090, the contacts 1072, the winding 1082 and the right winding of the balancing coil 1065 to battery. Thus, a circuit through the connector switch wipers 1177 and 1178 is established for maintaining the energization of the pulsing relay R450 after the relay R1100 is released to interrupt the previously traced alternative circuit for energizing this pulsing relay. In this regard it will be noted that the relay R1100 restores shortly following the operation of the line switching relay R1110. It will also be noted that the busy test relay R1130 restores shortly following operation of the line switching relay R1110 to open, at its contacts 1135, the prepared busy tone transmission circuit.

The line switching relay R1110, in operating, also completes, at its contacts 1116, the prepared operating circuit for the relay R1070, this circuit extending from the grounded contact engaged by the wiper 1182, by way of this wiper, the contacts 1116, C1093, the winding of R1070 and the contacts 1015 to battery. In this regard it is pointed out above that only those contacts of the contact set 1176 which correspond to the two trunk circuits illustrated in Figs. 3, 4, 5 and 6 of the drawings, are connected to ground, the remaining contacts of this contact set being left unwired. The same wiring is used in the other connector switches provided in the tandem exchange. The relay R1070, in operating, completes, at its contacts 1071 and 1073, a second alternative circuit for energizing the relay R450 in series with the two windings of the differentially wound relay R460. One branch of this circuit extends from ground by way of the winding of R450, the lower winding of R460, C407, the winding 306, the conductor 43a, the wiper 1177, the contacts 1111, C1090, the contacts 1071, C983, the contacts 941 and the resistor 944 to battery. The other branch of this circuit extends from ground by way of the winding of R450, the upper winding of R460, C408, the winding 307, the conductor 43b, the wiper 1178, the contacts 1113, C1091, the contacts 1004 and 1073, C983, the contacts 941 and the resistor 944 to battery. After this alternative circuit is completed, the relay R1070, at its contacts 1072 and 1074, opens the circuit initially established through the connector switch wipers for energizing the pulsing relay R450.

It will be observed that following operation of the relay R1070, the line R940 is connected to repeat the impulses of the second digit dialed at the operator's position 60 to the pulsing relay R450 of the trunk circuit illustrated in Figs. 3 and 4 of the drawings. Thus, during the open circuit period of each impulse, the relay R940 restores to open, at its pulsing contacts 941, the two branches of the second alternative circuit for energizing the pulsing relay R450 in series with the two windings of the differentially wound relay R460. Further, these pulsing contacts are closed at the end of the open circuit period of each impulse to recomplete the circuit for energizing the pulsing relay R450.

The relay R450, upon restoring at the beginning of the open-circuit period of the first impulse of the second digit dialed at the operator's position 60, completes, at its contacts 451, the 70 previously traced operating circuit for the relay R420, and prepares, at its contacts 452, the pulsing circuit to the relays R360, R362, R370, R372, R380 and R382. At its contacts 453, the relay R450 opens the operating circuit for the hold

relay R450. The relay R450, due to its slow-to-release characteristic, remains operated during impulsive. The relay R420, upon operating, completes, at its contacts 421, an obvious alternative circuit over which current pulses are transmitted through its winding in response to further operation of the pulsing relay R450. Due to its slow-to-release characteristic, the relay R420 remains operated during impulsive. 5 At its contacts 422, the relay R420 completes the prepared pulsing circuit, thereby to energize the relay R360, this circuit extending from ground by way of the contacts 452 and 423, C419, the contacts 376 and 366, and the winding of R360 to battery. In operating, the relay R360 locks to ground over a path including the contacts 361, the winding of R362, the contacts 378 and 381, C423, and the contacts 442. When this locking circuit is completed, the relay R362 is 10 short-circuited in an obvious manner. In operating, the relay R420 also completes the prepared operating circuit for the reverting call relay R390, this circuit extending from ground by way of the contacts 452 and 423, C419, the contacts 395 and the upper winding of R390 to battery. The relay R390, in operating, locks to ground over a path including the contacts 394, C418, and the contacts 482 and 441. At its contacts 395, the relay R390 opens its operating circuit after the above-traced locking circuit is completed. At one of its sets of contacts 391, 392 and 393, the relay R390 opens the completed one of the previously traced paths for impressing positive or negative potential upon one of the 15 two sides of the trunk 31, thereby to deenergize the operated one of the three line switching relays R120, R130 and R140 provided at the distant switching center 10. This relay, in releasing, disconnects the calling one of the three lines 20 11, 12 and 13 from the trunk 31.

At the end of the open-circuit period of the first impulse transmitted to the pulsing relay R450, this relay reoperates to open, at its contacts 452, the path short-circuiting the winding of the relay R362. When the path short-circuiting the relay R362 is broken, this relay is 25 energized in series with the relay R360 over a circuit which extends from ground by way of the contacts 442, C423, the contacts 381 and 378, the winding of R362, the contacts 361 and the winding of R360 to battery. In operating, the relay R362 opens, at its contacts 366, the pulsing circuit to the relay R360. At its contacts 367, the relay R360 extends the pulsing circuit to the relay R370. At its contacts 365, the relay R362 prepares an alternative circuit for energizing the relay R310. At its contacts 364, the relay R362 opens a point in the above-traced operating circuit for the slow-to-release relay R420. At its contacts 363, the relay R362 prepares or completes a path for impressing negative battery potential upon the trunk conductor 31a, depending upon the position of the relay R310. Thus, if the relay R310, which corresponds to the line 11 terminating at the switching center 10, is operated, the path mentioned above is completed, this path extending from the negative terminal of the exchange battery provided in the tandem exchange, by way of the resistor 397, the contacts 363 and 312, and the winding 304 to the conductor 31a. When this path is completed, the relay R130, provided at the switching center 10 and corresponding to the line 11, is energized and operates to connect the line 11 to the trunk 31. If, on the other

hand, the relay R310 is not operated at the time the relay R362 operates, the path just traced is held open at the contacts 312.

At the beginning of the open circuit period of the second impulse transmitted to the relay R450, this relay again restores to complete the prepared circuit for energizing the relay R370, this circuit extending from ground by way of the contacts 452 and 423, C419, the contacts 376 and 367, and the winding of R370 to battery. The relay R370, in operating, locks to ground over a path extending by way of the contacts 371, the winding of R372, the contacts 387, C423 and the contacts 442. In completing this path, the relay R370 short-circuits the winding of the relay R372 in an obvious manner. When the pulsing relay R450 subsequently reoperates, this short-circuiting path is interrupted at the contacts 452, permitting the relay R372 to be energized in series with the relay R370 over a circuit extending by way of the grounded conductor C423, the contacts 387, the winding of R372, the contacts 371, and the winding of R370 to battery. In operating, the relay R372 opens, at its contacts 378, the previously traced circuit for energizing the relay R362 in series with the relay R360. The relay R362 is thus caused to restore to open, at its contacts 363, the completed or prepared path for impressing negative battery potential upon the upper trunk conductor 31a. Assuming the relay R310 to be energized, the interruption of this path results in the deenergization and release of the line switching relay R130 provided at the switching center 10, whereby the line 11 is disconnected from the trunk 31. At its contacts 365, the relay R362, in releasing, opens the prepared alternative operating circuit for the relay R310. At its contacts 364, the relay R362 reprepares a point in the previously traced operating circuit for the relay R420. At its contacts 366, the relay R362 reprepares the operating circuit for the relay R360. At its contacts 367, the relay R362 opens a point in the above-traced operating circuit for the relay R370.

The relay R372, in operating, also opens, at its contacts 376, a further point in the operating circuit for the relay R370. At its contacts 377, the relay R372 extends the pulsing circuit to the relay R380. At its contacts 375, the relay R372 prepares an alternative operating circuit for the relay R330. At its contacts 374, the relay R372 opens another point in the previously traced operating circuit for the relay R420. At its contacts 373, the relay R372 prepares or completes a path for impressing negative battery potential upon the lower trunk conductor 31b, depending upon the position of the relay R330. Thus, if the line 12 terminating at the switching center 10, is the calling line, such that the relay R330 is operated, the above-mentioned path is completed, this path extending from the negative terminal of the exchange battery by way of the resistor 396, the contacts 373 and 333, and the winding 305 to the trunk conductor 31b. When this path is completed, the relay R140 is energized and operates to connect the conductors of the calling line 12 to the trunk 31. If, on the other hand, the relay R330 occupies its restored position at the time the relay R372 operates, the above-traced path is only prepared, this path being held open at the restored contacts 333 of the relay R330.

At the beginning of the open circuit period of the third impulse transmitted to the pulsing re-

lay R450, this relay restores to complete the prepared operating circuit for the relay R380. This circuit extends from ground by way of the contacts 452 and 423, C419, the contacts 377 and 386, and the winding of R380 to battery. In operating, the relay R380 locks to ground over a path including the contacts 381, the winding of R382, C423 and the contacts 442. When this path is completed, the relay R382 is short-circuited in an obvious manner. At the end of the open circuit period of the third impulse, the pulsing relay R450 reoperates to open the path short-circuiting the winding of the relay R382. A circuit is thus completed for energizing the relay R382 in series with the relay R380, this circuit extending from ground by way of the contacts 442, C423, the winding of R382, the contacts 381 and the winding of R380 to battery. The relay R382 now operates to open, at its contacts 387, the previously traced locking circuit for the two series connected relays R370 and R372, causing both of these relays to restore. The relay R372, in releasing, opens, at its contacts 375, the prepared alternative operating circuit for the relay R330. At its contacts 374, the relay R372 reprepares the previously traced operating circuit for the relay R420. At its contacts 377, the relay R372 opens another point in the operating circuit for the relay R380. At its contacts 376, the relay R370 reprepares the operating circuit for the relay R360. At its contacts 378, the relay R370 reprepares the above-traced locking circuit for the two relays R360 and R362. At its contacts 373, the relay R372 opens the above-traced path for impressing negative battery potential upon the lower trunk conductor 31b, thereby to deenergize the line switching relay R140, if operated.

The relay R382, in operating, opens, at its contacts 386, a further point in the operating circuit for the relay R380. At its contacts 385, the relay R382 prepares an alternative circuit for energizing the relay R350. At its contacts 384, the relay R380 opens another point in the previously traced operating circuit for the relay R420. At its contacts 383, the relay R382 prepares or completes a path for connecting the positive terminal of the auxiliary current source provided in the tandem exchange to the upper trunk conductor 31a, depending upon the position occupied by the relay R350. If the relay R350 is operated, this path, which includes the resistor 398, the contacts 383, 352 and 313, and the winding 304, is completed. When positive potential is thus impressed upon the trunk conductor 31a, the relay R120 is energized and operates to connect the line 13 to the trunk 31. If, on the other hand, the relay R350 is not operated, the above-traced path is only prepared at the contacts 383 in response to operation of the relay R382.

As indicated by the above explanation, the number of impulses of the second digit dialed at the control operator's position 60 determines which of the three lines 11, 12 and 13 is to be connected to the trunk 31. Thus, if a second digit of one impulse is dialed, only the relays R360 and R362 of the line selecting relay group are operated at the end of the digit. These relays correspond to the line 11, as will be apparent from the following explanation. On the other hand, if the second digit dialed at the control operator's position comprises two impulses, the relays R370 and R372 are locked operated at the end of the digit. These relays correspond

to the line 12 terminating at the switching center 10. Finally, if the second digit dialed at the control operator's position comprises three impulses, the relays R380 and R382 are locked up at the end of the digit. These relays correspond to the line 13.

At the end of the digit, the relay R450 is operated to maintain the relay R420 deenergized. Accordingly, the relay R420 restores shortly following the end of the digit. At its contacts 423, the relay R420 opens a point in the common portion of the operating circuits for the relays R360, R370 and R380. At its contacts 422, the relay R420 completes the auxiliary operating circuit for one of the three relays R310, R330 and R350. More specifically, if the relay R362 is operated at the end of the digit, the auxiliary operating circuit for the relay R310 is completed in response to the release of the relay R420. This circuit extends from ground by way of the contacts 422, C418, the contacts 365 and the winding of R310 to battery. In operating, the relay R310 locks to ground over a path including the contacts 317 and the grounded conductor C423. At its contacts 312, the relay R310 completes the previously traced path for impressing negative battery potential upon the upper trunk conductor 31a, thereby to energize the relay R130. In operating, the relay R130 connects the called line 11 to the trunk 31.

If the relay R372 is operated at the end of the second digit dialed at the control operator's position, indicating that the line 12 is the called line, the relay R420, in releasing, completes the prepared operating circuit for the relay R330. This circuit extends from ground by way of the contacts 422, C418, the contacts 375 and the winding of R330 to battery. The relay R330, in operating, locks to ground over a path including its contacts 336 and the lead C423. At its contacts 333, the relay R330 completes the previously traced path for impressing negative battery potential upon the lower trunk conductor 31b, thereby to energize the relay R140 provided at the switching center 10. In operating, the relay R140 connects the called line 12 to the trunk 31.

If the relay R382 is operated at the end of the second digit dialed at the control operator's position, indicating that the line 13 is the called line, the relay R420, upon restoring, completes the prepared operating circuit for the relay R350. This circuit extends from ground by way of the contacts 422, C418, the contacts 385, and the winding of R350 to battery. The relay R350, in operating, locks to the grounded lead C423 through its contacts 355. At its contacts 352, the relay R350 completes the previously traced path for connecting the positive terminal of the auxiliary current source provided in the tandem exchange to the upper trunk conductor 31a, thereby to energize the relay R120 provided at the switching center 10. The relay R120, in operating, connects the conductors of the called line 13 to the conductors of the trunk 31. It will be observed that, after one of the three relays R120, R130 and R140 operates to connect the called subscriber's line to the trunk 31, a connection including the repeating coil 393 is completed between the called line and the line contacts 1071 and 1073 of the relay R1070. In order to extend this connection to the operator's position, the operator restores the dial key 1285 to normal, thereby to cause the momentary operation of the two relays R950 and R1000, in the manner previously explained. In operating, the relay

R1000, at its contacts 1003, completes the prepared operating circuit for the relay R1020. The relay R1020, accordingly, operates and locks to ground over a path including the contacts 1021 and the winding of the relay R1010. The relay R1010 is thus short-circuited. At its contacts 1001, the relay R1000 opens the previously traced branch circuit extending by way of the upper winding of the relay R460 for energizing the relay R450. The lower winding of this relay is held energized in series with the relay R450 over the other of the two branch circuits traced above. Thus, the differentially wound relay R460 is caused to operate. In operating, the relay R460 completes a circuit for energizing the relay R470, this circuit extending from ground by way of the contacts 441 and 482, C416, the contacts 394, C417, the contacts 462, and the winding of R470 to battery. At its contacts 461, the relay R460 opens a point in the common portion of the locking circuits for the relays R390, R470 and R480. In operating, the relay R470 locks to the grounded lead C417 over a path including its contacts 471 and the winding of R480 and thus short-circuits the relay R480. Shortly following the operations just described, the relays R950 and R1000 are caused sequentially to restore, in the manner previously described. In releasing, the relay R1000 recompletes, at its contacts 1001, the branch circuit for energizing the upper winding of the relay R460 in series with the pulsing relay R450. At its contacts 1003, the relay R1000 opens the path short-circuiting the relay R1010, permitting the latter relay to be energized in series with the relay R1020. In operating, the relay R1010 opens, at its contacts 1014, a point in the operating circuit for the relay R1020 and, in so doing, opens another point in the path for short-circuiting its own winding. At its contacts 1013, the relay R1010 prepares the operating circuit for the relay R1040. At its contacts 1015, the relay R1010 opens the previously traced operating circuit for the relay R1070. The relay R1070 now restores to again connect the line terminals of the repeating coil windings 1081 and 1082 to the trunk conductors 43a and 43b through the line wipers of the connector switch 1070. In response to this operation, the relay R450 is again energized in series with the two windings of the relay R460 over the initially traced circuit extending through the connector switch wipers 1177 and 1178. After the recompletion of this circuit, the contacts 1071 and 1073 of the relay R1070 are disengaged to open the previously traced auxiliary circuit for energizing the pulsing relay R450 in series with the two windings of the relay R460.

When the relay R1000 restores to recomplete the branch circuit for energizing the upper winding of the relay R460 in series with the relay R450, the relay R460 is differentially energized and restores. In releasing, the relay R460 opens, at its contacts 462, the path short-circuiting the winding of the relay R480. The relay R480 is thus energized in series with the relay R470 over a circuit which extends from ground by way of the contacts 441 and 482, C416, the contacts 394, C417, the winding of R480, the contacts 471 and the winding of R470 to battery. When thus energized, the relay R480 operates after an interval to complete a locking circuit for itself and the relay R470. This locking circuit extends from ground by way of the contacts 441, 461 and 481, C416, the contacts 394, C417, the winding of R480, the contacts 471 and the winding of R470

to battery. It will be noted that a branch of this circuit extends through the lower winding of the reverting call relay R390. After this circuit is completed, the relay R480, at its contacts 482, opens the initially traced operating circuit for the relay R470 and the initially completed locking circuit for the relay R390.

Following the operations just described, the operator handling the call at the operator's position 60 may signal the desired substation associated with the called one of the three lines 11, 12 and 13, by actuating the ringing key 1291 in accordance with the code assigned to the desired substation. Each time this key is moved off normal, the operating circuit for the ringing relay R1200 is completed, so that ringing current is transmitted from the generator 1293 to the signal devices provided at the substations served by the called line. The circuit traversed by this current includes the repeating coil 1275, the control trunk 45, the repeating coil 1080, the link line C1090, C1091, the connector switch wipers 1177 and 1178, the trunk conductors 43a and 43b, the repeating coil 303, the trunk 31, and the line contacts of the operated one of the three relays R120, R130 and R140. From this point the ringing current is transmitted over the called line to energize the ringers bridged across this line at the respective substations associated therewith. The coded signals produced by the energized ringers serve to inform the called subscriber that his substation is being called, and to inform the other subscribers served by the called line that the call is not intended for their substations.

After the ringing operation is completed and the call is answered, the operator momentarily actuates the connect key 1292 in order to cause the calling one of the three lines 11, 12 and 13 to be reconnected to the trunk 31. When this key is operated to its off-normal position, the relays R1210, R950 and R1000 are caused sequentially to operate, in the order named and in the manner previously explained. These relays obviously restore in the same order when the non-locking connect key 1292 is released by the operator. In operating, the relay R1000 completes the previously traced operating circuit for the relay R1040, and opens, at its contacts 1001, the branch circuit for energizing the upper winding of the differentially wound relay R460 in series with the relay R450. The relays R460 and R1040 are thus caused to operate. In operating, the relay R1040 locks to the grounded lead C1092 over a path including the upper winding of the relay R1030 and the contacts 1041. When this path is completed, the upper winding of the relay R1030 is short-circuited. The relay R460, in operating, opens, at its contacts 461, the previously traced locking circuit for the two relays R470 and R480. At its contacts 461, the relay R460 also opens the locking circuit for the relay R390. Thus, the relays R470, R480 and R390 are deenergized and restore. In releasing, the relay R390 completes, at one of its three sets of contacts 391, 392 and 393, the battery potential path which corresponds to the calling line. Thus, if the relay R310 is operated and corresponds to the calling line, the previously traced path is completed for impressing negative battery potential upon the upper trunk conductor 31a, thereby to energize the line switching relay R130 provided at the switching center 10. This relay, in operating, connects the calling line 11 to the trunk 31. On the other hand, if the relay R330 is operated and corresponds to the calling line, the

relay R390, in releasing, completes the previously traced path for impressing negative battery potential upon the lower trunk conductor 31b to cause the energization and operation of the relay R140. The relay R140, in operating, connects the calling line 12 to the trunk 31. Finally, if the relay R350 is operated and corresponds to the calling line, the relay R390, in releasing, completes the previously traced path for impressing the positive potential of the auxiliary current source upon one of the trunk conductors 31a and 31b, thereby to cause the energization and operation of the line switching relay R120 provided at the switching center 10. The relay R120, in operating, connects the calling line 13 to the trunk 31. From the above explanation it will be apparent that any two of the three line switching relays R120, R130 and R140 may be energized under the control of the trunk circuit illustrated in Figs. 3 and 4 to connect any two of the lines 11, 12 and 13 to the trunk 31. Thus, connections may be set up between any two of the three lines terminating at the switching center 10 under the control of this trunk circuit.

Shortly following the operations just described, the relay R1000 restores to recomplete the branch circuit for energizing the upper winding of the relay R460 in series with the relay R450. The relay R460 accordingly restores to reprepare, at its contacts 461, the above-traced locking circuits for the three relays R390, R470 and R480. In releasing, the relay R1000 also opens the path short-circuiting the upper winding of the relay R1030, permitting this winding to be energized in series with the relay R1040. The relay R1030 now operates to open a further point in the operating circuit for the relay R1040. At its contacts 1031 and 1032, the relay R1030 completes a multiple connection which extends from the trunk conductors 43a and 43b through the finder switch wipers 976 and 977 to the line terminals of the repeating coil windings 1081 and 1082. Thus, a multiple circuit for maintaining the relay R450 energized in series with the two windings of the relay R460 is completed. At its contacts 1034, the relay R1030 opens a further point in the locking circuit for the relay R1100. Following the operations just described, no further operation of the apparatus occurs until the connection is released under the control of the operator attending the operator's position 60.

When the disconnect signal device embodied in the operator's cord circuit in use at the operator's position 60 is energized to indicate that the connection is no longer desired, the operator may release the connection by withdrawing the answer plug of her cord circuit from the jack 1281. In response to this operation, the trunk circuit terminating the control trunk 45 at the operator's position 60 and the finder-connector link 40 are released in a manner clearly apparent from the above explanation with reference to the call routed to the subscriber's line 61. During the release of the finder-connector link 40, the reverting call relay R1120 is deenergized and restores in response to the release of the relay R1160. The circuits for energizing the pulsing relay R450 in series with the two windings of the relay R460 are also interrupted during the release of the link. The relay R450, upon restoring, opens the operating circuit for the hold relay R440 and re-completes the previously traced operating circuit for the relay R420. The resulting momentary operation of the relays R420, R360 and R390 is without effect. Shortly following the release

of the relay R450, the hold relay R440 restores to disconnect the holding lead C423 from ground and thus opens a point in the common portion of the locking circuits for the relays R360, R362, R370, R372, R380 and R382. Thus, the two operated relays of this group are deenergized and restore. In releasing, the operated one of the relays R362, R372 and R382 opens the associated auxiliary operating circuit for one of the relays R310, R330 and R350. When the lead C423 is disconnected from ground, the two operated ones of the relays R310, R330 and R350 are deenergized and restore to open the two completed paths for impressing battery potentials upon the two sides of the trunk 31. When battery potential is removed from the conductors of this trunk, the two operated ones of the relays R120, R130 and R140 are deenergized and restored. The relay R440, in restoring, also opens the operating circuit for the relay R420, and a point in the common portion of the operating circuits for the relays R390 and R360. Thus, the relays R360 and R390 are deenergized and restore. Shortly thereafter, the relay R430 restores to again connect the hold lead C423 to ground. Following the release of this relay, the trunk circuit illustrated in Figs. 3 and 4 of the drawings, and the apparatus provided at the switching center 10, are fully released. Thus, all of the equipment involved in setting up the connection between two of the 30 lines terminating at the switching center 10 is restored to normal.

Calls initiated on the subscribers' lines terminating at the tandem exchange are routed through the finder-connector links of the tandem exchange to the operator's position 60 in the central office in the exact manner described above with reference to the call routed through the trunk circuit illustrated in Figs. 3 and 4 of the drawings to the operator's position 60. Thus, if a call is initiated at the substation F served by the line 61, for example, the line relay of the line circuit 62 operates to connect the distributor start conductor C49 to ground and to mark the calling line in the bank contacts of the finder switches having access thereto. When ground potential is impressed upon the conductor C49, the finder portion of the assigned link functions to seize the calling line, to mark this line as busy, and to extend a connection from the calling line to the control trunk 45, all in the manner explained previously. Assuming that the link illustrated is assigned to the calling line 61, the two relays R1060 and R1050 cooperate momentarily to energize the signal control relay R1240 when the calling line is seized. The relay R1240, in operating, causes the operation of the two relays R1260 and R1270, whereby the signal lamp 1283 is energized. When the call is answered at the operator's position 60, a communication connection is established between the operator's telephone set and the calling substation. Further, the relays R1230, R1220, R940, R930 and R1160 are caused to operate and the two relays R950 and R1000 momentarily operate, but without effect.

The manner in which the call may be extended through the connector portion of the link to a substation associated with another subscriber's line terminating at the tandem exchange is exactly the same as set forth above with reference to the call routed to the substation F. In this regard it will be understood from the preceding description that, since the wipers of the finder switch 970 are positioned in engagement with the

5 contacts terminating the conductors of the subscriber's line 61, the two finder switch wipers 979 and 980 engage open-circuited contacts, assuming that the line 61 does not extend to a substation of the paystation type. In any case, the wiper 980 and the circuits in which this wiper is included, are not utilized in handling a call of the character under consideration. The wiper 979, on the other hand, may be utilized for the purpose of transmitting paystation tone current to the control operator's position 60 in the event a selected calling substation line terminating at the tandem exchange is of the paystation type. The manner in which the paystation tone current is transmitted over the control trunk 45 to the control operator's position in response to the momentary operation of the relay R1000 when the call is answered at the operator's position is exactly the same as set forth above. It is further pointed out that in handling a call of the character under consideration, the connector switch wiper 1182 engages an unwired contact. Accordingly, the circuits in which this wiper is included are not utilized in setting up the desired connection. It will also be understood that the conductors C989 and C989' interconnecting the contacts of the connector switch contact set 1174 with the contacts of the finder switch contact set 974 of the finder switch 970 have no utility in a call of the character under consideration. The manner in which the connection is released under the control of the operator handling the call at the operator's position 60, is also exactly the same as described above with reference to the call routed to the line 61 from one of the three lines terminating at the switching center 10.

40 If the call originating at the substation F and routed to the operator's position 60 is intended for a substation served by one of the three lines terminating at the switching center 10, the operator, after answering the call and ascertaining the line desired, may set up the connection to the desired line by dialing the two digits of the directory number assigned to this line. The impulses of the first digit are utilized to direct the wipers of the connector switch 1170 into engagement with the contacts terminating the conductors of the trunk 43 extending to the trunk circuit apparatus shown in Figs. 3 and 4 of the drawings. If this trunk circuit is in use at the time it is thus selected by the connector switch 1170, the trunk line 43 will test busy and, accordingly, a busy signal will be returned to the control operator, in the manner previously explained. Upon receipt of the busy signal, the operator may instruct the calling party that the called line is busy and release the connection in the manner described above.

45 If the trunk circuit apparatus illustrated in Figs. 3 and 4 of the drawings is idle at the time the trunk 43 is selected by the connector switch 1170, the line switching relay R1110 is energized over a circuit which extends from ground by way of the contacts 1161, 1112 and 1131, the upper winding of R1110, the contacts 1141, the wiper 1179, the private conductor 43d, the contacts 403 and the winding of the cut-off relay R410 to battery. When energized over this circuit, the relay R1110 operates and locks to ground through the contacts 1114 and 1163. At its contacts 1112', the relay R1110 completes a path including the wiper 1179 for impressing ground potential directly upon the private conductor 43d of the trunk line 43. When energized over the above-traced circuit, the cut-off relay R410 operates to

open, at its contacts 412, a point in the previously traced path for impressing ground potential upon the distributor start conductor C49. At its contacts 413 and 414, the relay R410 opens the previously traced operating circuits for the start relay R400. At its contacts 411, the relay R410 completes a path including the private conductor 43d for impressing ground potential upon the control conductor 43c.

At its contacts 1111 and 1113, the relay R1110 completes the previously traced circuit, including the right winding of the balancing coil 1065 and the connector switch line wipers 1177 and 1178, for energizing the pulsing relay R450 in series with the two windings of the differentially wound relay R460. At its contacts 1116, the relay R1110 completes the previously traced operating circuit for the relay R1070. In operating, the relay R1070, at its contacts 1071 and 1073, completes the previously traced alternative circuit, including the pulsing contacts 941 and the resistor 944, for energizing the pulsing relay R450 in series with the two windings of the relay R460. After this circuit is completed, the relay R1070, at its contacts 1072 and 1074, disconnects the line terminals of the repeating coil windings 1081 and 1082 from the trunk conductors 43a and 43b. Thus, the initially completed circuit for energizing the pulsing relay R450 in series with the two windings of the relay R460 is interrupted. Following the operation of the relay R1070, the control apparatus of the finder-connector link 40 is conditioned to repeat the impulses of the second digit to the trunk circuit illustrated in Figs. 3 and 4 of the drawings.

The relays R450, R449 and R430 sequentially operate in the order named when the above-traced circuit for energizing the relay R450 in series with the two windings of the differentially wound relay R460 is completed. The relay R449, at its contacts 442, connects multiple ground to the holding lead C423, and prepares, at its contacts 441, the previously traced operating and locking circuits for the relays R390, R420, R470, and R480. The relay R430, in operating, opens its contacts 431 to disconnect multiple ground from the holding lead C423. Following the relay operations just described, the trunk circuit illustrated in Figs. 3 and 4 of the drawings is conditioned to respond to the impulses repeated to this circuit by the pulsing relay R940 of the finder-connector link 40.

The manner in which the relay pairs R360, R362 and R370, R372 and R380, R382 are sequentially operated in response to the first, second and third impulses of the second digit dialed at the control operator's position and, more particularly, in response to operation of the pulsing relay R450 is exactly the same as set forth above. At the beginning of the open circuit period of the first impulse, when the line pulsing relay R450 first restores, the previously traced operating circuit for the relay R420 is completed. This relay, in operating, completes the path shunting the series connected contacts 364, 374 and 384, whereby its pulsing circuit is not opened in response to operation of the relays R362, R372 and R382. At its contacts 422, the relay R420 opens a point in the common portion of the previously traced auxiliary circuits for energizing the relays R310, R330 and R350. The reverting call relay R390 is energized over its previously traced operating circuit in response to the release of the pulsing relay R450 at the beginning of the open circuit period of the first impulse transmitted to the

pulsing relay. In operating, the relay R390 locks to ground over a path including the contacts 394, C416 and the contacts 482 and 441. After this locking circuit is completed, the relay R390 opens its operating circuit at its contacts 395. At its contacts 391, 392 and 393, the relay R390 opens certain of the previously traced paths for impressing positive and negative battery potentials upon the conductors of the trunk 31.

As indicated previously, the one of the three lines terminating at the switching center 10, selected through operation of the trunk circuit illustrated in Figs. 3 and 4 of the drawings, is determined by the number of impulses transmitted to the pulsing relay R450. More specifically, if a second digit comprising a single impulse is dialed at the control operator's position 60, the two relays R360 and R362 are locked energized at the end of the digit. Accordingly, when the relay R420 restores shortly after the end of the digit, the auxiliary operating circuit for the relay R310 is completed. With the relays R310 and R362 operated, the previously traced path is completed for impressing negative battery potential upon the upper trunk conductor 31a, thereby to energize the relay R130 provided at the switching center 10. This line switching relay, in operating, connects the line 11 to the trunk 31.

If a second digit comprising two impulses is dialed at the control operator's position 60, the relays R370 and R372 are locked energized at the end of the digit. Accordingly, the relay R420, upon restoring shortly after the digit is ended, completes the previously traced auxiliary circuit for energizing the relay R330. With the two relays R330 and R372 operated, the previously traced path is completed for impressing negative battery potential upon the lower trunk conductor 31b, thereby to energize the switching relay R140 provided at the switching center 10. This relay, in operating, connects the line 12 to the trunk 31.

Finally, if a second digit comprising three impulses is dialed at the control operator's position 60, the relays R380 and R382 are locked energized at the end of the digit. Accordingly, the auxiliary operating circuit for the relay R350 is completed in response to the release of the relay R420. With the relays R350 and R382 operated, the previously traced path is completed for impressing the positive potential of the auxiliary current source provided in the tandem exchange upon the upper trunk conductor 31a, thereby to energize the line switching relay R120 provided at the switching center. This relay, in operating, connects the subscriber's line 13 to the trunk 31.

After the desired line terminating at the switching center 10 is selected in the manner explained above, the operator may signal the called substation associated with this line by restoring the dial key 1285 to normal and operating the ringing key 1291 in accordance with the code designating the desired substation. When the dial key 1285 is restored to normal, the relays R950 and R1000 are caused momentarily to operate in the manner explained above. In operating, the relay R1000, at its contacts 1001, opens the branch circuit for energizing the upper winding of the relay R460, causing the latter relay to operate. At its contacts 1003, the relay R1000 completes the prepared operating circuit for the relay R1020. The relay R1020, in operating, operates and locks to ground through the winding of its associated relay R1010 and thus short-circuits the latter relay. The relay R460, upon operating, completes the previously traced operating circuit for the relay

R470. In operating, the relay R470 locks to the grounded lead C417 through the winding of the relay R480 and thus short-circuits the winding of the relay R480. Thereafter, and when the relays R950 and R1000 sequentially restore, the path short-circuiting the winding of the relay R1010 is opened at the contacts 1003, and the branch circuit for energizing the upper winding of the relay R460 is recompleted at the contacts 1081. The relay R460 now restores to open the path short-circuiting the winding of the relay R480, permitting this relay to be energized in series with the relay R470. In operating, the relay R480 completes the previously traced alternative locking circuits for the relays R390, R470 and R480. It is noted that the relays R390, R470 and R480 have no utility in setting up a connection of the type under consideration.

The relay R1010, when energized in series with the relay R1020, operates to open the previously traced operating circuit for the relay R1070. The relay R1070 now restores to connect the trunk conductors 43a and 43b to the line terminals of the repeating coil windings 1081 and 1082. Thus, the pulsing relay R450 is again energized in series with the two windings of the relay R460 over the circuit initially completed through the connector switch wipers 1177 and 1178. After this circuit is recompleted, the relay R1070, at its contacts 1071 and 1073, opens the previously traced alternative circuit for energizing the relay R450 in series with the two windings of the relay R460. At its contacts 1011 and 1012, the relay R1010 completes paths including the condensers 1016 and 1017 for transmitting ringing current over the calling end of the connection to signal the calling subscriber that the called substation is being rung. At its contacts 1014, the relay R1010 opens a point in the operating circuit for the relay R1020. At its contacts 1013, the relay R1010 prepares the previously traced operating circuit for the relay R1040. Following the release of the relay R1070, the operator may, by actuating the ringing key 1291, transmit ringing current over the called one of the lines 11, 12 and 13, to signal the called substation, in the exact manner described above. When the call is answered at the called substation, the operator may establish a through metallic circuit between the calling line 61 and the trunk circuit illustrated in Figs. 3 and 4 of the drawings, by momentarily operating the connect key 1292 to cause the sequential operation of the relays R1210, R940 and R1000, in the manner described above. These relays obviously restore in the same order when the key 1292 is released. In response to operation of the relay R1000, the relay R460 operates to open the locking circuit for the relays R390, R470 and R480, causing the latter relays to restore. At its contacts 1002, the relay R1000 completes the previously traced operating circuit for the relay R1040, whereby this relay and the relay R1030 are energized in series when the key 1292 is released to cause the sequential restoration of the relays R1210, R950 and R1000. The relay R1030, in operating, opens the operating circuit for the relay R1040. At its contacts 1031 and 1032, the relay R1030 connects the conductors of the calling line 61 to the line terminals of the repeating coil windings 306 and 307, thereby to establish the desired through connection between the calling and called lines. The apparatus utilized in setting up the connection between the line 61 and one of the lines ter-

minating at the switching center 10 is released in the exact manner described above when the operator withdraws the answer plug of her cord circuit from the jack 1281.

Calls originating on the lines terminating at the central office may be routed by way of the connector portion of the link 40 to any one of the lines terminating at the tandem exchange, or through the trunk circuit apparatus illustrated in Figs. 3 and 4 of the drawings and the switching center 10 to any one of the three lines 11, 12 and 13. To extend a call of this character, the operator attending the position 60 inserts the plug terminating one end of her cord circuit in the jack 1281. In response to this operation, the contact springs 1282 are closed to complete the operating circuit for the relay R1230. In operating, the relay R1230 prepares the operating circuit for the relay R1220 and, at its contacts 1232, 1233 and 1237, completes the previously traced circuit for energizing the pulsing relay R940 in series with the two windings of the relay R950. Only the relay R940 operates when the two branches of this circuit are thus completed. In operating, the relay R940 completes the previously traced operating circuit for the hold relay R930. The relay R930, upon operating, opens, at its contacts 931, the above-traced path for impressing ground potential upon the guard conductor 912, thereby to mark the link 40 as busy in the distributor 48. At its contacts 931, the relay R930 also opens a point in the operating circuit for the magnet 981. At its contacts 933, the relay R930 completes the operating circuit for the relay R1160. The relay R1160, in operating, completes the previously traced operating circuits for the relays R1030 and R1050. Following the operation of these relays, the link 40 is conditioned to respond to impulses comprising the first digit of the directory number designating the desired line. From this point on, the call may be forwarded to any line terminating at the tandem exchange, or through the trunk circuit apparatus illustrated in Figs. 3 and 4 of the drawings to one of the lines terminating at the switching center 10, in the exact manner described above. Further, the connection is released under the control of the operator handling the call at the operator's position 60 in a manner clearly apparent from the preceding explanation. Referring now more particularly to the operation of the trunk circuit illustrated in Figs. 5 and 6 of the drawings, it will be noted that this trunk circuit is substantially similar to the trunk circuit illustrated in Figs. 3 and 4 of the drawings. In considering the operation of this circuit, it will be recalled from the preceding explanation that when a call is initiated on the line 14 terminating at the switching center 70, ringing current is projected over the lower trunk conductor 55b. On the other hand, when a call is initiated at a substation served by the line 15, ringing current is transmitted from this line over the upper trunk conductor 55a. When ringing current is transmitted over the trunk conductor 55b, the relay R600 is energized over a circuit including this conductor and the contacts 613 and 633. In operating, the relay R600 completes, at its contacts 601, an obvious circuit for energizing the relay R610. The relay R610, in operating, locks to ground over a path including its X contacts 612, C586, and the contacts 531. After this locking circuit is completed, the relay R610 opens, at its contacts 613 and 614, the respective operating circuit for the relays R600 and R620. At

its contacts 616, the relay R610 bridges the repeating coil windings 691 and 692 across the conductors of the trunk 55 in series with the condenser 695. At its contacts 615, the relay R610 completes a path including the resistor 685, the contacts 683, and the winding 691 for impressing negative battery potential upon the lower trunk conductor 55b to energize the line switching relay R710 provided at the switching center 70. The relay R710, upon operating, connects the conductors of the line 14 to the conductors of the trunk 55 and opens the previously traced circuit for transmitting ringing current from the line 15 over the upper trunk conductor 55a. Thus, the line 15 is effectively prevented from obtaining access to the trunk 55.

At its contacts 611, the relay R610 completes a circuit for energizing the relay R500, this circuit extending from ground by way of the contacts 512, C583, the contacts 611, C585 and the winding of R500 to battery. When energized over this circuit, the relay R500 prepares or completes a locking circuit for itself, depending upon the character of the calling line 14. If this line extends to a paystation, a strap connection 583a is provided between the conductor C583 and one of the make contacts 503 controlled by the relay R500, so that the relay R500, in operating, locks to ground over a path including the contacts 522 and 503, the strap connection 583a, C583, the contacts 611 and C585. With this circuit completed, the relay R500 is not deenergized when the call is answered. If, on the other hand, the calling line is not of the paystation type, the strap connection 583a is omitted from the circuit wiring. Accordingly, the relay R500, in operating, does not complete the above-traced locking circuit for itself. At its contacts 502, the relay R500 prepares a circuit for transmitting paystation tone signal current to the operator's position 60 when the call is answered at the operator's position. At its contacts 505, the relay R500 opens a point in one of the circuits for energizing the cut-off relay R510. At its contacts 504, the relay R500 connects the control conductor 44c of the trunk 44 to the negative terminal of the exchange battery through the winding of the cut-off relay R510, thereby to mark the trunk 44 as a calling line in the bank contacts of the finder switches having access thereto. At its contacts 506, the relay R500 completes an obvious path for impressing ground potential upon the private conductor 44d of the trunk 44, thereby to mark this trunk as busy in the bank contacts of the connector switches having access thereto. At its contacts 501, the relay R500 completes an obvious path for impressing ground potential upon the distributor start conductor C49. When this conductor is connected to ground, the finder portion of an assigned one of the finder-connector links provided in the tandem exchange operates to seize the calling trunk 44 and to extend the connection to the operator's position 60, in the exact manner described above with reference to the operation of the trunk circuit illustrated in Figs. 3 and 4 of the drawings. From this explanation it will be apparent that if the link 40 is assigned to handle the call, ground potential is impressed upon the control conductor 44c, thereby to energize the cut-off relay R510, when the finder switch operates to seize the trunk 44. This relay, in operating, locks to the grounded conductor 44c through its contacts 514; opens, at its contacts 511, the path for impressing

ground potential upon the distributor start conductor C49; and, at its contacts 512 and 513, opens the two operating circuits for the start relay R500. In the event the line 14 is of the paystation type, the relay R500 is held energized over its locking circuit, as traced above, following operation of the cut-off relay R510. On the other hand, if the calling line is not of the paystation type, no locking circuit is completed for the relay R500. Accordingly, the start relay R500 is deenergized and restores when the cut-off relay R510 operates. In releasing, this relay completes a path including the contacts 505 and 514 for connecting the two conductors 44c and 44d together, thereby to ground the private conductor 44d over an obvious alternative path. At its contacts 506, the relay R500 opens the initially completed path for impressing ground potential upon the private conductor 44d. At its contacts 501, the relay R500 opens another point in the path for impressing ground potential upon the distributor start conductor C49. At its contacts 502, the relay R500 opens the paystation signaling circuit to prevent paystation tone current from being transmitted to the operator's position 60 when the call is answered. Following operation of the cut-off relay R510 and the release of the relay R500, no further operation of the trunk circuit apparatus illustrated in Figs. 5 and 6 of the drawings occurs until the call is answered at the operator's position 60.

Calls initiated at the substations served by the line 15 are forwarded through the trunk circuit apparatus illustrated in Figs. 5 and 6 of the drawings to the control operator's position 60 in the distant central office, in a manner similar to that just described with reference to the call originating on the line 14. Thus, when ringing current is transmitted over the upper trunk conductor 55a, the relay R620 is energized over a circuit including this conductor and the contacts 614 and 634. In operating, the relay R620 completes, at its contacts 621, an obvious circuit for energizing the relay R630. The relay R630, in operating, locks to ground over a path including its X contacts 632, C586, and the contacts 531. After this locking circuit is completed, the relay R630 opens, at its contacts 633 and 634, the respective operating circuits for the relays R600 and R620. At its contacts 636, the relay R630 bridges the repeating coil windings 691 and 692 across the conductors of the trunk 55 in series with the condenser 695. At its contacts 635, the relay R630 completes a path including the resistor 686, the contacts 684, and the winding 692 for impressing negative battery potential upon the upper trunk conductor 55a, thereby to energize the line switching relay R700 provided at the switching center 70. This relay, in operating, connects the calling line 15 to the trunk 55, and opens the circuit for transmitting ringing current from the line 14 over the lower trunk conductor 55b, thereby to prevent the line 14 from obtaining access to the trunk 55. At its contacts 631, the relay R630 completes an alternative operating circuit for the start relay R500, this circuit extending from ground by way of the contacts 513, C584, 631, C585, and the winding of R500 to battery. When thus energized, the relay R500 operates and, depending upon the character of the calling line 15, prepares or completes a locking circuit for itself at its contacts 503. In this regard it will be understood that if the line 15 is of the paystation type, a strap connection is provided

between the conductor C584 and one of the two make contacts 503 controlled by the relay R500. The relay R500, in operating, also performs the other functions described above, whereby the call is extended through one of the finder-connector links of the tandem exchange to the control operator's position 60 in the distant central office. It will be understood that when the finder switch of the assigned link operates to seize the trunk 44, the cut-off relay R510 is energized and operates to deenergize the start relay R500 in the event the calling line is not of the paystation type.

When the call is answered by the operator attending the operator's position 60, negative battery potential is impressed upon the trunk conductors 44a and 44b through the line wipers of the finder switch occupied with the call, in the manner described above with reference to the operation of the trunk circuit illustrated in Figs. 3 and 4 of the drawings. When these trunk conductors are thus connected to the negative terminal of the exchange battery, the pulsing relay R550 is energized in series with the two windings of the differentially wound relay R560. One branch of the circuit for energizing the relay R550 may partially be traced as extending from ground through the winding of this relay by way of the upper winding of R560, C594 and the winding 694 to the trunk conductor 44a. The other branch of this circuit extends by way of the winding of R550, the lower winding of R560, C593 and the winding 693 to the trunk conductor 44b. When its two windings are thus energized, the differentially wound relay R560 does not operate. The relay R550, however, operates to complete, at its contacts 552, an obvious circuit for energizing the slow-to-release hold relay R540. At its contacts 553, the relay R550 opens a point in the circuit for transmitting current pulses to the four line select relays R640, R650, R660 and R670. At its contacts 551, the relay R550 opens a point in the circuit for transmitting current pulses to the slow-to-release control relay R520. The relay R540, in operating, completes, at its contacts 542, an obvious circuit for energizing the relay R530. At its contacts 541, the relay R540 completes an obvious multiple path for impressing ground potential upon the conductor C586, thereby to maintain the energization of the operated one of the two relays R610 and R630. At its contacts 542, the relay R540 further prepares certain of the operating and locking circuits for the relays R680, R570 and R580. Following the operations just described, no further operation of the trunk circuit apparatus illustrated in Figs. 5 and 6 of the drawings, occurs until the connection is released, assuming that the call is routed from the operator's position 60 to a line terminating at the central office, the tandem exchange, or to the switching center 10. The manner in which the call may be forwarded to any line terminating at any one of these three points under the control of the operator handling the call at the operator's position 60, will be clearly apparent from the preceding explanation. The release of the trunk circuit and of the operated relay at the switching center 10 is under the control of the operator handling the call at the operator's position 60. Thus, when the finder-connector link in use is released, negative battery potential is removed from the trunk conductors 44a and 44b, in the manner previously described with reference to

operation of the finder-connector link 40. The two relays R550 and R560 are thus deenergized. The relay R550, in restoring, momentarily completes the operating circuits for the relays R640, R680 and R520, but the resulting momentary operation of these three relays is without effect. At its contacts 552, the relay R550 opens the operating circuit for the hold relay R540. The relay R540 restores after an interval to open, at its contacts 542, the operating circuit for the relay R530, the operating circuit for the relay R520, and the holding circuit for the relay R680. At its contacts 541, the relay R540 disconnects the lead C586 from ground, thereby to deenergize the operated one of the two relays R610 and R630. The relay R520, upon restoring, opens the operating circuits for the two relays R640 and R680. Thus, the relays R640, R680, R520, R530, R540 and the operated one of the two relays R610 and R630 are all deenergized and restore. During the release of the link utilized in forwarding the call to the operator's position 60, the control conductor 44c is disconnected from ground so that the cut-off relay R510 is deenergized and restores. When ground potential is removed from this conductor, it is also removed from the private conductor 44d, so that negative battery potential is impressed upon the private conductor over a path including the winding of R510 and the contacts 505. Thus, the trunk 44 is marked as idle in the bank contacts of the connector switches having access thereto. When the operated one of the two relays R610 and R630 is deenergized and restores, the completed path for impressing negative battery potential upon one of the two conductors 55a and 55b is opened, thereby to deenergize the operated one of the two line switching relays R700 and R710 provided at the distant switching center 10. Thus, the trunk circuit illustrated in Figs. 5 and 6 of the drawings and the equipment provided at the switching center 10, are fully released.

In the event the call initiated on one of the lines 14 and 15 is intended for the other of these lines, the operator handling the call will seize the trunk 44 through the connector end of the link in use, in the manner described above with reference to the operation of the trunk circuit shown in Figs. 3 and 4. After the trunk 44 is seized through the connector end of the link, the pulsing relay R550 is energized over an alternative circuit which includes the pulsing contacts, such, for example, as the contacts 941, of the pulsing relay embodied in the link circuit occupied with the call. Thus, the relay R550 is conditioned to respond to the impulses of the digit designating the desired one of the two lines 14 and 15. In this regard it is pointed out that, if a single impulse is transmitted to the trunk circuit to cause the release and reoperation of the pulsing relay R550, the line 14 is selected. On the other hand, if a second digit of two impulses is dialed at the operator's position 60, the line 15 is selected. More specifically, when the pulsing relay R550 restores at the beginning of the open circuit period of the first impulses, it completes, at its contacts 551, the above-mentioned circuit for energizing the relay R520, this circuit extending from ground by way of the contacts 542 and 551, C587, the contacts 651 and 671, C588 and the winding of R520 to battery. At its contacts 552, the relay R550 opens the operating circuit for the slow-to-release hold relay R540. At its contacts 553, the relay R550 prepares a circuit for ener-

gizing the relay R640 in parallel with the upper winding of the relay R680. When energized over its operating circuit, as traced above, the relay R520 immediately operates to complete, at its contacts 521, an obvious path in shunt with the contacts 651 and 671, whereby further current pulses are transmitted through its winding in response to further operation of the pulsing relay R550. At its contacts 522, the relay R520 opens a point in the common portion of the auxiliary operating circuits for the two relays R610 and R630. At its contacts 523, the relay R520 completes the prepared circuit for energizing the relay R640 in parallel with the upper winding of the relay R680. This circuit extends from ground by way of the contacts 553 and 523 to C590 where it divides, one branch extending through the contacts 681 and the upper winding of R680 to battery, and the other branch extending through the contacts 653 and the winding of R640 to battery. When energized over this circuit, the relay R680 operates and locks to ground over a path including its X contacts 682, C592, and the contacts 582 and 542. After this locking circuit is completed, the relay R680 opens its contacts 681 to deenergize its upper winding. At its contacts 683 and 684, the relay R680 opens points in the two previously traced paths for impressing negative battery potential upon the respective trunk conductors 55b and 55a. In response to this operation, the operated one of the two relays R700 and R710 is deenergized and restores to disconnect the calling line from the trunk 55. The relay R640 also operates when energized over the above-traced circuit and, in operating, locks to ground over a path including the contacts 641, the winding of R650, the contacts 674, C586 and the contacts 541. In this regard it is pointed out that the relays R520 and R540, due to their slow-to-release characteristics, remain operated during impulsion. In completing the above-traced locking path, the relay R640 short-circuits the winding of the relay R650 over an obvious path. Thereafter, and when the relay R550 re-operates at the end of the open circuit period of the first impulse, the path short-circuiting the winding of R650 is opened at the pulsing contacts 553. The relay R650 is thus energized in series with the relay R640 over a circuit extending from ground by way of the contacts 541, C586, the contacts 674, the winding of R650, the contacts 641, and the winding of R640 to battery. In operating, the relay R650 opens, at its contacts 651, a point in the above-traced operating circuit for the relay R520. At its contacts 652, the relay R650 prepares the auxiliary operating circuit for the relay R610. At its contacts 653 and 654, the relay R650 opens a point in the above-traced operating circuit for the relay R640 and prepares the operating circuit for the relay R660. At its contacts 655, the relay R650 prepares or completes an alternative path for impressing negative battery potential upon the lower trunk conductor 55b, depending upon the position of the relay R610. Thus, if the line 14 is the calling line, such that the relay R610 is operated, this auxiliary path, which includes the resistor 685 and the contacts 655 and 615, is completed to cause the reoperation of the relay R710. On the other hand, if the line 15 is the calling line, such that the relay R610 occupies its restored position, this auxiliary path is held open at the contacts 615.

At the beginning of the open circuit period of

the second impulse transmitted to the relay R550, this relay restores to recomplete the circuit for energizing the relay R520, and to complete the prepared operating circuit for the relay R660. 5 The last-mentioned circuit extends from ground by way of the contacts 553 and 523, C590, the contacts 654 and 673, and the winding of R660 to battery. When thus energized, the relay R660 operates and locks to ground over a path including the contacts 661, the winding of R670, C586 and the contacts 541. In completing this locking circuit, the relay R660 short-circuits the winding of the relay R670. When the pulsing relay R550 subsequently reoperates at the end of the open circuit period of the second impulse, the path short-circuiting the winding of the relay R670 is opened at the contacts 553. The relay R670 is thus energized in series with the relay R660 over a circuit extending from ground by way of the contacts 541, C586, the winding of R670, the contacts 661, and the winding of R660 to battery. When energized over this circuit, the relay R670 operates and opens, at its contacts 673, a point in the common portion of the operating circuit for the relay R660 and the path for short-circuiting its own winding. At its contacts 674, the relay R670 opens the previously traced series locking circuit for the two relays R640 and R650, causing both of these relays to restore. The relay R650, upon restoring, opens the above-traced auxiliary path for impressing negative battery potential upon the trunk conductor 55b, thereby to deenergize the line switching relay R710, if operated. At its contacts 672, the relay R670 prepares the alternative operating circuit for the relay R630. At its contacts 671, the relay R670 opens another point in the previously traced operating circuit for the relay R520. At its contacts 675, the relay R670 prepares an alternative path for impressing negative battery potential upon the upper trunk conductor 55a.

From the above explanation it will be apparent that if one impulse is transmitted to the pulsing relay R550 in response to operation of the calling device 1284 provided at the control operator's position 60, the two relays R640 and R650 are locked energized at the end of the digit. On the other hand, if the calling device 1284 is actuated 45 to transmit two impulses to the pulsing relay R550, the relays R660 and R670 are locked energized at the end of the digit. In any case, the relay R550 is held energized and remains in its operated position after the dialing operation is completed at the control operator's position. With this relay operated, the slow-to-release relay R520 is deenergized and, accordingly, restores shortly following the dialing operation. In releasing, the relay R520 opens, at its contacts 521, a further point in its multiple operating circuit. At its contacts 523, the relay R520 opens a further point in the previously traced operating circuits for the relays R680, R640 and R660. At its contacts 522, the relay R520 completes the prepared auxiliary operating circuit for one of the two relays R610 and R630. Thus, if the relay R650 is operated at the end of the dialing operation, the relay R520, upon restoring, completes the auxiliary operating circuit for the relay 50 R610, this circuit extending from ground by way of the contacts 522, C589, the contacts 652 and the winding of R610 to battery. In operating, the relay R610 locks to ground over the previously traced path, and opens, at its contacts 613 and 614, two additional points in the operating cir-

cuits for the relays R600 and R620. At its contacts 616, the relay R610 completes an obvious shunt across the operated contacts 636 of the relay R630. At its contacts 615, the relay R610 completes the above-traced alternative path for impressing negative battery potential upon the lower trunk conductor 55b. When this path is completed, the line switching relay R710 operates to connect the called line 14 to the trunk 55. In the event the two relays R660 and R670 are operated at the end of the dialing operation, the relay R520, upon restoring, completes the prepared auxiliary operating circuit for the relay R630, this circuit extending from ground by way of the contacts 522, C589, the contacts 672, and the winding of R630 to battery. The relay R630, in operating, locks to ground over the previously traced path, and, at its contacts 633 and 634, opens two additional points in the operating circuits for the two relays R600 and R620. At its contacts 636, the relay R630 completes an obvious shunt across the contacts 616 of the operated relay R610. At its contacts 635, the relay R630 completes a path including the resistor 686, the contacts 675, and the winding 692 for impressing negative battery potential upon the upper trunk conductor 55a, thereby to energize the line switching relay R700 provided at the distant switching center 70. This line switching relay, in operating, connects the called line 15 to the trunk 55. From the above explanation it will be apparent that following the dialing operation performed at the control operator's position 60, both of the relays R610 and R630 are operated. However, only the one of these relays which corresponds to the called line is effective to complete the circuit for energizing the corresponding switching relay provided at the distant switching center 70, the circuit for energizing the other switching relay being held open at the operated contacts of the reverting call relay R680.

After the operations just described are completed, the operator may, by restoring the dial key 1285 to normal and actuating the ringing key 1291, transmit ringing current over the established connection to the called line for the purpose of energizing the ringer provided at the called substation. If the called line is of the multiparty type, the operator will, of course, actuate the ringing key 1291 in accordance with the code assigned to the desired substation, so that a signal is produced by the ringers connected to this line indicating that only one of the several substations served by the line is being called. When the dial key 1285 is restored to normal, one of the above-traced branch circuits for energizing the pulsing relay R550 in series with one of the windings of the relay R560 is momentarily interrupted through operation of the relays embodied in the link circuit in use, in the manner previously described. In response to this operation, the relay R560 operates to complete, at its contacts 582, the prepared operating circuit for the relay R570, this circuit extending from ground by way of the contacts 542 and 582, C592, the contacts 682, C591, the contacts 582 and the winding of R570 to battery. In operating, the relay R570 locks to ground over a path including the contacts 571 and the winding of R580 and thus completes an obvious path for short-circuiting the winding of the latter relay. Thereafter, and when the operating circuit for the two relays R550 and R560 is again balanced, the differentially wound relay R560 restores. At its contacts 592, the relay R560 opens the path short-circuit-

ing the winding of the slow-to-operate relay R580. The relay R580 is thus energized in series with the relay R570 over a circuit which extends from ground by way of the contacts 542 and 582, C592, the contacts 682, C591, the winding of R580, the contacts 571, and the winding of R570 to battery. When energized over this circuit the relay R580 operates after an interval to complete, at its contacts 581, an obvious alternative locking circuit for itself and the relay R570. At its contacts 581, the relay R580 also completes an alternative locking circuit, including the contacts 561, for the reverting call relay R680. After these alternative circuits are completed, the relay R580 opens its contacts 582 to interrupt the initially completed operating and locking circuits for the relays R680, R570 and R580.

After the ringing operation is completed and the call is answered at the called substation, the operator may momentarily operate the connect key 1292 to again connect the calling line to the trunk 55. In response to this operation, the series operating circuit for the relays R550 and R560 is momentarily unbalanced. The relay R560 is thus caused momentarily to operate. In operating, the relay R560 opens, at its contacts 561, the above-described alternative locking circuits for the relays R680, R570 and R580, causing all three of these relays to restore. The release of the relays R570 and R580 is without effect. The relay R680, upon restoring, opens, at its contacts 682, a further point in its two locking circuits, reprepares its operating circuit at the contacts 681, and at one of its two sets of contacts 683 and 684, completes the path, corresponding to the calling line, for impressing negative battery potential upon one of the two trunk conductors 55a and 55b. Thus, if the line 14 is the calling line, the relay R680, in releasing, impresses negative battery potential upon the lower trunk conductor 55a to cause the operation of the relay R710. On the other hand, if the line 15 is the calling line, the relay R680 closes its contacts 684 to impress negative battery potential upon the upper trunk conductor 55a, thus energizing the relay R700. This relay, in operating, connects the line 15 to the trunk 55. From the above explanation it will be apparent that following the release of the reverting call relay R680, both of the line switching relays R700 and R710 are operated and, accordingly, both of the lines 14 and 15 are connected to the trunk 55. Thus, a three-way communication circuit is established between the calling and called substations and the telephone set of the operator's cord circuit in use at the operator's position 60. The manner in which the connection is released under the control of the operator attending this position, is substantially the same as described above. In this regard it will be apparent that when the hold relay R540 restores in response to the release of the pulsing relay R550, the holding lead C586 is disconnected from ground to deenergize the two operated relays R610 and R630 and the two operated ones of the relays R640, R650, R660 and R670. The manner in which the remaining relays of the trunk circuit illustrated in Figs. 5 and 6, and the operated relays of the switching center 70, are released, is clearly apparent from the above explanation.

If a call intended for one of the two lines 14 and 15 is routed to the operator's position 60 from another line of the system, the operator may extend the call through the connector portion of one of the links provided in the tandem exchange to the trunk circuit illustrated in Figs.

5 and 6, in the manner previously explained. When the trunk 44 is seized by the connector switch of the link in use, negative battery potential is impressed upon the two trunk conductors 44a and 44b to energize the relay R550 in series with the two windings of the relay R560. Thus, the relays R550, R540 and R530 are caused sequentially to operate in the order named. When the trunk 44 is seized, ground potential is impressed upon the private conductors 44d through the private wiper of the connector switch to energize the cut-off relay R510 over an obvious circuit. The relay R510, in operating, completes, at its contacts 514, a path for connecting the grounded private conductor 44d to the control conductor 44c. At its contacts 512 and 513, the relay R510 opens points in the respective operating circuits for the start relay R500. At its contacts 511, the relay R510 opens a point in the above-traced path for impressing ground potential upon the distributor start conductor C49. Following the operation of the four relays R550, R540, R530 and R510, the trunk circuit apparatus is conditioned to respond to the impulse or impulses designating the desired one of the two lines 14 and 15. The manner in which this equipment responds to the impulses is exactly the same as described above, it being pointed out that the reverting call relay R680 is energized at the beginning of the first impulse. Depending upon which line is desired and, hence, the number of impulses transmitted to the trunk circuit, the relay pair R640, R650 or the relay pair R660, R670 will be locked energized at the end of the digit. Assuming that the line 14 is desired, only one impulse is transmitted to the trunk circuit and, accordingly, the relays R640 and R650 will occupy their respective operated positions at the end of the digit. Shortly after the digit is ended, the relay R520 restores to complete the previously traced alternative operating circuit for the relay R610. The relay R610, accordingly, operates and locks to the grounded lead C586 through its contacts 612. At its contacts 616, the relay R610 bridges the repeating coil windings 691 and 692 across the conductors of the trunk 55 in series with the condenser 695. With the relays R610 and R650 operated, negative battery potential is impressed upon the lower trunk conductor 55b through the contacts 615 and 655, to energize the relay R710. This relay, in operating, connects the line 14 to the trunk 55. If the line 15 is desired, such that the relays R660 and R670 are operated at the end of the dialing operation, the relay R520 completes the prepared auxiliary operating circuit for the relay R630. The relay R630, upon operating, locks to the grounded lead C586 through its contacts 632 and, at its contacts 636, bridges the repeating coil windings 691 and 692 across the conductors of the trunk in series with the condenser 695. With the two relays R630 and R670 operated, the previously traced path is completed for impressing negative battery potential upon the upper trunk conductor 55a, thereby to energize the line switching relay R700. This relay, in operating, connects the line 15 to the trunk 55.

After the operations just described are completed, and when the dial key 1285 is restored to normal, the relays R560, R570 and R580 operate in the manner pointed out above, but the operation of these relays is without effect in setting up a connection of the character under consideration. After the ringing operation is completed, the operator may momentarily actuate the connect key 1292, and thus cause the momentary op-

eration of the differentially wound relay R560. When this relay operates the second time, the three relays R680, R570 and R580 are deenergized and restore, but the release of these relays is without effect. The manner in which the connection, as routed to one of the two lines 14 and 15, is released under the control of the operator attending the position 60 will be clearly apparent from the preceding explanation.

From the foregoing explanation it will be understood that calls may be routed from the sub-stations served by the lines terminating at the distant switching center 10 through the automatic switching equipment provided in the tandem exchange to the lines terminating at the switching center 18 under the control of the operator attending the control operator's position 60 in the central office. It will also be apparent that connections involving any one of the five subscribers' lines terminating at the two switching centers 10 and 18, may be set up between these lines and any of the other lines of the system. Further, the two switching centers and the associated control equipment is so arranged that no batteries or other sources of current are required at the switching centers for the purpose of energizing the line switching relays provided thereat. Thus, the initial cost of the equipment provided at these points, and the cost of maintaining this equipment, is reduced to a minimum.

While there have been described what are at present considered to be the preferred embodiments of the invention, it will be understood that various modifications may be made therein, and it is contemplated to cover in the appended claims all such modifications as fall within the true spirit and scope of the invention.

What is claimed is:

1. In a telephone system, a plurality of subscribers' lines, a first exchange terminating said lines, a second exchange, a trunk interconnecting said exchanges, means in said second exchange for selectively impressing voltages of different polarities upon one side of said trunk and for impressing voltage upon the other side of said trunk, and line switching means in said first exchange energized by said voltages and selectively controlled in accordance with the sides of said trunk to which voltage is applied and the polarities of the voltages applied to said one side of said trunk for setting up connections between different pairs of said lines.

2. In a telephone system, a pair of subscribers' lines, a first exchange terminating said lines, a second exchange, a trunk interconnecting said exchanges, means in said second exchange for selectively impressing voltages upon the two sides of said trunk, and switching devices in said first exchange individually corresponding to said lines and individually energized by the voltages applied to different sides of said trunk for connecting the respective corresponding lines to said trunk.

3. In a telephone system, a pair of subscribers' lines, a first exchange terminating said lines, a second exchange, a trunk interconnecting said exchanges, means in said second exchange for selectively impressing voltages upon the two sides of said trunk, means in said first exchange energized by the voltage applied to one side of said trunk for connecting one of said lines to said trunk, and means in said first exchange energized by the voltage applied to the other side of said trunk for connecting the other of said lines

to said trunk, thereby to establish a connection between said lines.

4. In a telephone system, a plurality of subscribers' lines, a first exchange terminating said lines, a second exchange, a trunk interconnecting said exchanges, means in said second exchange for selectively impressing voltages of different polarities upon at least one side of said trunk, a network in said first exchange including polarized relays selectively energized by said voltages of different polarities applied to said trunk, and means controlled by said relays for selectively interconnecting said lines.

5. In a signaling system, a switching center, at least three lines extending to said switching center, a control center, a trunk interconnecting said control center and said switching center, means at said control center for selectively impressing voltage of one polarity upon the two sides of said trunk and voltage of a different polarity upon one side of said trunk, and means at said switching center selectively energized by said voltages for selectively interconnecting said lines.

6. In a signaling system, a switching center, at least three lines extending to said switching center, a control center, a trunk interconnecting said control center and said switching center, means at said control center for selectively impressing voltages of different polarities upon one side of said trunk and for impressing voltage upon the other side of said trunk, relays at said switching center individually corresponding to said lines and connected to be energized by the voltages applied to said trunk in said exchange, means polarizing said relays so that said relays are selectively operated in accordance with the polarities of said voltages and the sides of said trunk to which said voltages are applied, and means controlled by said relays for selectively interconnecting said lines.

7. In a signaling system, a switching center, at least three lines extending to said switching center, a control center, a trunk interconnecting said control center and said switching center, means at said control center for selectively impressing voltages of different polarities upon the respective sides of said trunk, a first relay at said switching center connected to be energized by voltage of one polarity impressed on one side of said trunk and operative to connect one of said lines to said trunk, a second relay at said switching center connected to be energized by voltage of said one polarity impressed on the other side of said trunk and operative to connect a second of said lines to said trunk, a third relay connected to be energized by voltage of the opposite polarity impressed on either side of said trunk and operative to connect a third of said lines to said trunk, and means controlled by one of said first and second relays for selectively connecting said third relay to be energized over the two sides of said trunk.

8. In a telephone system, a switching center, a pair of lines extending to said switching center, an exchange, a trunk interconnecting said exchange and said switching center, means for selectively transmitting ringing currents over said lines to said switching center, means individually associated with said lines at said switching center for projecting said ringing currents over different sides of said trunk to said exchange, means in said exchange for selectively impressing control voltages upon different sides of said trunk, and means at said switching center

selectively energized by said voltages and operative selectively to connect said lines to said trunk and to prevent ringing current from being transmitted over said trunk from the disconnected one of said lines.

9. In a telephone system, a switching center, a pair of lines extending to said switching center, an exchange, a trunk interconnecting said exchange and said switching center, means for selectively transmitting ringing currents over said lines to said switching center, means individually associated with said lines at said switching center for projecting said ringing currents over different sides of said trunk to said exchange, means in said exchange selectively controlled in accordance with the side of said trunk over which ringing current is projected from one of said lines for selectively impressing control voltages upon different sides of said trunk, and means at said switching center selectively energized by said voltages and operative selectively to connect said lines to said trunk.

10. In a telephone system, a switching center, a pair of lines extending to said switching center, an exchange, a trunk interconnecting said switching center and said exchange, means for selectively transmitting ringing currents over said lines, means at said switching center for rectifying said currents and for transmitting the rectified currents over said trunk to said exchange with different polarities, control means in said exchange selectively controlled by said rectified ringing currents of different polarities, means in said exchange for selectively impressing control voltages upon different sides of said trunk, and means at said switching center selectively energized by said voltages and operative selectively to connect said lines to said trunk.

11. In a telephone system, a switching center, a pair of lines extending to said switching center, an exchange, a trunk interconnecting said exchange and said switching center, means for selectively transmitting ringing currents over said lines to said switching center, means individually associated with said lines at said switching center for projecting said ringing currents over different sides of said trunk to said exchange, an operator's position, signal devices at said operator's position individually corresponding to said lines, means in said exchange selectively energized by the ringing currents transmitted over different sides of said trunk for energizing each of said signal devices when ringing current is transmitted to said trunk over the corresponding line, means in said exchange and controllable from said operator's position for selectively impressing control voltages upon different sides of said trunk, and means at said switching center selectively energized by said voltages and operative selectively to connect said lines to said trunk and to prevent ringing current from being transmitted over said trunk from the disconnected line.

12. In a telephone system, a switching center, a pair of lines extending to said switching center, an exchange, a trunk interconnecting said switching center and said exchange, means for selectively transmitting ringing currents over said lines, means at said switching center for rectifying said currents and for transmitting the rectified currents over said trunk to said exchange with different polarities, an operator's position, signal devices at said operator's position individually corresponding to said lines, means in said exchange selectively energized by said rectified ringing currents of different polarities for ener-

gizing said signal devices when ringing current is transmitted over the corresponding lines to said switching center, means in said exchange and controllable from said operator's position for selectively impressing control voltages upon different sides of said trunk, and means at said switching center selectively energized by said control voltages and operative selectively to connect said lines to said trunk.

13. In a telephone system, a switching center, a pair of lines extending to said switching center, an exchange, a trunk interconnecting said switching center and said exchange, means for selectively transmitting ringing currents over said lines, means at said switching center for rectifying said currents and for transmitting the rectified currents over said trunk to said exchange with different polarities, means in said exchange selectively controlled in accordance with the polarities of said rectified ringing currents for selectively impressing control voltages upon different sides of said trunk, and means at said switching center selectively energized by said voltages and operative selectively to connect said lines to said trunk.

14. In a telephone system, a switching center, a plurality of lines terminating at said switching center, an exchange including an operator's position, a trunk interconnecting said operator's position and said switching center, signal devices at said operator's position individually corresponding to said lines, means responsive to the initiation of a call on one of said lines for energizing the corresponding signal device, means in said exchange selectively controllable from said operator's position for impressing control voltages on different sides of said trunk, and means at said switching center energized by a control voltage impressed on one side of said trunk for connecting said one line to said trunk.

15. In a telephone system, a switching center, a plurality of lines terminating at said switching center, an exchange including an operator's position, a trunk interconnecting said operator's position and said switching center, signal devices at said operator's position individually corresponding to said lines, means responsive to the initiation of a call on one of said lines for energizing the corresponding signal device, means in said exchange selectively controllable from said operator's position for impressing control voltages on different sides of said trunk, and means at said switching center selectively energized by said voltages for connecting said one line to a called one of said lines.

16. In a telephone system, a switching center, a plurality of lines terminating at said switching center, an exchange, a trunk interconnecting said switching center and said exchange, an operator's position, signal devices at said operator's position individually corresponding to said lines, means responsive to the initiation of a call on one of said lines for energizing the signal device corresponding to the calling line, means in said exchange selectively controllable from said operator's position for selectively impressing control voltages of different polarities on either side of said trunk, and means at said switching center energized by one of said voltages for connecting the calling line to said trunk.

17. In a telephone system, a switching center, a plurality of lines terminating at said switching center, an exchange, a trunk interconnecting said switching center and said exchange, an operator's

position, signal devices at said operator's position individually corresponding to said lines, means responsive to the initiation of a call on one of said lines for energizing the signal device corresponding to the calling line, means in said exchange selectively controllable from said operator's position for selectively impressing control voltages of different polarities on either side of said trunk, and means at said switching center selectively energized by said voltages for connecting the calling line to a called one of said lines.

18. In a telephone system, a switching center, a plurality of lines terminating at said switching center, an exchange, a trunk interconnecting said switching center and said exchange, an operator's position, signal devices at said operator's position individually corresponding to said lines, line jacks at said operator's position individually corresponding to said lines, means responsive to the initiation of a call on one of said lines for energizing the signal device corresponding to the calling line, means comprising relays selectively controllable over circuits including predetermined contacts of said jacks for selectively impressing control voltages on different sides of said trunk, and means at said switching center energized by one of said voltages for connecting the calling line to said trunk.

19. In a telephone system, a switching center, a plurality of lines terminating at said switching center, an exchange, a trunk interconnecting said switching center and said exchange, an operator's position, signal devices at said operator's position individually corresponding to said lines, line jacks at said operator's position individually corresponding to said lines, means responsive to the initiation of a call on one of said lines for energizing the signal device corresponding to the calling line, means comprising relays selectively controllable over circuits including predetermined contacts of said jacks for selectively impressing control voltages on different sides of said trunk, and means at said switching center selectively energized by one of said control voltages for connecting the calling line to a called one of said lines.

20. In a telephone system, a switching center, a plurality of lines terminating at said switching center, an exchange, a trunk interconnecting said switching center and said exchange, an operator's position, signal devices at said operator's position individually corresponding to said lines, line jacks at said operator's position individually corresponding to said lines, means responsive to the initiation of a call on one of said lines for energizing the signal device corresponding to the calling line, means comprising relays selectively controllable over circuits including predetermined contacts of said jacks for selectively impressing control voltages of different polarities on either side of said trunk, and means at said switching center energized by one of said control voltages for connecting the calling line to said trunk.

21. In a telephone system, a switching center, a plurality of lines terminating at said switching center, an exchange, a trunk interconnecting said switching center and said exchange, an operator's position, signal devices at said operator's position individually corresponding to said lines, line jacks at said operator's position individually corresponding to said lines, means responsive to the initiation of a call on one of said lines for energizing the signal device corresponding to the calling line, means comprising relays selectively controllable over circuits including predetermined contacts of said jacks for selectively impressing

control voltages of different polarities on either side of said trunk, and means at said switching center selectively energized by said voltages for connecting the calling line to a called one of said lines.

22. In a telephone system, a switching center, a plurality of lines terminating at said switching center, an exchange, a trunk interconnecting said exchange and said switching center, an operator's position, a signal device at said operator's position, means responsive to the initiation of a call on one of said lines for energizing said signal device, means in said exchange and selectively controllable from said operator's position for selectively impressing control voltages on the different sides of said trunk, and means at said switching center energized by one of said voltages for connecting the calling line to said trunk.

23. In a telephone system, a switching center, a plurality of lines terminating at said switching center, an exchange, a trunk interconnecting said exchange and said switching center, an operator's position, a signal device at said operator's position, means responsive to the initiation of a call on one of said lines for energizing said signal device, means in said exchange and selectively controllable from said operator's position for selectively impressing control voltages on the different sides of said trunk, and means at said switching center selectively energized by one of said voltages for connecting the calling line to a called one of said lines.

24. In a telephone system, a switching center, a plurality of lines terminating at said switching center, an exchange, a trunk interconnecting said exchange and said switching center, an operator's position, a signal device at said operator's position, means responsive to the initiation of a call on one of said lines for energizing said signal device, means in said exchange and selectively controllable from said operator's position for selectively impressing control voltages of different polarities on either side of said trunk, and means at said switching center energized by one of said voltages of a predetermined polarity applied to one side of said trunk for connecting the calling line to said trunk.

25. In a telephone system, a switching center, a plurality of lines terminating at said switching center, an exchange, a trunk interconnecting said exchange and said switching center, an operator's position, a signal device at said operator's position, means responsive to the initiation of a call on one of said lines for energizing said signal device, means in said exchange and selectively controllable from said operator's position for selectively impressing control voltages of different polarities on either side of said trunk, and means at said switching center selectively energized by two of said voltages of predetermined polarities applied to different sides of said trunk for connecting the calling line to a called one of said lines.

26. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltage of opposite polarity upon said trunk in response to the initiation of a call on the other of said lines, and control means in said exchange selectively controlled in accordance

with said voltages of different polarities impressed upon said trunk.

27. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltages of opposite polarity upon said trunk in response to the initiation of a call on the other of said lines, signal devices in said exchange individually corresponding to said lines, means operative in response to the application of voltage of said one polarity to said trunk for energizing the signal device corresponding to said one line, and means operative in response to the application of voltage of said opposite polarity to said trunk for energizing the signal device corresponding to the other of said lines.

28. In a telephone system, a switching center, a pair of lines extending to said switching center, an exchange including an operator's position, a trunk interconnecting said switching center and said operator's position, means at said switching center for impressing voltage of one polarity upon said trunk in response to the initiation of a call on one of said lines and for impressing voltage of opposite polarity upon said trunk in response to the initiation of a call on the other of said lines, signal devices at said operator's position individually corresponding to said lines, means responsive to the application of voltage of said one polarity to said trunk for energizing the signal device corresponding to said one line, means responsive to the application of voltage of said opposite polarity to said trunk for energizing the signal device corresponding to the other of said lines, and means responsive to the answering of a call routed from either of said lines to said operator's position for preventing said first-named means from operating in response to the initiation of a call on the other of said lines.

29. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltage of opposite polarity upon said trunk in response to the initiation of a call on the other of said lines, means including apparatus in said exchange operative in response to the application of voltage of said one polarity to said trunk for preventing said first-named means from operating in response to the initiation of a call on said other line, and means including apparatus in said exchange operative in response to the application of voltage of said opposite polarity to said trunk for preventing said first-named means from operating in response to a call initiated on said one line.

30. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltage of opposite polarity upon said trunk in response to the initiation of a call on the other of said lines, an operator's position, means including a finder switch having access to said trunk in said exchange for extending a connec-

tion from said trunk to said operator's position, and means controlled by the application of either of said voltages to said trunk for causing said finder switch to seize said trunk.

31. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltage of opposite polarity upon said trunk in response to the initiation of a call on the other of said lines, an operator's position, means including a finder switch having access to said trunk in said exchange for extending a connection from said trunk to said operator's position, means controlled by the application of either of said voltages to said trunk for causing said finder switch to seize said trunk, and means selectively controlled in accordance with the polarity of the voltage impressed upon said trunk when a call is initiated on one of said lines for preventing said first-named means from operating in response to the initiation of a call on the other of said lines.

32. In a telephone system, a switching center, a pair of lines extending to said switching center, an exchange, a trunk interconnecting said exchange and said switching center, means at said switching center for impressing voltage of one polarity upon said trunk in response to the initiation of a call on one of said lines and for impressing voltage of opposite polarity upon said trunk in response to the initiation of a call on the other of said lines, an operator's position, means including a finder switch having access to said line in said exchange for extending a connection from said trunk to said operator's position, means including apparatus in said exchange operative in response to the application of voltage of one polarity to said trunk for causing said finder switch to seize said trunk and for preventing said first-named means from operating in response to the initiation of a call on said other line, and means including apparatus in said exchange operative in response to the application of voltage of said opposite polarity to said trunk for causing said finder switch to seize said trunk and for preventing said first-named means from operating in response to a call initiated on said one line.

33. In a telephone system, a switching center, a pair of lines extending to said switching center, an exchange, a trunk interconnecting said exchange and said switching center, means at said switching center for impressing voltage on one side of said trunk in response to the initiation of a call on one of said lines and for impressing voltage on the other side of said trunk in response to the initiation of a call on the other of said lines, and control means in said exchange selectively controlled in accordance with the side of said trunk to which voltage is applied by said first-named means.

34. In a telephone system, a switching center, a pair of lines extending to said switching center, an exchange, a trunk interconnecting said exchange and said switching center, means at said switching center for impressing voltage on one side of said trunk in response to the initiation of a call on one of said lines and for impressing voltage on the other side of said trunk in response to the initiation of a call on the other of said lines, signal devices in said exchange individually

corresponding to said lines, means operative in response to the application of voltage to said one side of said trunk for energizing the signal device corresponding to said one line, and means operative in response to the application of voltage to the other side of said trunk for energizing the signal device corresponding to said other line.

35. In a telephone system, a switching center, a pair of lines extending to said switching center, an exchange including an operator's position, a trunk interconnecting said switching center and said operator's position, means at said switching center for impressing voltage on one side of said trunk in response to the initiation of a call on one of said lines and for impressing voltage on the other side of said trunk in response to the initiation of a call on the other of said lines, signal devices at said operator's position individually corresponding to said lines, means responsive to the application of voltage to said one side of said trunk for energizing the signal device corresponding to said one line, means responsive to the application of voltage to the other side of said trunk for energizing the signal device corresponding to the other of said lines, and means responsive to the answering of a call routed from either of said lines to said operator's position for preventing said first-named means from responding to a call initiated on the other of said lines.

36. In a telephone system, a switching center, a pair of lines extending to said switching center, an exchange, a trunk interconnecting said exchange and said switching center, means at said switching center for impressing voltage on one side of said trunk in response to the initiation of a call on one of said lines and for impressing voltage on the other side of said trunk in response to the initiation of a call on the other of said lines, an operator's position, means including a finder switch having access to said trunk for extending a connection from said trunk to said operator's position, and means controlled by the application of voltage to either side of said trunk for causing said finder switch to seize said trunk.

37. In a telephone system, a switching center, a pair of lines extending to said switching center, an exchange, a trunk interconnecting said exchange and said switching center, means at said switching center for impressing voltage on one side of said trunk in response to the initiation of a call on one of said lines and for impressing voltage on the other side of said trunk in response to the initiation of a call on the other of said lines, an operator's position, means including a finder switch having access to said trunk for extending a connection from said trunk to said operator's position, means controlled by the application of voltage to either side of said trunk for causing said finder switch to seize said trunk, and means selectively controlled in accordance with the side of said trunk to which voltage is applied when a call is initiated on one of said lines for preventing said first-named means from operating in response to the initiation of a call on the other of said lines.

38. In a telephone system, a switching center, at least three lines extending to said switching center, an exchange, a trunk interconnecting said exchange and said switching center, means at said switching center for impressing voltage of one polarity on one side of said trunk in response to the initiation of a call on one of said lines and for impressing voltage of opposite polarity on said one side of said trunk in response to the initiation of a call on a second of said lines,

means at said switching center for impressing voltage on the other side of said trunk in response to the initiation of a call on a third of said lines, and control means in said exchange selectively controlled by the application of said voltages to said trunk.

39. In a telephone system, a switching center, at least three lines extending to said switching center, an exchange, a trunk interconnecting said exchange and said switching center, means at said switching center for impressing voltage of one polarity on one side of said trunk in response to the initiation of a call on one of said lines and for impressing voltage of opposite polarity on said one side of said trunk in response to the initiation of a call on a second of said lines, means at said switching center for impressing voltage on the other side of said trunk in response to the initiation of a call on a third of said lines, signal devices in said exchange individually corresponding to said lines, and means selectively controlled by said voltages for energizing said signal devices only when calls are initiated on the respective corresponding lines.

40. In a telephone system, a switching center, at least three lines extending to said switching center, an exchange, a trunk interconnecting said exchange and said switching center, means at said switching center for impressing voltage of one polarity on one side of said trunk in response to the initiation of a call on one of said lines and for impressing voltage of opposite polarity on said one side of said trunk in response to the initiation of a call on a second of said lines, means at said switching center for impressing voltage on the other side of said trunk in response to the initiation of a call on a third of said lines, an operator's position in said exchange, signal devices at said operator's position individually corresponding to said lines, control means selectively controlled by said voltages for energizing said signal devices only when calls are initiated on the respective corresponding lines, and means at said switching center revertively controlled by said control means over said trunk for preventing said first and second-named means from operating in response to a call initiated on one of said lines when said trunk is occupied with a call.

41. In a telephone system, a switching center, at least three lines extending to said switching center, an exchange, a trunk interconnecting said exchange and said switching center, means at said switching center for impressing voltage of one polarity on one side of said trunk in response to the initiation of a call on one of said lines and for impressing voltage of opposite polarity on said one side of said trunk in response to the initiation of a call on a second of said lines, means at said switching center for impressing voltage on the other side of said trunk in response to the initiation of a call on a third of said lines, an operator's position, means including a finder switch having access to said trunk in said exchange for extending a connection from said trunk to said operator's position, and control means operative in response to the application of any one of said voltages to said trunk for causing said finder switch to seize said trunk.

42. In a telephone system, a switching center, at least three lines extending to said switching center, an exchange, a trunk interconnecting said exchange and said switching center, means at said switching center for impressing voltage of one polarity on one side of said trunk in response

to the initiation of a call on one of said lines and for impressing voltage of opposite polarity on said one side of said trunk in response to the initiation of a call on a second of said lines, means at said switching center for impressing voltage on the other side of said trunk in response to the initiation of a call on a third of said lines, an operator's position, means including a finder switch having access to said trunk in said exchange for extending a connection from said trunk to said operator's position, control means operative in response to the application of any one of said voltages to said trunk for causing said finder switch to seize said trunk, and means at said switching center revertively controlled by said control means over said trunk for preventing said first-named means from operating in response to a call initiated on one of said lines when said trunk is occupied with a call.

43. In a telephone system, a switching center, a pair of lines extending to said switching center, an exchange, a trunk interconnecting said switching center and said exchange, means for selectively impressing ringing voltages upon said lines, means at said switching center for rectifying said voltages and for impressing the rectified voltages on said trunk with opposite polarities, and control means in said exchange selectively controlled in accordance with the polarities of said rectified voltages.

44. In a telephone system, a switching center, a pair of lines extending to said switching center, an exchange, a trunk interconnecting said switching center and said exchange, means for selectively impressing ringing voltages upon said lines, thereby to initiate calls on said lines, means including a rectifier at said switching center for rectifying ringing voltage impressed on one of said lines and for impressing the rectified voltage on said trunk, means including a second rectifier at said switching center for rectifying ringing voltage impressed on the other of said lines and for impressing the rectified voltage on said trunk, said rectifiers being so connected and arranged that said rectified voltages are impressed on said trunk with opposite polarities, an operator's position, signal devices at said operator's position individually corresponding to said lines, and means operative in response to the application of voltage of one polarity to said trunk for energizing one of said signal devices and operative in response to the application of voltage of the opposite polarity to said trunk for energizing the other of said signal devices.

45. In a telephone system, a switching center, a pair of lines extending to said switching center, an exchange, a trunk interconnecting said switching center and said exchange, means for selectively impressing ringing voltages upon said lines, means at said switching center for rectifying said voltages and for impressing the rectified voltages on said trunk with opposite polarities, an operator's position, signal devices at said operator's position individually corresponding to said lines, control means in said exchange selectively controlled by said voltages of opposite polarities impressed on said trunk for selectively energizing said signal devices, and means operative in response to the answering of a call routed from one of said lines to said operator's position for preventing said rectifying means from operating in response to ringing voltage impressed upon the other of said lines.

46. In a telephone system, a switching center,

a pair of lines extending to said switching center, an exchange, a trunk interconnecting said switching center and said exchange, means for selectively impressing ringing voltages upon said lines, means at said switching center for rectifying said voltages and for impressing the rectified voltages on said trunk with opposite polarities, an operator's position, means including a finder switch having access to said trunk in said exchange for extending a connection from said trunk to said operator's position, and control means operative in response to the application of either of said rectified voltages to said trunk for causing said finder switch to seize said trunk.

47. In a telephone system, a switching center, a pair of lines extending to said switching center, an exchange, a trunk interconnecting said switching center and said exchange, means for selectively impressing ringing voltages upon said lines, means at said switching center for rectifying said voltages and for impressing the rectified voltages on said trunk with opposite polarities, an operator's position, means including a finder switch having access to said trunk in said exchange for extending a connection from said trunk to said operator's position, control means operative in response to the application of either of said rectified voltages to said trunk for causing said finder switch to seize said trunk, and means at said switching center revertively controlled by said control means over said trunk for preventing said rectifying means from rectifying ringing voltage impressed on one of said lines when the other of said lines is occupied with a call.

48. In a telephone system, a switching center, at least three lines extending to said switching center, an exchange, a trunk interconnecting said exchange and said switching center, means for selectively impressing ringing voltages on said lines, means at said switching center for rectifying said voltages as impressed on two of said lines and for impressing the rectified voltages on one side of said trunk with opposite polarities, means at said switching center for impressing ringing voltage impressed on a third of said lines on the other side of said trunk, and control means in said exchange selectively controlled by said voltages.

49. In a telephone system, a switching center, at least three lines extending to said switching center, an exchange, a trunk interconnecting said exchange and said switching center, means for selectively impressing ringing voltages on said lines, means at said switching center for rectifying said voltages as impressed on two of said lines and for impressing the rectified voltages on one side of said trunk with opposite polarities, means at said switching center for impressing ringing voltage impressed on the third of said lines on the other side of said trunk, an operator's position, signal devices at said operator's position individually corresponding to said lines, and control means selectively controlled by the voltages impressed on said trunk for selectively energizing said signal devices.

50. In a telephone system, a switching center, at least three lines extending to said switching center, an exchange, a trunk interconnecting said exchange and said switching center, means for selectively impressing ringing voltages on said lines, means at said switching center for rectifying said voltages as impressed on two of said lines and for impressing the rectified voltages on one side of said trunk with opposite polarities, means

at said switching center for impressing ringing voltage impressed on the third of said lines on the other side of said trunk, control means in said exchange selectively controlled by said voltages, and means at said switching center revertively controlled over said trunk by said control means for preventing more than one of said voltages from being impressed on said trunk at the same time.

51. In a telephone system, a switching center, at least three lines extending to said switching center, an exchange, a trunk interconnecting said exchange and said switching center, means for selectively impressing ringing voltages on said lines, means at said switching center for rectifying said voltages as impressed on two of said lines and for impressing the rectified voltages on one side of said trunk with opposite polarities, means at said switching center for impressing ringing voltage impressed on the third of said lines on the other side of said trunk, an operator's position, means including a finder switch having access to said trunk in said exchange for extending a connection from said trunk to said operator's position, and control means operative in response to the application of any one of said voltages to said trunk for causing said finder switch to seize said trunk.

52. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means controllable through said connector switch from said operator's position for selectively impressing control voltages on the two sides of said trunk, and means at said switching center selectively energized by said voltages for selectively connecting said lines to said trunk.

53. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means controllable through said connector switch from said operator's position for selectively impressing control voltages of different polarities on said trunk, and means at said switching center selectively energized by said control voltages of different polarities for selectively connecting said lines to said trunk.

54. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means controllable through said connector switch from said operator's position for selectively impressing control voltages of different polarities on different sides of said trunk, and means at said switching center selectively energized by said control voltages of different polarities impressed on different sides

of said trunk for selectively connecting said lines to said trunk.

55. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means comprising impulse-responsive switching apparatus controllable through said connector switch from said operator's position for selectively impressing control voltages on the two sides of said trunk, and means at said switching center selectively energized by said voltages for selectively connecting said lines to said trunk.

56. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means comprising impulse responsive switching apparatus controllable through said connector switch from said operator's position for selectively impressing control voltages of different polarities on said trunk, and means at said switching center selectively energized by said control voltages of different polarities for selectively connecting said lines to said trunk.

57. In a telephone system, a switching center, a plurality of lines extending to said switching center, an exchange, a trunk interconnecting said switching center and said exchange, a link in said exchange including finder and connector switches each having access to said trunk, an operator's position, means including said finder switch for routing a call initiated on one of said lines to said operator's position, means comprising impulse responsive switching apparatus controllable through said connector switch from said operator's position for selectively impressing control voltages of different polarities on different sides of said trunk, and means at said switching center selectively energized by said control voltages of different polarities impressed on different sides of said trunk for selectively connecting said lines to said trunk.

58. In a telephone system, a switching center, a plurality of lines extending to said switching center, an exchange, a trunk interconnecting said exchange and said switching center, a link in said exchange including finder and connector switches having access to said trunk, an operator's position, means in said exchange operative in response to the initiation of a call on one of said lines for causing said finder switch to seize said trunk, thereby to route the call to said operator's position, and for impressing a predetermined voltage on one side of said trunk, means at said switching center energized by said voltage for connecting the calling line to said trunk, means controllable through said connector switch from said operator's position for impressing a control voltage on the other side of said trunk, and means at said switching center energized by said last-named voltage for connecting the calling line to a called one of said lines.

59. In a telephone system, a switching center, a plurality of lines extending to said switching

center, an exchange, a trunk interconnecting said exchange and said switching center, a link in said exchange including finder and connector switches having access to said trunk, an operator's position, means in said exchange operative in response to the initiation of a call on one of said lines for causing said finder switch to seize said trunk, thereby to route the call to said operator's position, and for impressing a predetermined voltage on one side of said trunk, means at said switching center energized by said voltage for connecting the calling line to said trunk, means controllable through said connector switch from said operator's position for selectively impressing control voltages of different polarities on the other side of said trunk, and means at said switching center selectively energized by said voltages of different polarities impressed on the other side of said trunk for selectively connecting the calling line to any called one of said lines.

60. In a telephone system, a switching center, a plurality of lines extending to said switching center, an exchange, a trunk interconnecting said exchange and said switching center, a link in said exchange including finder and connector switches having access to said trunk, an operator's position, means in said exchange operative in response to the initiation of a call on one of said lines for causing said finder switch to seize said trunk, thereby to route the call to said operator's position, and for impressing a predetermined voltage on one side of said trunk, means at said switching center energized by said voltage for connecting the calling line to said trunk, and means controllable from said operator's position through said connector switch for selectively deenergizing and energizing said last-named means.

61. In a telephone system, a switching center, a plurality of lines extending to said switching center, an exchange, a trunk interconnecting said exchange and said switching center, a link in said exchange including finder and connector switches having access to said trunk, an operator's position, means in said exchange operative in response to the initiation of a call on one of said lines for causing said finder switch to seize said trunk, thereby to route the call to said operator's position, and for impressing a predetermined voltage on one side of said trunk, means at said switching center energized by said voltage for connecting the calling line to said trunk, means selectively controllable from said operator's position through said connector switch for selectively deenergizing and energizing said last-named means, means controllable through said connector switch from said operator's position for impressing a control voltage on the other side of said trunk, and means at said switching center energized by said last-named voltage for connecting the calling line to a called one of said lines.

62. In a telephone system, a switching center, a plurality of lines extending to said switching center, an exchange, a trunk interconnecting said exchange and said switching center, a telephone station, a line selecting switch in said exchange having access to said trunk, means in said exchange controllable through said line selecting switch from said telephone station for selectively impressing control voltages upon different sides of said trunk, and means at said switching center selectively energized by said control voltages for selectively connecting said lines to said trunk.

63. In a telephone system, a switching center,

a plurality of lines extending to said switching center, an exchange, a trunk interconnecting said exchange and said switching center, a telephone station, a line selecting switch in said exchange having access to said trunk, means in said exchange controllable through said line selecting switch from said telephone station for selectively impressing control voltages of different polarities upon said trunk, and means at said switching center selectively energized by said control voltages of different polarities for selectively connecting said lines to said trunk.

64. In a telephone system, a switching center, a plurality of lines extending to said switching center, an exchange, a trunk interconnecting said exchange and said switching center, a telephone station, a line selecting switch in said exchange having access to said trunk, means in said exchange controllable through said line selecting switch from said telephone station for selectively impressing control voltages of different polarities upon either side of said trunk, and means at said switching center selectively energized by said voltages of different polarities impressed upon the different sizes of said trunk for selectively connecting said lines to said trunk.

65. In a telephone system, a switching center, a plurality of lines extending to said switching center, an exchange, a trunk interconnecting said exchange and said switching center, a telephone station, a line selecting switch in said exchange having access to said trunk, means comprising impulse responsive apparatus controllable through said line selecting switch from said telephone station for selectively impressing control voltages on the two sides of said trunk, and means at said switching center selectively energized by said voltages for connecting the calling line to said trunk.

66. In a telephone system, a switching center, a plurality of lines extending to said switching center, an exchange, a trunk interconnecting said exchange and said switching center, a telephone station, a line selecting switch in said exchange having access to said trunk, means comprising

5 impulse responsive apparatus controllable through said line selecting switch from said telephone station for selectively impressing control voltages of different polarities upon said trunk, and means at said switching center selectively energized by said voltages of different polarities impressed upon said trunk for selectively connecting said lines to said trunk.

67. In a telephone system, a switching center, first and second lines extending to said switching center, an exchange, a trunk interconnecting said exchange and said switching center, a circuit network at said switching center including means controlled in accordance with the direction of current flow in said network for selectively connecting said first and second lines to said trunk, a circuit including said trunk line for conducting current to said network, a telephone station, a line selecting switch in said exchange having access to said trunk, and means controllable through said line selecting switch from said station for completing said circuit and for selectively determining the direction of current flow through said circuit network.

68. In a telephone system, a switching center, first and second lines extending to said switching center, an exchange, a trunk interconnecting said exchange and said switching center, a circuit network at said switching center including means controlled in accordance with the direction of current flow in said network for selectively connecting said first and second lines to said trunk, a circuit including said trunk line for conducting current to said network, a telephone station, a line selecting switch in said exchange and directly controllable from said telephone station to seize said trunk, and means comprising impulse responsive apparatus controllable through said line selecting switch from said telephone station for completing said circuit and for determining the direction of current flow through said circuit network.
